FIG. 36

UNITED STATES PATENT OFFICE

HANNIBAL C. FORD, OF JAMAICA, NEW YORK, ASSIGNOR TO FORD INSTRUMENT COMPANY, INC., OF LONG ISLAND CITY, NEW YORK, A CORPORATION OF NEW YORK

ARTILLERY COMPUTING SYSTEM

Application filed October 16, 1924. Serial No. 744,052.

This invention relates to a method of and means for controlling the fire of guns, and it is especially adapted to directing the fire of coast defense guns against a moving 5 target, such as hostile warcraft.

A purpose of this invention is to bring into existence such a system as has been indicated, which shall in all respect be accurately adjusted to the requirements of warfare in its most recently developed aspect. Since the high-powered ordnance of the present enables an approaching enemy to fire at a range that renders him nearly invisible, the point blank and close range firing of earlier 15 periods, when the contending forces were comparatively close to each other, is rendered obsolete, and errors, which in those times might be ignored, would now result in gross ineffectiveness.

It is accordingly proposed to eliminate the deficiencies of former practice and to substitute therefor mathematical precision by the use of electrical and mechanical means. Even at the present time, though gun development has greatly increased the range capacities of ordnance, the method of controlling the aiming of the guns has not correspondingly improved, the result being that, though the guns are able to efficiently meet 25 the exigencies of a situation, they are dependent upon what may be aptly termed hand-computation, and the loss of time involved tends to nullify the improved efficiency of the guns. The truth of this may readily be appreciated, when it is understood that with a projectile leaving a modern gun at the velocity of 3000 feet per second, it still requires nearly two minutes for it to reach a target at a maximum range. In 35 that time a swift battle cruiser is capable of traveling about a mile and a half, from which it may be seen that the gunner is not aiming at the target at all, but at some predicted point in advance of the target, which 45 he cannot even see.

As the gunners, therefore, are dependent upon instructions which can only be given after computation, and, as, at present, these computations are mental efforts that find expression through and are restricted to the ra-

pidity of the manipulation of the hand, which is apt to be much slower than the mental processes of the calculator, it becomes at once apparent that recourse must be had to short cuts and approximations. There is, 55 of course, a consequent loss of accuracy in gun fire. When it is realized that, in future artillery duels, salvos will be exchanged at the rate of two or three per minute, and that the calculations pre-requisite to the aiming 60 of the guns must take into account the amount the projectile will swerve from the true path, involving allowances for such quantities as the temperature of the powder just prior to firing, the direction and velocity of the wind, the drift due to the spin of the shell, the barometric pressure, and so on, it is clear that there is insufficient time to properly and accurately calculate the pointing 65 of the guns between succeeding salvos. 70 Yet, without proper aiming, the most modern guns are as valueless as antiquated ones, the shorter range capacities of which did not multiply errors as greatly as the longer range capabilities of present day rifles. 75

The herein disclosed system of fire control contemplates the continuous transmitting of the training of the observer's telescope, obviating the inaccuracies involved in making intermittent observations at long ranges. 80 Moreover, the system permits of advantageous flexibility in the selection of observing stations, and in changing stations during an engagement. If the view of the target is or becomes obscured from the observing stations, as by an enemy smoke screen, or otherwise, the automatic computation of firing data is continued through the agency of airplane observations, to the use of which the system is adjustable, this constituting an ac- 85 complishment hitherto unattained. 90

A plurality of observing stations, for instance, two, are included in the system, and there is a normal transmission of observed data from them to a computing instrument, 95 which may be descriptively referred to as the target computer. It functions to compute the range and azimuth of the target from a reference point and plots these quantities against time. From the slopes of resultant 100

curves, means with which the target computer is provided determines the target's course and speed and generate target range and azimuth which the target computer continually transmits to another instrument which may be called the battery computer.

The latter instrument determines the advanced range and azimuth of the target from the battery position due to movement of the target during time of flight of the projectile, as computed by the instrument. It also computes the ballistic corrections for atmosphere, initial velocity, wind, height of battery and drift. The battery computer adds these corrections to the advanced range, and to the sum it adds the firing corrections, or "spots", giving the final corrected range and azimuth of the target, which is electrically transmitted to the battery, where it is used for setting 20 the guns.

Without any intention of imposing limitations upon the possibilities and restrictions as to the ramifications of this invention, it may be stated that one way of practising the same is to use a target computer for each target on which it is regarded as necessary or advisable to concentrate gun fire at any one time. Each target computer is adapted to receive data from, say, two available observing stations, and to direct the fire of any number of batteries. Ordinarily, there will be one battery computer for each battery, the guns of which are so designed and located that they can use common ballistic data.

With the system comprised in this invention, there is a very material saving in the personnel, it requiring comparatively few operators, thereby lessening the requirement for the maintenance and training of a large staff 40 of skilled operators.

The operating process in its entirety takes place almost instantaneously, so that the complete information is available at the guns within a few seconds after the observations 45 have been made, and the computers, not being human, coldly and dispassionately proceed with their work in marked contrast to the high nervous tension that develops in the officers and men under the excitement of battle conditions. Since all the calculations are 50 performed by the instruments, there is no chance of personal error. Records are made of the range and azimuth of the target's position both with respect to the reference point 55 and the battery, which records are available for future inspection and study.

The employment of the herein described system not only effects a high degree of efficiency, but produces economy, the investment 60 in high powered ordnance becoming more fully warranted by the effectiveness the artillery computing system endows it with, which in turn so much more securely protects the coast that the cost sinks into insignificance as compared with the mammoth losses

possible as the result of an inadequately defended coast line.

Other features and advantages becoming apparent hereinafter are, of course, to be understood as forming part of the invention, and various alterations and modifications may be indulged in without departing from the spirit of this invention as defined by the appended claims.

In the drawings,

Fig. 1 is a diagram illustrating a typical coast defense problem as presented by modern conditions, the solution of which may be expeditiously accomplished by the herein disclosed system and apparatus;

Fig. 2 is another diagram, showing variously located apparatus embodied in the system and indicating the interconnection of correlated portions thereof;

Figs. 3, 4, 5 and 6 are mechanical diagrams of mechanism, which are mutually complementary and co-operative to effect a unitary diagrammatic illustration of an instrument which may be appropriately termed the target computer;

Fig. 7 is a miniature diagram, showing the proper arrangement of the sheets of drawings containing Figs. 3, 4, 5 and 6 whereby the latter merge, in effect, into a single diagram;

Fig. 8 is a fragmentary section through the plotter portion of Fig. 6, and illustrates the method and means for controlling the record paper;

Fig. 9 is a vertical detail section through the range and azimuth gears and range screw shown as mounted upon a slide in Fig. 3, the section being taken on the line 9-9 of the latter figure;

Fig. 10 is a similar section taken on the line 10-10 of Fig. 3, through another set of range and azimuth gears and a different range screw, which are co-operatively combined with the set shown in Fig. 9;

Fig. 11 is a view somewhat similar to Fig. 8, but is taken on the line 11-11 of Fig. 6, through the target course and speed gears and crank;

Fig. 12 is a vertical section taken on the line 12-12 of Fig. 4 showing the generated 115 and observed azimuth dials, as well as the target course pointer, together with the driving shafts therefor;

Fig. 13 is a detached view of the range scale bar associated with the plotter of the 120 target computer, showing one set of graduations;

Fig. 14 is a similar view of the same bar but showing an adjacent face bearing another set of graduations;

Fig. 15 shows another scale bar bearing azimuth graduations used at times when the target computer is conformed to longer ranges;

Fig. 16 shows the scale bar of Fig. 15 pre- 125

senting the azimuth graduations associated with calculations for the shorter ranges;

Fig. 17 is a sectional view of one of the clutches of the instrument;

Fig. 18 is a view showing the pitch circles of the gearing of the clutch;

Fig. 19 is a view of one of the controlling devices;

Fig. 20 is a plan view of value-changing means for adjusting the target computer to the magnitude of the problem;

Fig. 21 is an elevational view of the parts shown in Fig. 20, and discloses additional value-changing means;

Fig. 22 is a diagrammatic view of one of the variable transmitters shown in Fig. 21;

Figs. 23 and 24 are complementary subdivisions of a wiring diagram of the controls adapted to be set up in the target computer;

Fig. 25 is another wiring diagram illustrating the means for operating and controlling the plotting pencils of the target computer;

Figs. 26 to 33 inclusive are mechanical diagrams of mechanism, which are mutually complementary and co-operate to effect a unitary diagrammatic illustration of an instrument aptly termed the battery computer;

Fig. 34 (Sheet 13) is a miniature diagram showing the proper arrangement of the sheets of drawings containing Figs. 26 to 33 inclusive, whereby these views are combined to constitute a unitary diagram;

Fig. 35 is an electrical diagram of wiring in the battery computer;

Fig. 36 is another electrical diagram similar to that of Fig. 25, but showing means for operating and controlling the plotting pencils of the battery computer;

Fig. 37 (Sheet 11) is a diagrammatic view of one of the magnetic locks for a shaft affecting the base line setting;

Fig. 38 (Sheet 1) is a diagram of a problem requiring the employment of the A control for the target computer;

Fig. 39 is a diagram of another problem to be suited to which the target computer is operated under the A control;

Fig. 40 is a segregated portion of the problem of Fig. 1, which is treated by the battery computer;

Fig. 41 (Sheet 13) illustrates a time of flight graph;

Fig. 42 shows a wind vector diagram; and

Fig. 43 is a diagram illustrating the manner in which the base lines of the problem of Fig. 1 are arranged to be coincident with the zero line of the instrument.

Referring now to the drawings, the diagram shown in Fig. 1 represents a typical coast artillery layout, wherein A and B denote base-end observing stations, from which the movements of the target R are optically followed. P represents an arbitrary reference point, while G shows the position of the battery. Fig. 1 shows that these various lo-

cations are at vertices of a triangulation wherein PA and PB are auxiliary base lines whose lengths PA and PB and azimuths MPA and MPB are accurately known, having been determined by surveying. PG is another base line of a further triangle whose other two sides are PR and GR, and the length and azimuth of base line PG is also accurately determined by surveying. The line M—N is a common zero reference line, which may be the usual North and South line, or any other convenient line, which will be referred to later.

In view of the foregoing it may now be understood that the line AR represents the line of sight from the observing station A, while the line BR denotes the line of sight from the observing station B. The line PR from the reference point P is termed and gives a measure of reference point range. A line GR from the battery G to the target R represents what may be termed relocated range, since it is the range of the target as it is relocated to the battery. It is to be noted that the target R is shown in dotted lines at R' in an advanced position, and this represents the position to which the target will have travelled from the place it occupied when its range was considered at the reference point P to the location where a projectile from the battery G will meet it. The line GR', therefore, is indicative of advance range, which, after it has corrections for temperature, the direction and velocity of the wind, drift of the shell, the barometric pressure, height of the battery, and the like algebraically added to it, results in the final corrected range supplied to the guns by the battery computer.

In the diagram of Fig. 1, the target's course and speed are indicated by the vector R—D, which, as considered at the reference point P, may be resolved into two components, one R—R^a which is in the direction of the reference point range line P—R and is proportional to the range rate due to the change of the target's position, the other component, R^a—D, being perpendicular to the reference point range line and is proportional to the rate of the target's deflection.

The vector R—D representing the target's course may also be resolved into another pair of components, as considered in connection with the battery position. In this case, the component R—R^b is in the direction of the line of sight from the battery G, and is proportional to the relocated range rate, while the other component R^b—D is proportional to the rate of the target's deflection.

Reference to Fig. 2 will serve to improve the comprehension of the distribution of the apparatus of the artillery system as applied to the coast defense layout illustrated in Fig. 1. The observing, sending and receiving devices symbolically shown in enclosures marked A-station and B-station, in Fig. 2,

are located, respectively, at A and B in Fig. 1. The target computer is associated with the reference point P, and may be located at P in Fig. 1, though not necessarily so, since it 5 may take account of the reference point, and, in some instances be located elsewhere, if that for any reason be more advisable. Similarly, the battery computer, while naturally thought of in connection with the battery G, 10 of Fig. 1, may be either there, or, it may be elsewhere but in communication with the battery G. It will be obvious, however, that the gun range and gun train receiving instrument indicated in the enclosure of Fig. 2 that bears 15 the legend "Battery" are at the guns, since they disclose directly to the gunners the gun elevation and train to be given to the guns.

In ordinary practice, an enemy fleet will be "picked up" telescopically by either the 20 A-station or the B-station, which immediately informs the other of these stations, as by telephone, since they may be some miles apart. Thereupon both stations become active, and both transmit data to the target 25 computer simultaneously or intermittently, according to the controlling conditions of circumstance.

When the atmospheric conditions develop 30 low visibility, it is quite possible that, while the observing station nearest the on-coming enemy may discover him, the other station will not be able to discern the hostile craft. Or, a smoke screen may obscure the view of 35 one of the observing stations, and in all such cases, where but one of the stations can see the enemy, that station will furnish data to the target computer as long as the other observing station is excluded from participation. In the meantime, the target computer 40 will compute the reference point range and azimuth from the data received from the sending observation station for comparison with generated reference point range. If, for any reason, such as an enemy-developed 45 smoke screen, both observing stations A and B are rendered temporarily useless, or should become destroyed, the target computer may continue functioning by receiving data from airplane observations. Different controls 50 are rendered effective in the target computer, according to the requirements of circumstances, as hereinafter explained.

Normally, the telescopes 1a at the A station and 1b at the B station train continuously on 55 the target and their movements in azimuth are continuously and automatically sent by transmitters 2a and 2b, through cables 3a and 3b to the receiver motors 4a and 4b, respectively, which are in the target computer. 60 Other transmitters 5a and 5b, which form part of the target computer, act in response to azimuth measurements developed in the latter instrument, as later set forth, and by cables 6a and 6b operate receiver motors 7a 65 and 7b, in the A and B observing stations, re-

spectively, which cause indicators 8a and 8b in these stations to show the target's azimuth as indicated by the target computer. Thus, the target computer is supplied with measures of the target's azimuth from both the observing stations A and B, and, in turn, these stations are informed as to the target's azimuth used by the target computer, whereby a check on the accuracy is constantly maintained.

From available sources at the A and B observing stations, such as range finders, the range readings of counters or indicators 9a and 9b are sent by transmitters 10a and 10b and cables 11a and 11b to range receiver motors 12a and 12b, which form part of the target computer. Ranges AR and BR indicated by this instrument are sent by transmitters 13a and 13b thereof and cables 14a and 14b to receiver motors 15a and 15b in the A and B stations, respectively, which operate the range indicators 16a and 16b.

The target computer is provided with a transmitter 17 which sends the azimuth of reference point range by cable 18 to a receiver motor 19 in the battery computer. Reference point range is sent from the target computer by a transmitter 20 and cable 21 to a reference point receiver motor 22 in the battery computer. Furthermore, the target's course and speed are sent by transmitters 23 and 24, respectively, through cables 25 and 26 from the target computer to receiver motors 27 and 28 in the battery computer.

The final corrected relocated range is sent from the battery computer, by a transmitter 29 and cable 30 to a gun range indicator 31 at the battery. The azimuth for this range is sent from the battery computer by a transmitter 32 and cable 33 to a gun train indicator 34 at the battery.

A typical coast defense problem having been set forth and described in connection with Fig. 1, and an outline of the distribution of the artillery computer system having been traced in Fig. 2 in connection with the relation of the latter figure to Fig. 1, it will now be possible to investigate more intimately the working of the artillery system within the instruments known as the target and battery computers.

First taking the target computer under consideration, and arranging the sheets of drawings containing Figs. 3, 4, 5 and 6 as indicated in Fig. 7, let it be assumed that the A observing station has discovered an enemy fleet. Observing station B will be immediately notified, and both stations will train their telescopes 1a and 1b, respectively, (shown in Fig. 2), upon the enemy, if vision from both stations is possible. The station A azimuth transmitter 2a and station B azimuth transmitter 2b are automatically operable with and in proportion to the movements of the telescopes 1a and 1b with which they are

- associated, and consequently the azimuths of the lines of sight to the target are automatically transmitted by means of cables 3a and 3b from stations A and B to the receiver 5 motors 4a and 4b, which are included in the elements composing the target computer. The receiver motors 4a and 4b are indicated in Figs. 3 and 5, respectively, at opposite sides of the target computer.
- 10 In the interests of clear comprehension, it is here pointed out that the target computer has natural subdivisions, which have been adhered to in its physical arrangement. Accordingly, the mechanism shown in Fig. 3 is, 15 in general, responsive to data received from the A observing station, while the mechanism of Fig. 5 responds to information from the B observing station. Fig. 4 shows mechanism which treats of the reference point conditions, and Fig. 6 deals with range and azimuth generating means of the target computer, as related to the reference point of the problem. Also, disclosed in Fig. 6 is plotting mechanism for graphically recording reference point range and azimuth.

While the azimuths of the lines of sight from stations A and B are automatically transmitted, the ranges from these stations are determined in the usual manner, as with 30 range finders, and at each station the range is set up on a range indicator, 9a at station A and 9b at station B. Automatically operable with and in proportion to the actuation of the range indicators 9a and 9b are range transmitters 10a at the A station and 10b at the B station, which through cables 11a and 11b produce responsive movement in the receiver motor 12a in Fig. 3 and receiver motor 12b in Fig. 5.

40 Therefore, the magnitudes of the line of sight AR from the A station and the line of sight BR from the B station, together with azimuth AZ of AR and the azimuth BZ of BR, have been translated into movements of 45 corresponding receiver motors in proportion to the values of the above quantities.

It is evident that, as the enemy approaches, the triangulation of imaginary lines shown in Fig. 1 changes in form and values, and to 50 insure smooth operation of the target computer, irrespective of the position of the target, this instrument is provided with a so-called control knob 35, shown in Fig. 23, which knob is shifted by the operator as the 55 target passes from one control region to another. These control regions are sub-divisions of a charted harbor, and as the target becomes located in one of these sub-divisional areas, the operator will turn the control knob 60 35, which through shaft 36 and gearing 37 sets the control dial 38 to read against an index to show what particular control has been effected.

As seen in Fig. 23, the graduations of the 65 control dial are effected by identifications of

the various controls, and these are seen, in the form illustrated, to designate the following controls: A, a, Ab, P, Ba, B and b, O indicating the off-position of the control knob.

The explanation of the above control designations is that the large letter signifies that the azimuth from the observing station identified by such letter controls the reference point range, and the small letter in the control designations signifies that the range from the station identified by that letter controls the reference point azimuth. This will be more fully understood from the following tabulation:

Control	Reference point azimuth controlled by:	Reference point range controlled by:
A	A station range	A station azimuth
a	A station azimuth	A station range
Ab	B station azimuth	A station azimuth
P	Generated azimuth	Generated range
Ba	A station azimuth	B station azimuth
B	B station range	B station azimuth
b	B station azimuth	B station range

In the operation of the target computer, three general conditions determine the selection of the control, and are dependent upon the manner in which data are received from the observing stations, as set forth in the following cases:

Case I

When receiving azimuth from two fixed observing stations, Ab or Ba controls should be used. The one to use will be found from the chart. In general, the Ab control is used when the angle ARP, in Fig. 1, is greater than the angle BRP, the Ba control being used when the angle BRP is greater than the angle ARP.

Case II

When receiving range and azimuth from a single fixed observing station, if it be the A observing station, A or a control will be used; if it be from the B observing station, B or b control will be used. The proper control will be shown by the chart.

In general, the following rule applies:

A control is used when receiving range and azimuth from the A station and the angle ARP, in Fig. 1, is greater than 45°.

a control is used when receiving range and azimuth from the B station and the angle BRP, in Fig. 1, is greater than 45°.

b control is used when receiving range and azimuth from the B station and the angle BRP, in Fig. 1, is less than 45°.

Case III

When receiving target course and speed only, from airplane observations, P control will be used. This control is also used for the initial setting of the target computer, and for test purposes. It is also used in releasing the target computer and restoring it to nor-

mal after it has been stalled by being operated beyond some of the limits of the mechanism for which one of the other control positions may not be adapted.

5 In the harbor chart showing the location on the various observing stations and the reference point, the co-ordinate of the observing stations will be noted together with the designation as to whether the station is to be considered as an A station or a B station. This will depend upon the relative location of the stations with respect to the defended portion of the harbor. The latter will be divided into sections properly lettered to denote which particular control position is to be used in each of the first two general cases.

In addition to selecting the proper control under which to operate the target computer, the operator thereof must consider the magnitude of the field of operations, which may be regarded as falling within two classes, to wit: those involving relatively high and low values, or, in other words, long and short range problems. For example, if it be desired to open an engagement soon after the discovery of the presence of the enemy, before he gets into close range, the target computer will be set to deal with high values commensurate with the extent of the field of operations, whereas, at shorter ranges the instrument will be reset in harmony with the lessened values. Accordingly, the target computer is, in its illustrated form, designed to operate either at "low ranges" varying from 5000 to 25000 yards, or at "long ranges" of 10000 to 50000 yards. In the drawings, the target computer is set to operate for low ranges.

40 In adjusting the target computer to the problem presented, the auxiliary base lines PA and PB are set up by turning the handle αL in Fig. 3 for the former, and the handle βL , in Fig. 5 for the latter. Handle αL turns shaft 39, in Fig. 3, comprising separable parts joined by a coupling. The shaft 39, through gears 40, turns another shaft 41, a worm 42 thereon turning a worm wheel 43 secured to a shaft 44, that has a threaded portion that is screwed into a nut-like part of a slide 45, included in the target computer portion that is associated with the A station.

A pointer 46 from the slide 45 moves along a changeable scale 47, showing "thousands of yards", and shown to be set for low values, until the magnitude of the base line PA is set off. The PA setting shaft 39, through gears 48 turn a pointer 49 to read against a changeable annular minor value scale 50, readable in "hundreds of yards". The combined reading of the two scales 47 and 50, in the present instance, equals approximately 7,937 yards, which is the linear extent of the base line PA, in Fig. 1.

65 Likewise, the handle βL , in Fig. 5, turns a

shaft 51, which through gears 52 turn another shaft 53, which carries a worm 54 that imparts rotary movement to a worm wheel 55 that is mounted on a shaft 56. This shaft has a screw-threaded portion that is screwed into a nut-like part of a slide 57, which is associated with the target computer subdivision that is affiliated with the B observing station.

Extending from slide 57 is a pointer 58 that reads against a changeable scale 59, graduated to read in "thousands of yards". Shaft 51, through other gears 60, turns a rotary pointer 61 that reads against a changeable annular minor scale 62, readable in "hundreds of yards". The combined reading of the two scales 59 and 62 is approximately 3625 yards, which is the linear measure of the base line PB, in Fig. 1.

When the proper reading in yards shall have been set up for the base line PA, as described, the common center of the A station azimuth gear 91 and the A station range gear 92, shown in Fig. 3, will have been placed the proper distance from the common center of the reference point azimuth and range gears 93 and 94, respectively, to establish a setting proportional to the reading shown by the PA length scales 47 and 49. In the same way, the common center of the B station azimuth and range gears 95 and 96, to be seen in Fig. 5, are properly spaced from the reference azimuth and range gears 93a and 94a, also shown in Fig. 5.

The azimuth of the base lines PA and PB is read on pairs of circular dials, the azimuth of the line PA being read on the dials 63 and 64 against fixed indices 65 and 66, respectively, in Fig. 3, while the azimuth of the line PB is read on the dials 67 and 68, in Fig. 5, against fixed indices 69 and 70, respectively. It is accordingly seen that, in Fig. 3, the azimuth of line PA of Fig. 1 is shown by the two dials 63 and 64 to be substantially 13.75° , or $13^\circ 45'$; the azimuth of the line PB of Fig. 1 being observed in Fig. 5, to give a reading on dials 67 and 68 of about 153.75° or $153^\circ 45'$. The major dials 63 and 67 are divided into 360° , while one revolution of each of the minor dials 64 and 68 is equivalent to 1° , i. e., one of the minor subdivisions of the major scales, the single degree circumscribing each minor dial 64 and 68 having fractional subdivisions decimal expressed.

To set up the readings of the azimuth of the base lines PA and PB, on the dials above referred to, the handles αL and βL are turned. First considering the effect of turning handle αL , shown in Fig. 3, it will be seen that the shaft 71 responsively turns, and through gears 72 turns another shaft 73, which continues to drive through gears 74, shaft 75, gears 76, thereby rotating a shaft 77. The shaft 77 drives spiral gears 78, one of which is related to and effects the turning of the

minor PA azimuth dial 64. The shaft 77 also carries a worm 79 which turns a worm wheel 80 and the major PA azimuth dial 63 with it.

5 In like manner, the actuation of handle βL , in Fig. 5 turns a shaft 81, gears 82, another shaft 83, gears 84, shaft 85, and through other gears 86 turns a shaft 87. The last named shaft drives spiral gears 88, which 10 turn the minor PB azimuth dial 68. The shaft 87 also carries a worm 89 that turns a worm wheel 90 and the major PB azimuth dial 67 operable therewith.

15 In addition to setting the dials 63 and 64, in Fig. 3, and dials 67 and 68, in Fig. 5, to give readings of azimuth for the base lines PA and PB, the operation of handles αL and βL effect other results. The handle αL sets the center 97' of a differential aX , in Fig. 3, 20 the handle βL also setting the center 311' of a differential bX , in Fig. 5. The effect of setting the centers 97' and 311' of the differentials aX and bX is to shift the bases of the 25 triangles ARP and BRP to zero. Reference to Fig. 43 shows how the base lines PA and PB thereby become coincident with the zero line MN. In this way, the triangles ARP and BRP, which, of course, from a geographical viewpoint actually remain related as depicted in the problem of Fig. 1, are separated 30 for mathematical treatment in the target computer in accordance with the physical arrangement of the natural subdivisions of this instrument.

35 For the purpose of demonstration, it will be assumed that the artillery computer system is operating under the Ab control, and that the target is sufficiently near for the target computer to be set for short ranges 40 and low values. The plotter reference point range scale 99, to be seen in Fig. 6, is distributed on two flat faces of a pivoted bar, to form separate scale sections which may be substituted for each other to fit the range 45 to be dealt with, as more fully explained hereinafter. The graduations of each of these scale sections and their values read as shown in Figs. 13 and 14, and each scale section is suited to short or long ranges, certain mental 50 evaluations being required under some circumstances. For long reference point ranges, if the particular range is not readable on the section of scale 99 that is illustrated in Fig. 14, either directly or with a mental evaluation, the bar bearing the sections of scale 99 is turned by handle 378, (see Fig. 6), thus presenting the other section of scale 99 shown in Fig. 13, and by mental evaluation the 55 graduations of this section may exceed those of Fig. 14. The azimuth scale 100, shown in Fig. 6, for the reference point azimuth will present the graduations and their values as depicted in Fig. 16. When long reference point ranges prevail, the handle 102, (see Fig. 6), is manipulated turning the azimuth

scale bar so that the graduations shown in Fig. 15 come into use.

Reference to Fig. 21 will disclose a knob 103 mounted on the same shaft that carries a crank 104, the outer end of the latter carrying a pin 105 that is adapted to play in a groove-like guide 106 that is mounted on a double-armed lever 107, which is fulcrumed at 108. This lever is shown to have its long arm thrown to the left, in Fig. 21, its slotted upper end embracing a pin 109 carried by a bracket that is secured to a shutter 110.

70 As shown in Fig. 20, the shutter 110 is provided with a contour that, in its illustrated position, uncovers a plurality of counters which register various types of ranges, to which reference will be made later. When the knob 103, shown in Fig. 21, is turned clockwise, the shutter 110 is driven to the right, covering the now exposed range counters and uncovering other range counters for use in connection with longer ranges. In the illustrated embodiment of the invention, the longer range counters have been shown 75 to give readings of twice the magnitude of the counters for shorter ranges.

80 The shutter 110 is provided with a projection 111 adapted to travel between two spaced actuating levers 112 and 113, which are respectively pivoted at 114 and 115 and which extend therebeyond and form slotted lever arms. Into the slots in these arms project pins 116 and 117 that are carried by a shiftable slide 118 upon which are engraved, or otherwise imprinted, alternate value designations for the graduations of the hereinbefore referred to changeable PA and PB base line scales 47, 50, 59 and 62. The sets of value-indicating numerals of these scales that have 85 been shown in the A and B station portions of the target computer, as illustrated in Figs. 3 and 5, have been surrounded with dot and dash circles, which correspond to the windows through which they are disclosed. These are the values for short range problems, 90 the numerals interposed between the circle-enclosed numbers being adapted to replace the first mentioned numerals, thereby affecting the graduations of scales 47, 50, 59 and 62 with values that suit these scales to long 95 range problems.

100 When, therefore, the knob 103, shown in Fig. 21, is turned clockwise to throw the shutter 110 to the right, for the purpose of setting the target computer to long range problems, the shutter projection 111 moves ineffectively for the major portion of the travel of the shutter 110, engaging, however, the unslotted end of lever 113 sufficiently 105 before the end of the shutter's travel to swing this lever an amount requisite to shift the slide 118 to the left, thereby substituting the higher values of scales 47, 50, 59 and 62 for the lower ones. In like manner, when the shutter 110 is returned to the 110

115

120

125

130

left hand position to disclose low values, its projection 111 ultimately swings lever 114 and moves it to the illustrated position, whereupon the lower values of scales 47, 50, 5 59 and 62 replace the higher ones.

It may be observed in Fig. 21 that the shift lever 107 has a short arm from its fulcrum 108 to its lower bifurcated end which embraces a pin 119 carried by a bracket that 10 is attached to a shift bar 120. Mounted upon this bar are a plurality of electrical contact brushes, certain of which 121, 122, 123, 121', 122', 123', 121'', 122'' and 123'' are grouped in sets and are associated with terminal contacts of a number of electrical transmitters 13a, 20 and 13b, previously noted in Fig. 2, as being employed to transmit range information from the target computer to the observing station A, the battery computer 15 and the observing station B.

Also carried by the shift bar 120 is another contact finger 124, which, is spaced from a contact 125, when the target computer is adjusted to short ranges. When 20 this instrument is set for long ranges, the shift bar 120 moves the finger 124 into engagement with the contact 125, establishing an electric circuit from the positive line conductor 126 through a conductor 127, contact 25 125, finger 124, conductors 128 and 129 to and through the windings of solenoids 130 and 131, returning by conductors 132 and 133 to the negative line conductor. The energization of the windings of the solenoids 30 130 and 131 moves their respective cores 135 and 136, causing shift forks 137 and 138 affixed respectively to solenoid cores 135 and 136, to move toward the solenoids 130 and 35 131. The shift fork 137 slides the conjoined spur gears 140 and 139 along the splined shaft 141. Unified spur gears 143 and 142 are 40 slidable along another splined shaft 144 under the action of shift fork 138 operable by solenoid 131.

45 In Fig. 6, the shifting forks 137 and 138 and the combined gears 139 and 140, as well as the rigidly related gears 142 and 143 are reproduced. The gears 139 and 140 are associated respectively with companion gears 145 and 146. Similarly, the gears 142 and 143 co-act, respectively, with other gears 147 and 148. Both gears 145 and 146 are rigidly combined with a shaft 149, and the gears 147 and 148 are both fixed to a shaft 150.

50 55 As will best be understood from Fig. 21, the gears 145 and 139 associated with the solenoid 130, as well as the gears 147 and 142, affiliated with the solenoid 131, have a 2:1 gear ratio, while the associated gears 140 and 146 and fellow gears 143 and 148 have a 1:1 gear ratio. Accordingly, when the solenoids 130 and 131 are de-energized, the spring-urged shift fork 137 meshes gear 139 and 145, and the spring-affected shift 55 fork 138 meshes gears 142 and 147. From

this it will be seen that the shaft 141 is driven from shaft 149 at twice the speed of the latter shaft, while shaft 144 is driven from shaft 150 at twice the speed of the last named shaft.

70 Since it is the adaptation of the target computer to short or long ranges that is now being considered, it will suffice to say that, as will become evident hereinafter, this is the correct speed for shafts 141 and 144 when the target computer is dealing with short ranges and low values. For long ranges and high values, the solenoids 130 and 131 will become energized, as previously described, whereupon the gear ratio between shafts 149 and 141, and also between the shafts 150 and 144, will be 1:1.

75 The shift bar 120, shown in Fig. 21, also shifts a further pair of brushes 151 and 152 mounted upon an insulating post 153, which will be described at a more appropriate place in connection with the control of the reference point range and azimuth pencils, by the electrical and mechanical means 80 shown in Fig. 25.

85 The adaptation of the target computer to short and long ranges, involving the previously set forth considerations and adjustments, by a simple twist of the wrist, reveals the ease and rapidity with which the 90 artillery system is fitted to the situation irrespective of how it may develop.

95 Remembering that it was assumed that the artillery system was to operate under the Ab control, and at a relatively short range, 100 it will be seen that the knob 108, shown in Fig. 21, has been turned to effect the already described shift adapting the target computer to the short range. It will also be recalled that the A observing station was supposed to 105 have sighted the enemy and had notified the B observing station, and that both of these stations had become active.

110 Consequently, both the A and B stations are automatically transmitting the target's azimuth under the Ab control to the target computer, as already described. The operator of this instrument will have turned knob 35, (see Fig. 23), to bring the graduation marked Ab opposite the index for the 115 dial 38. The gearing 37 includes a spur gear 154 which, as the dial 38 is set, will drive a rack 155 for a distance that will carry the insulating brush-supporting bar 156 into a position where the brushes carried by it will 120 bear upon the row of fixed contacts that belong to the Ab control, which row of contacts is so designated.

125 The receiver motor 4a in the target computer, shown in Fig. 3, will be delivering the target's azimuth from the A station, and the receiver motor 4b in the target computer, and found in Fig. 5, will be delivering the target's azimuth from the B station, the target's reference point range and azimuth being com- 130

puted by the target computer from these quantities. In ascertaining the relation of the target to the reference point through the mechanism of the target computer, the receiver motor 4a, (see Fig. 3), which is receiving the target's azimuth from the A-station, turns miter gears 157, and hence, shaft 158, gears 159, another shaft 160, which through gears 161 turns both one side 162' and the center 162" of a differential 162. The center 162" of the differential turns a shaft 163, which through gears 164 turns a cam 165. This cam is shown in its neutral position and is provided with a pair of dwells of different radii. The dwell of the lesser radius permits the spring-urged bell-crank lever 166 to swing a contact finger 167 carried by but insulated from the bell crank 166 into contact with an adjustable contact 168. The dwell of the greater radius forces this contact finger 167 into engagement with another adjustable contact 169. The foregoing group of elements constitute what, for convenience may be termed a controller, of which a considerable number are present in the artillery system. Consequently, the description of one will suffice for the others, and Fig. 19 illustrates one of the controllers on a larger scale and in structural form.

30 The particular controller described is designed as the AZ1C controller, and is shown in Figs. 3 and 24, and it will operate in accordance with the target's increasing and decreasing azimuth. If the contact finger 167 of the AZ1C controller is swung into engagement with contact 168, it will be because the target's azimuth, as observed from the A-station, is increasing. When this circuit closure is made, current will flow from the positive line conductor 126, shown in Fig. 24, by a conductor 170 to the contact finger 167, which now carries the current to contact 168, whence it goes by conductor 171, which continues in Fig. 23, to a fixed contact 172 in a master control switch 173.

45 It will be observed that contact 172 is in a row of contacts of the switch, wherefore, it will be borne upon by a brush 174 which is carried by the insulating brush bar 156. From the brush 174, the current continues by a conductor 175, continued in Fig. 24, to and through one coil 176 of an electro-magnetic clutch AZM, from which it emerges by a conductor 177, then returning through 50 a clutch brake coil 178 and by other conductors 179 and 180 to the negative line conductor 134.

55 The energized clutch is similar to that shown in Fig. 17, wherein the energized clutch coil is to be seen at 176 and the brake coil at 178. This clutch will now be described, since its action is the next step in the series of operations resulting from the already described actuation of the AZ1C controller.

Referring, first, however, to Fig. 3, a power motor 181 is provided with the usual armature shaft 182, which through gears 183 turns a power shaft 184. Other gears 185 operate a clock mechanism within a housing 186, which controls the supply circuit to the power motor, whereby the speed of the motor is synchronized with time. A mechanism suitable for this purpose is illustrated and described in United States Letters Patent No. 1,577,618, of March 23, 1926, issued to me for speed regulating mechanism. The shaft 184, therefore, rotating in accordance with time drives, through gears 187, another shaft 188, which through other gears 189 drives a further shaft 190. Through gears 191, another shaft 192 is turned, which through gears 193 drives the shaft 194 of the electro-magnetic clutch AZM.

Reverting now to Fig. 17, the power-driven shaft 194 of the clutch AZM has a hub 195 rigidly attached to its inner end, this hub being that of a gear 196. The coil 176 is inset in a metallic magnetizable block 198, and coacts with a disk 199 made of similar material and rigidly affixed to the inner end of another shaft 200. The disk 199 is provided with gripping pads 197 on its opposite sides, the pads being of any suitable material such as cork. Since the coil 176 has been described as being energized, a magnetic flux passes through the paths the disposition of the metal in the block 198 and the disk 199 form, and the latter is drawn toward the block 198. The gripping pads 197 on the side of the disk 199 that is adjacent to the block 198 are accordingly pressed against the relatively large spur gear 196, which is rigidly combined with the hub 195. The spur gear 196 is, therefore, seen to so frictionally engage the disk 199 as to drive it and the shaft 200. The gear 196 also drives another gear 201 that has a pinion 202 rigidly combined with it which pinion meshes with another pinion 203, which is fixedly combined with a gear 204. The gear 204 in turn drives a gear 205 which is similar to the gear 196 in size and proportions, and which carries in its hub a ball bearing 206 mounted on the shaft 200, thereby sensitively mounting the gear 205 on that shaft. When the disk 199 is attracted to the block 198, the gear 205 is free from frictional engagement with the gripping pads 197 adjacent to it and turns idly. Thus, under the foregoing conditions, the power shaft 194 drives through the gear 196 and the gripping pads 197 adjacent thereto to directly drive the disk 199 and the shaft 200 rigidly combined therewith. The disk 199 can move slightly toward another hollowed block 207 similar to the block 198 and having an inset coil 208, such movement resulting from the energization of this coil. When this occurs, the drive shaft 194 turns the gear 196, which turns the gear 201 and 130

the pinion 202, which revolves pinion 203 and gear 204, the latter turning the gear 205. Through frictional engagement therewith the disk 199 and the shaft 200 rigid therewith also revolve, but in a direction opposite to that when disk 199 frictionally engages the gear 196. When either of the clutch coils 176 or 208 is energized, the brake coil 178 is also in circuit, and an armature 178a, which is carried by a bell-crank lever 178b that is pivoted at 178c, is attracted, thus withdrawing a brake shoe 178d from the periphery of the clutch disk 195. At other times, a spring 178e forces the brake shoe 178d against the 15 clutch disk 195, preventing it from turning.

Again referring to Fig. 3, it will be observed that the shaft 200 is slidably in and is joined by a coupling to a shaft 209. As the shaft 209 turns, it turns a pair of gears 210, thereby turning a shaft 211, which through other gears 212 turns a shaft 213, thereby causing gears 214 to turn a shaft 215. The shaft 215 carries a worm 216 that turns a worm wheel 217, effecting the turning of a 25 shaft 218, which through gears 219 turns a pointer 220 over the dial 63 to give a major reading against the latter of the target's azimuth as observed from the A observing station. This reading is supplemented by that given by a pointer 221 against the minor dial 64, the pointer 221 being driven from shaft 218 through gears 222. The combined reading given by the pointers 220 and 221 is about 108° 75' or 108° 45', which corresponds to 30 what is shown at AZ in the problem of Fig. 1.

The shaft 211 also simultaneously operates the transmitter 5a, which through the cable 6a, extending to the A-station, operates the receiver motor 7a, shown in Fig. 2, which in 35 turn causes the A-station azimuth indicator 8a to show the azimuth that is set up in the target computer for the A-station azimuth, thereby giving a check at the A-station on the accuracy of the target computer's performance.

During the driving of the shaft 209 through the AZM clutch, a worm 223 on the shaft 209 is turned, which is in mesh with a worm wheel 224 on a shaft 225. This 40 shaft, through bevel gears 226, turns one side 227' and the center 227" of differential 227, thereby turning a shaft 228, and so actuating a controller AZ2C. As the details of this controller are the same as those of the already 45 described AZ1C controller, reference will only be made to its contact finger 229 and its contacts 230 and 231.

Reference now being had to Fig. 24, it will be seen that with the contact finger 229 of the 50 AZ2C controller in engagement with contact 231 thereof, in consequence of the described movement of the shaft 209, current will flow from the positive line conductor 126, by conductors 232 and 233 to the contact finger 229, 55 which carries it to the contact 231. Thence

the current flows by a conductor 234, which continues in Fig. 23, to a fixed contact 235, in the Ab control row of contacts of the master control switch 173. Since the brush 236 engages the contact 235 when the Ab control 70 prevails, the current will continue from the brush 236 by a conductor 237, which enters Fig. 24 and goes to a now closed pair of contacts 238 of a reference point range relay. Proceeding by other conductors 239 and 240 75 the current passes through a coil 241 and the brake coil 242 of a clutch designated as PRM, returning by conductors 243 and 300 to the negative line conductor 134. It will be sufficient to say that the PRM clutch, like the 80 AZM clutch is similar to the clutch shown in Fig. 17, which has already been described in detail.

Momentarily referring to Fig. 3, it will be seen that the power-driven shaft 188 is 85 broken off at the right, but continues through Fig. 4, from which it passes into Fig. 5, where by miter gears 244 it drives another power shaft 245. Other miter gears 246 drive the shaft 194 of the PRM clutch, the 90 parts of which are like those of the clutch of Fig. 17, and, in Fig. 5, it is seen that the clutch shaft 200 is drivingly coupled with a shaft 247. Passing from Fig. 5 into and through Fig. 4, the shaft 247 is seen to enter Fig. 3, where, through gears 248, it drives another shaft 249. This shaft, through gears 250, and one side 251, the center 251', and the other side 251" of a differential PRX, and, hence, through gears 252, turns a shaft 253, 100 which through gears 254 also turns another shaft 255 and a gear 256 carried thereby and which meshes with the reference point range gear 94. The center 251' of the PRX differential remains stationary, its 105 gears merely revolving, but its spider and shaft not turning.

In acting, the gear 256 turns the reference point range gear 94, which, as shown in Fig. 10, is a two part crown gear comprising the 110 upper crown gear 94 and a lower crown gear 94' unified therewith. The crown gear 94' meshes with another gear 257, which is affixed to and drives a range screw 258 that is mounted in the slotted arm 259 of the reference point azimuth gear 93. The turning of the range screw 258 shifts a traveling nut 260, which, as shown in Fig. 9, has a separately formed lower part 260' with which it is swivellingly joined at 261. When the compound nut 260-260' is caused to travel along the range screw 258, as described, its lower portion 260' bears against the slotted arm 262 of the A-station azimuth gear 91, turning the latter until the AZ2C controller has its contact finger 229 returned to its neutral position. This occurs, since the A-station azimuth gear 91 drives a pinion 263, seen in Fig. 3, which through miter gears 264 drives a shaft 265, the latter through gears 266 130

turning one side 227" and the center 227" of the differential 227, whereby the shaft 228 operates to return the contact 229 to its neutral position, which contact finger was previously driven from the AZM clutch by shaft 209, worm 223, worm wheel 224, shaft 225, gears 226 and through differential 227, to operate the contact 231.

The return of the contact finger 229 of the AZ2C controller to its neutral position opens the circuit of the PRM clutch, whereupon the already described drive to the reference point range gear 94 becomes inactive.

But, while the PRM clutch is effective, and the shaft 247 is being driven by it as set forth, a pair of miter gears 267, shown in Fig. 5, turn a shaft 268 that turns gears 269, thereby driving through the side 270, the center 270' and the other side 270" of a differential PRX', so turning gears 271 and a shaft 272, which through gears 273 turn another shaft 274, mounted on which is a gear 275 that meshes with the reference point range gear 94a. The latter gear is similar to that shown in Figs. 9 and 10, previously described, and its under crown gear meshes with a gear 257a on a range screw 258a that is mounted in the slotted arm 259a of the reference point azimuth gear 93a. The turning of the range screw 258a shifts a nut 260a—260a', which is of the compound swivel type, such as is shown in Figs. 9 and 10. The moving of the travelling nut 260a—260a' causes it to bear against the slotted arm 276 of the B-station azimuth gear 95 thereby turning this gear about its axis. Consequently, the gear 95 turns the pinion 277 and miter gears 278, so turning the shaft 279, which through gears 280 turns one side 281' and the center 281" of a differential 281. The center 281" of this differential turns a shaft 282, thereby actuating a controller BZ2C, so that its contact finger 283, which in its neutral position is midway between the contacts 284 and 285, is engaged with the contact 284.

Referring now to Fig. 24, it will be seen that current will flow from the positive line conductor 126, by conductors 286 and 287 to the contact finger 283 of the BZ2C controller, then to the contact 284 thereof, and by conductor 288, which enters Fig. 23, to a fixed contact 289 of the master control switch 173, proceeding therefrom by a conductor 290 to another fixed switch contact 291 in Ab control row of contacts. The brush 292 is in engagement with the fixed contact 291 under the Ab control and carries the current to a conductor 293, which enters Fig. 24, and extends to a now closed pair of contacts 294 of a reference point azimuth relay. Proceeding from here by conductors 295 and 296, the current goes to a coil 297 in the PZM clutch, returning therefrom by a conductor 298, the PZM clutch brake coil,

and conductors 299 and 300 to the negative line conductor 134.

Upon this energization of the PZM clutch, a mechanical drive is set up from the power shaft 245, by gears 301 to the shaft 194 of the PZM clutch, as seen in Fig. 5. This clutch is like that shown in Fig. 17, and drives a shaft 302, shown in Fig. 5, and which also extends through Fig. 4 and enters Fig. 3. In the last named figure, the shaft 302 turns gears 304, thereby driving through the side 97, the center 97' and the other side 97" of the aX differential, this causing the sleeve 305 from the side 97" of the aX differential to turn gears 306 and a shaft 307, which, through miter gears 308 and a spur pinion 309, turn the reference point azimuth gear 93.

Simultaneously with the drive effecting the turning of the reference point azimuth gear 93, seen in Fig. 3, the shaft 302, as shown in Fig. 5, drives spur gears 310, thereby driving through the side 311, the center 311' and the other side 311" of the bX differential, thereby turning the gears 312 and a shaft 313. The latter shaft turns miter gears 314 and a spur pinion 315, thereby turning the reference point azimuth gear 93a shown in Fig. 5, simultaneously with the reference point azimuth gear 93, shown in Fig. 3, until the arm 259a causes the compound swivelled nut 260a—260a' to bear against the slotted arm 276 of the B-station azimuth gear 95 and turn this gear. Thereupon, the gear 95 turns the pinion 277, and with it the miter gears 278, whereby the shaft 279 turns the gears 280 and the side 281' and the center 281" of the differential 281. The center 281" of this differential turns the shaft 282, causing the BZ2C controller to move its contact finger 283 into its neutral position. This brakes the circuit which energized the PZM clutch, which accordingly stops driving the shaft 302, and, hence the movement of the azimuth gears above referred to.

Attention is now directed to the previously referred to turning of the azimuth gears 91, 93, 93a and 95. Were any of these azimuth gears to turn while the double crown range gear associated with it remained stationary, it is obvious that, as the turning azimuth gear swings its arm, the range screw carried thereby would be turned by the gear it carried, which is in mesh with the then stationary range gear. This would shift the compound nut on the range screw and position the nut to represent a greater or less range whenever the azimuth gear was turned, since the radial distance of such nut from the center of the azimuth gear represents the range of the target from the station or point the gear is associated with.

Thus, when the A-station azimuth gear 91 turns the pinion 263, (see Fig. 3), and miter

gears 264, the shaft 265, which turns the gears 266, also turns other gears 267, thereby turning a shaft 316, and the center 317" and one side 317' of a differential 317, which through gears 318 turns a shaft 319, the latter carrying a gear 320 which drives the range gear 92 in the same direction and at the same speed as its companion azimuth gear 91. Hence, there will be no relative movement of the azimuth and range gears 91 and 92 as they turn in unison, which, of course, prevents an incorrect range-indicating radial position of the nut 260—260', as it is being swung to a position representing the target's azimuth from the A-station.

With this explanation in mind, it will only be necessary to point out the actual drives for effecting similar conditions in connection with the remaining sets of associated azimuth and range gears. In Fig. 3, when the reference point azimuth gear 93 turns the pinion 309 and the miter gears 308, thereby turn the shaft 307, the latter turns gears 321, which turn a shaft 322, the center 251' and the side 251" of the PRX differential. This turns gears 252, shaft 253, gears 254, shaft 255 and the reference point range-gear-driving gear 256.

Now, considering the reference point azimuth gear 93a, shown in Fig. 5, it will be seen that its turning sets up a drive through pinion 315, the miter gears 314, the shaft 313, the gears 323, a shaft 324, the center 270' and one side 270" of the PRX' differential, the gears 271, the shaft 272, the gears 273 and the shaft 274 whereby the gear 275 carried thereby turns range gear 94a with the azimuth gear 93a.

Similarly, when the B-station azimuth gear 95 turns, it sets up a drive through the pinion 277, miter gears 278, the shaft 279, gears 325, a shaft 326, the center 327" and one side 327'" of a differential 327, gears 328 and a shaft 329 which has affixed to it a gear 330, that turns B-station range gear 96 in unison with the B-station azimuth gear 95, in the way and for the reason set forth hereinbefore.

Reverting again to the actuation of the PRM clutch, which has been described as driving the shaft 247, as shown in Fig. 5, when electrically energized as hitherto explained, it will become apparent that the shaft 247 extends into Fig. 4, and there, through gears 331, drives a shaft 332, which, through other gears 333 drives a shaft 334. Mounted on this shaft are gears 335 and 336, the former meshing with another gear 337 to drive a reference point long range counter 338 at a 1:1 gear ratio, while the gear 336 drives a still different gear 339 at a 1:2 gear ratio to operate a reference point short range counter 340. The latter counter is shown as being uncovered by the shutter, which is intended to represent the shutter 110, for read-

ing purposes, since the instrument has been assumed to be set for short ranges.

In addition to rendering effective all the drives previously shown to be controlled by it, the PRM clutch, when energized as described, so as to drive the shaft 247, actuates plotting board mechanism. Tracing the shaft 247, in Fig. 5, to the gears 331 in Fig. 4, it is to be seen that when the shaft 332 turns in response to the drive from the shaft 247, gears 341 turn another shaft 342. The shaft 342 extends into Fig. 3, where, through gears 343, it drives a shaft 344, turning pairs of gears 345 and 346. The gears 345 drive one side 347' and the center 347" of a differential 347, the differential center 347" turning a shaft 348 that operates a controller QRC, so that the contact finger 349, which is normally positioned midway of a pair of contacts 350 and 351, moves into engagement with the contact 350.

Now inspecting Fig. 25, it is seen that current will, under these conditions, flow from the positive line conductor 126, by a conductor 352 to the brush 152, then by a conductor 353 to a post 354 and by a conductor 355 to the contact finger 349 and the contact 350. The current continues by a conductor 356 to a post 357, then going by a conductor 358 to a post 359, through a pair of now closed contacts 360, and by a conductor 361 to a post 362, from which the current flows by a conductor 363 to and through a coil 364 and a brake coil 365 of the QRM clutch, returning by a conductor 366 to the negative line conductor 134.

The result of this electrical energization of the QRM controller will be traced through Figs. 3, 4, 5 and 6, and it may, in effect, be traced in Fig. 25. In Fig. 5, the clutch QRM is seen to drive a shaft 367 that enters and passes through Fig. 4, from which it enters Fig. 3. Here, through gears 368, it turns a shaft 369 that through gears 370 turns another shaft 371 that through gears 372 turns a further shaft 373.

Perforce of circumstances, Fig. 6 is drawn on a smaller scale, but it properly is co-extensive with the combined widths of Figs. 3, 4 and 5, as indicated by dotted lines in Fig. 7.

Resuming tracing the partly described drive, the shaft 373 enters Fig. 6 at the extreme left, where by gears 374 it turns a threaded range screw 375. A pencil and protractor carriage 376 has a portion through which the range screw 375 passes, and which acts as a travelling nut, whereby the carriage 376 may be driven back and forth on the range screw 375, in response to increasing and decreasing range. The carriage 376 carries a pointer 377 that reads against the range scale 99, the latter being shown on a larger scale in Figs. 13 and 14, the graduation numerals indicating numbers of yards of reference point range. The range bar 99 is shifted, by a handle 378, from long to short

ranges, or vice versa, which may be read on either of the scales of Figs. 13 and 14.

By way of further explanation, it may be said that the reference point range scale 99 does not show the full yardage of range, but on one face of the range scale bar, shows the change in range within a distance of 6500 yards, while on the other face of the bar it reveals such range change for a distance 10 from 5000 yards up to 11500 yards. Thus, for example, the complete reference point range is shown, in the present instance, by the counter 340, (see Fig. 4), to be 14,350 yards, and, therefore, the pointer 377 of the carriage 376, shown in Fig. 6, will read midway between 4300 and 4400 on the range graduations of the reference point range scale 99, as shown in Fig. 13. Were this range to continue to increase beyond the directly indicated readings afforded by the range graduations shown in Fig. 13, it will be seen that when the pointer 377 reaches the graduation marked 6500 on the range scale of Fig. 13, an insulation block 379 carried by 25 the carriage 376, as shown in Fig. 25, will engage the nearest of a pair of electrical contacts 380, pressing them together. This will close a circuit that extends from the positive line conductor 126, by a conductor 381 to 30 a post 382, from which it continues by conductors 383 and 384 through the winding of an electro-magnet 385, from which it goes by a conductor 386, a post 387, a conductor 388, another post 389 and another conductor 390 to the now closed contact fingers 380. From here the current continues by a conductor 391 to a reversing coil 392 of the QRM clutch and through the brake coil 365, returning by the conductor 366 to the negative 40 line conductor 134.

When the magnet 385 became energized, it attracted its armature thereby moving the insulation arm 393 attached to it, whereupon the previously closed contacts 360 opened 45 causing the hitherto energized coil 364 of the QRM clutch to become dead, the other coil 392 of this clutch then driving the shaft 367 reversely to its former direction of rotation. Through the previously described mechanical drive the pencil and protractor carriage 376 is consequently reversely driven along the range screw 375 toward the left. This causes the contact finger 380 to open, which, however, does not prevent the continued 50 reverse drive of the pencil and protractor carriage 376, since when the armature of the magnet 385 was attracted, its insulation 393 effected the closing of a pair of electrical contacts 394. The current from the winding 55 of the magnet 385 thus continued by conductor 386 to post 387, and by a new path through the then closed contacts 394, conductors 395 and 396 to a post 397, then through a closed pair of contacts 398, continuing by a conductor 399 to a post 400,

from which it goes by conductors 401 and 391 to the reversing coil 392 and brake coil 365 of the QRM clutch. The current then returns by the conductor 366 to the negative line conductor 134. This assures the continued reversed drive of the pencil and protractor carriage 376, irrespective of the opening of the contact fingers 380, until it has moved back a distance equivalent to 5000 yards, when if the reference point range is 75 still increasing, it will resume its travel toward the right for increasing range.

This re-establishment of the increasing range drive of the pencil and protractor carriage 376 is due to the action of the cam of 80 the QRC controller, one revolution of which corresponds to a travel of the carriage 376, which is equivalent to a measurement of 5000 yards.

Now, referring to Fig. 13, if the range carriage pointer 377 moves, in response to increasing range, to the graduation marked 6,500, and the range still increases, the contacts 380, shown in Fig. 25 will close and the carriage 376 will move back toward the left, 90 as already described. The operator will then turn the handle 378, shown in Fig. 6, thereby partly rotating the range scale bar until a substitute set of graduations, shown in Fig. 14, is presented to the operator's 95 view.

Since the range carriage 376 moves back a distance indicative of 5,000 yards, the pointer 377 of the carriage 376 will stop opposite the graduation marked 6500, which denotes 100 the same value which this pointer last identified on the displaced set of graduations. Hence, there is a smooth and uninterrupted display of increasing range the reading of which corresponds to the last four figures of 105 the reading shown by the reference point range counter 340. This counter, in Fig. 4, shows a reading of 14,350 yards of reference point range, and in Fig. 13, the pointer 377 shows a reading of 4,350 yards, it being convenient for immediate considerations to ignore the tens of thousands of yards. 110

Were the range pencil and protractor carriage 376 to have its pointer 377 at the 4,350 yard mark in Fig. 13, and were this to correspond to the actual reference point range, and to be identical with the reading of the reference point range counter 340, constantly increasing range would find the pointer 377 carried, in Fig. 13, to a reading of actual range 115 120 equal to 6,500 yards, when, in the manner described, the pointer 377 would be run back an amount representing 5,000 yards to read against the 6,500 yard mark in the substituted graduations shown in Fig. 14. With 125 continuing reference point range, the pointer 377 will go to the end of this row of graduations, the end mark being 1,500, which, when mentally added to the understood 10,000 yards, gives a reading of 11,500 yards. If the 130

range still increases, the pointer 377 is again driven back an amount indicative of 5,000 and the scale bar is turned back to again present the graduations shown in Fig. 13. This will discover the pointer 377 at the 1,500 graduation, which, it will be recalled, at this time denotes 11,500 yards.

It being assumed that the range sufficiently further increases, the pointer will reach the 6,500 mark again, but it now denotes 16,500 yards, and runs back the usual 5,000 yard retraction, and is once more associated with the graduations of Fig. 14, where it will read against the 6,500 mark, which mentally means 16,500 yards under the present consideration. Proceeding to the end mark 1,500, in Fig. 14, the understood reading is 21,500 yards. In this fashion, the reference point range can be followed on the shiftable scale 99 as long as it increases, and, it is obvious, subtractions can be made in a similar way for decreasing range.

In connection with decreasing reference point range, Fig. 25 shows that when the carriage 376 carries its insulating block 402 to the left hand end of its travel, a pair of contact fingers 403, similar to fingers 380 at the right hand limit of travel of the carriage 376, are closed by pressure applied by the block 402. Current thereupon flows from the positive line conductor 126, by conductor 381 to post 382, then by the conductor 383 to the winding of a magnet 404, going by a conductor 405 to a post 406, and then by a conductor 407 to a post 408, proceeding therefrom by a conductor 409 to and through the now closed contact fingers 403, then going by conductors 410 and 363 to the increasing range coil 364 of the QRM clutch and the brake coil 365 thereof, returning by the conductor 366 to the negative line conductor 134.

The QRM clutch then turns the shaft 367, and the remaining drive to the reference point range screw 375, in the direction for increasing reference point range, thereby driving the pencil and protractor carriage 376 toward the right. Like the contact fingers 380, the contact fingers 410 open as soon as the carriage 376 moves away sufficiently to remove the pressure that closes the contact fingers.

As, however, the energization of the magnet 404 attracted its armature and moved the insulation arm 411 carried thereby, a pair of contacts 412 became closed, so that the current from the winding of the electro-magnet 404 then goes by the conductor 405 to the post 406, thereafter going through the now closed contacts 412, and proceeding by a new path through the conductors 413 and 358 to the post 359, through the closed pair of contacts 360, thence going by the conductor 361 to the post 362, then by the conductor 363 to coil 364 of the QRM clutch, for increasing range, through the clutch brake coil 365, and by the conductor 366 to the negative line conductor 134. Therefore, though the contact fingers

403 opened as the pencil and protractor carriage 376 moved away from them the QRM clutch continued to drive in the direction for increasing range, but only for a distance representative of 5,000 yards, after which the pencil and protractor carriage 376 resumes its travel in the direction of decreasing range.

It has now been shown, that the pencil and protractor carriage 376 travels either toward the right for increasing reference point plotted range, or toward the left for decreasing reference point plotted range, and that at either limit of its travel, it is automatically and quickly retracted for a suitable distance, immediately resuming its former direction of travel if the target's range is progressing in the same direction.

It will now be shown why and how, after its retraction, representing say, 5,000 yards, the pencil and protractor carriage 376 resumes travel in its former direction. 5,000 yards is a convenient multiple, which lends itself to ready transference from the one to the other of the sets of graduations on the two scales of the shiftable scale bar 99, as already set forth.

In the demonstration of how the pencil and protractor carriage 376 resumes its former direction of travel, after its 5,000 yard retraction, reference will be made to Fig. 19, the reference characters in which will be enclosed in parenthesis after the reference characters applied to the QRC controller, whereby equivalent parts in the two different controllers may be readily identified. Thus, in referring to the contact finger of the QRC controller, it will be written: "contact finger 349 (167, Fig. 19). In this analogy and cross reference, unidentified parts will be referred to by the characters used in Fig. 19.

It has been shown that, when the QRM clutch, disclosed in Fig. 5, has its coil 364 energized, it drives the pencil and protractor carriage 376, seen in Figs. 6 and 25, toward the right in accordance with increasing range.

In so doing, the QRM clutch directly drives the shaft 367, which extends through Fig. 4 and enters Fig. 3 actuating the gears 368 and the shaft 369, the latter, through gears 414 turning another shaft 415, which turns spur gears 416, thereby turning one side 347''' of a differential 347. It has also been made clear that the QRM clutch was rendered effective by a circuit-closure due to the action of the QRC controller, shown in Fig. 3, and that this action of the QRC controller was due to a drive in accordance with increasing reference point range, the shaft 247 being driven by the PRM clutch, shown in Fig. 5, this shaft, as shown in Fig. 4, driving the gears 381, the shaft 332, other gears 341 and a shaft 342, which enters Fig. 3, there turning gears 343 and another shaft 130

344, whereby through gears 345, the other side 347' of the differential 347 is also driven.

As previously explained, the operation of the side 347''' and the center 347'' of the differential 347 turned shaft 348, thereby turning the cam 417 (similar to cam 165, Fig. 19) so that the QRC controller contact finger 349 (similar to finger 167, Fig. 19) engaged the contact 350 (similar to 168, Fig. 19), which energizes the QRM clutch coil 364 (Fig. 25) causing the shaft 367 to turn to effect the driving of the pencil and protractor carriage 376 in a direction for increasing range, as already explained. This direction of travel is maintained until the insulating block 379 on the pencil and protractor carriage 376 is moved into engagement with and closes the contacts 380, (see Fig. 25). In the manner hereinbefore set forth, the QRM clutch coil 364 becomes dead and its coil 392 is energized, reversing the direction of the shaft 367 and the carriage 376, and no current will then pass from the QRC controller contact finger 349 (similar to 167, Fig. 19), to the contact 350 (similar to 168, Fig. 19). The now reversed drive of the QRM clutch, (see Fig. 5), reversely turns the shaft 367, which, as seen in Fig. 3, reverses the direction of rotation of the gears 368, the shaft 369, the gears 414, the shaft 415, gears 416, and the side 347''' of the differential 347. In Fig. 3, the gears 343, the shaft 344 and the gears 345 are also reversed, the side 347' of the differential 347 becoming reversed as well. Therefore, both sides and the center of this differential are turning in the same direction.

It is advisable to now point out that the PRM clutch (see Fig. 5) is energized, as already described, in response to the receipt by the target computer of A-station azimuth, and it turns the shaft 247 to give measures of computed reference point range, readable on the high or low computed range counter 338 or 340 (see Fig. 4). With this in mind, attention is directed to the fact, that, while the QRM clutch contemporaneously drives the shaft 367 to effect the travel of the pencil and protractor carriage 376 in accordance with plotted reference point range, as previously set forth, the shafts 247 and 367 do not always rotate at the same speed. Moreover, though the PRM clutch rotates in a single direction as long as the target's range is changing in a given direction, the QRM clutch is subject to reversals for retractions of the pencil and protractor carriage 376, in the manner previously described, for distances indicative of, say 5,000 yards.

Therefore, the opposite sides 347' and 347''' of the differential 347 turn in opposite directions simultaneously at times when both the PRM and QRM clutches are driving their respective shafts 247 and 367 for reference point range of the same character, say, in-

creasing range. If, under these circumstances, the PRM and QRM clutches effect, through their respective drives, an opposite turning of the opposite sides 347' and 347''' of the differential 347 at the same speed, the center 347'' of this differential will remain stationary, and the contact finger 349 of the QRC controller, (see Fig. 3), will remain motionless. However, the opposite sides 347' and 347''' do not constantly turn at a uniform speed, as the PRM and QRM clutches, and their drives, fluctuate in their respective speeds, and, as stated, the QRM clutch is subject to reversals of direction in drive for predetermined periods.

So, in general, the drive from the PRM clutch for computed increasing reference point range tends to turn the side 347' of the differential 347 to thereby turn the center 347'' thereof and the shaft 348, so as to cause the contact finger 349 to engage the contact 350 of the QRC controller, thus energizing the coil 364 of the QRM clutch to cause the latter to drive in response to increasing plotted reference point range. This, in the already described manner, effects the turning of the other side 347''' of the differential 347 in a direction opposite to that of the side 347', and whenever the side 347''' exceeds the speed of the side 347', the center 347'' of the differential moves to carry the contact finger 349 away from the contact 350 of the QRC controller, (see Fig. 3).

Accordingly, the QRM clutch (see Fig. 5), becomes deenergized, and the shaft 367 ceases to be driven, whereupon the side 347''' of the differential stops, while the opposite side 347' becomes preponderant, due to its continued drive from the PRM clutch. Consequently, the differential center 347'' and its shaft 348 again turn to re-engage the contact finger 349 with the QRC controller contact 350. So, irrespective of fluctuations in the PRM and QRM drives, when the target's range is increasing, the contact finger 349 of the QRC controller seeks the contact 350 thereof.

When the pencil and protractor carriage 376 (see Fig. 25) causes the closure of the contacts 380, the coil 364 of QRM clutch is rendered dead, and the coil 392 thereof becomes energized and the shaft 367 turns in a direction to result in the movement of the carriage 376 in a direction for decreasing range, as hitherto explained. Consequently, the shaft 367, (see Fig. 3), also reverses the direction of movement of the gears 368, the shaft 369, the gears 414, the shaft 415, the gears 416 and, therefore, the side 347''' of the differential 347. As up to the time of this reversal the side 347''' of the differential, whenever preponderantly assertive, tended to move the QRC controller contact finger 349 away from the contact 350, the just referred to reversal tends to cause the differential side

347''' to move the contact finger 349 toward the contact 350.

Inasmuch as both sides 347' and 347''' now turn in the same direction, the differential center 347'' and its shaft 348 do likewise, as, of course, does the cam 417 (similar to cam 165, Fig. 19), and this direction is the one that tends to move the contact finger 349 (similar to contact finger 167, Fig. 19) toward the contact 350 (similar to contact 169, Fig. 19), which contact is affiliated with increasing plotted reference point range.

Under the foregoing conditions, the cam 417 (similar to cam 165, Fig. 19), starting from a neutral position *a*, (see Figs. 3 and 19), will have a dwell 419 engage the roller of the bell-crank lever 166, which carries the contact finger 349 (similar to contact finger 167, Fig. 19), so that this finger is forced into engagement with the contact 350 (similar to contact 169, Fig. 19). Since, however, the contacts 360 have been opened by the energization of the magnet 385, the coil 364 of the QRM clutch does not become energized, but the coil 392 remains in the circuit made by the closure of the contacts 380, which circuit was preserved effective, as already described, after the retracting of carriage 376 permitted the contacts 380 to open. Consequently the pencil and protractor carriage 376 continues in its retraction until the cam 417 (similar to cam 165, Fig. 19) makes a full revolution.

In continuing to make this revolution, the cam 417 (similar to cam 165, Fig. 19) brings a second neutral point *b* into engagement with the roller of the bell-crank lever 166, which will then move the contact finger 349 (similar to contact finger 167, Fig. 19) midway between the contacts 350 and 351 (similar to contacts 169 and 168, Fig. 19). This, however, produces no effect as the contacts 360 (see Fig. 25) are still open, and the circuit through the magnet 385 has not been broken. But, as soon as the continued turning of the cam 417 (similar to cam 165, Fig. 19) brings a dwell 418 into engagement with the roller of the bell-crank lever 166, this lever swings the contact finger 349 (similar to contact finger 167, Fig. 19) to make engagement with the contact 351 (similar to contact 168, Fig. 19).

Referring now to Fig. 25, it is evident that current paths from the positive side of the line 126 go to both terminals of the magnet 385, de-energizing it. Thus, briefly, positive line current would have to go by conductor 352 to the QRC controller contact 351, then to the closed contacts 394 to one side of the winding of the magnet 385, while, at the same, current from the positive line would have to go by conductor 381 to post 382, and then to the other side of the magnet 385. Since both terminals receive current from the positive side of the line, the magnet 385

becomes dead. Thereupon, its armature falls and the insulation arm 393 with it. The contacts 394, therefore, open and the contacts 360 close, but, as the contact finger 349 of the QRC controller is now engaged with the contact 351, current flows from the positive line conductor 126 by the conductor 352 to the contact 351, then going by a conductor 420 to a post 421, proceeding therefrom by conductors 422 and 396 to the post 397, through contacts 398 and by conductor 399 to the post 400, going therefrom by the conductors 401 and 391 to the coil 392 of the QRM clutch, returning through the brake clutch coil 365 and conductor 366 to the negative line conductor 134. The QRM clutch, therefore, continues to drive the shaft 367 to continue the retraction of the pencil and protractor carriage 376.

The cam dwell 418 finally passing off the roller of the bell crank lever 166, the neutral point *a* of the cam again engages the bell-crank lever roller, causing the contact finger 349 (similar to contact finger 167, Fig. 19) to assume its neutral position. The cam 417 (similar to cam 165, Fig. 19) has, therefore, made one complete revolution, and the pencil and protractor carriage 376 will have moved continuously to the left in the direction of decreasing plotted reference point range for a distance representing 5,000 yards. Continued movement of the cam 417 (similar to cam 165, Fig. 19) will again throw the contact finger 349 (similar to contact finger 167, Fig. 19) into engagement with the contact 350, since the cam cycle will begin over again. Accordingly, the coil 364 of the QRM clutch is energized and the coil 392 being dead, so that the QRM clutch now drives the shaft 367 to cause the pencil and protractor carriage 376 to resume travelling toward the right to indicate increasing plotted reference point range.

The travel of the pencil and protractor carriage 376 continues as described until, due to the target's own change of movement, its range is no longer increasing. When, therefore the A-station ceases to transmit increasing azimuth, the receiver motor 4a in the target computer will become inactive. The finger 167 of the AZ1C controller remains where it is when the receiver motor 4a stops, and, if the contact finger 167 is in engagement with the contact 168, as it will be when the target's azimuth has been increasing as described, the coil 176 of the AZM clutch will still be energized. Accordingly, as Fig. 3 will show, the shaft 209, the gears 210, the shaft 211 and gears 423 will turn the side 162''' and the center 162'' of the differential 162, thereby turning the shaft 163 and the cam 165 of the AZ1C controller, so that the bell-crank lever 166 will swing the contact finger 167 to its neutral position. Then the coil 176 of the AZM clutch will become de-energized, and both sides of the differential 162 becoming

stationary, the inactive AZ1C controller will render the AZM clutch inactive also, and all of the previously described operations, consequent upon the transmission of increasing 5 azimuth from the A-station will cease.

While the hereinbefore described actions are transpiring as a result of the transmission to the target computer of the target's azimuth from the A-observing station, the 10 B-observing station is simultaneously transmitting the target's azimuth as observed through the telescope 1^b at the B-station.

Fig. 2 shows that the telescope 1^b at the B-station is coupled with a transmitter 2^b, both 15 being operated simultaneously, whereby, as the telescope 1^b is trained on the target a measure of the target's azimuth is sent from the B-station by the cable 3^b to the B-station azimuth receiver motor 4^b in the target computer. 20

Referring to Fig. 5, the armature of the B-station azimuth receiver motor 4^b actuates a pair of gears 424, which turn a shaft 425 that, through gears 426, turns another shaft 25 427, that, through gears 428, turns one side 429' and the center 429'' of a differential 429. The differential center 429'' turns a shaft 430, which through suitable gears turns a cam 431 of a controller BZ1C. This moves a bell- 30 crank lever to cause it to throw the contact finger 432 into engagement with the contact 433 of the BZ1C controller, since the target's azimuth from the B-station is increasing, as shown in Fig. 1.

Reference to Fig. 24 shows that the current will consequently flow from the positive line conductor 126 by a conductor 434 to the contact finger 432, which now carries the current to the contact 433, whence it flows by a conductor 435, which extends into Fig. 23, to a fixed contact 436 of the master control switch 173, this contact being in the Ab row of contacts. A brush 437 is now bearing on the contact 436, so that it carries the current to a conductor 438 that extends into Fig. 24 and goes to a coil of a clutch 439 of a clutch BZM, returning therefrom by a conductor 440, the brake coil 441 of the BZM clutch, and conductors 442 and 300 to the negative line conductor 134. The clutch BZM is similar to that shown in Fig. 17, which has been described. 45

Since the coil 439 of the BZM clutch is energized in response to increasing target's 55 azimuth, it will turn a shaft 443, (Fig. 5), gears 444, another shaft 445, gears 446, a shaft 447, other gears 448, a shaft 449 and a worm 450 carried thereby, this turning a 60 worm wheel 451 and a shaft 452 that it is affixed to, the shaft 452, through gears 453 turning a pointer 454, in an increasing direction. The pointer 454 reads against the major PB azimuth dial 67 to show the target's azimuth from the B observing station, 65

the shaft 447 also operating, through gears 455, to drive another pointer 456 which gives a fractional reading on the minor PB azimuth dial 68. Thus, as applied to the problem of Fig. 1, the pointers 454 and 456 show the target's observed azimuth BZ from the B-station to be about 52.75° or 52°-45'. 70

The shaft 445, at the same time, also turns gears 457, which turn the other side 429'' of the differential 429, so that as both sides thereof are rotating, the differential center 429'' is, though subject to fluctuations characteristic of its follow-up nature, such as have been previously explained in connection with another controller, tends to remain stationary and in engagement with the contact 433 of the BZ1C controller. 75

Additionally, the shaft 445 turns a pair of gears 458 that operate the transmitter 5^b, 80 whereby the electrical transmission through the cable 6^b actuates the receiver motor 7^b at the B-station, to cause the indicator 8^b to show what target's azimuth was received by the target computer from the B-station. 85 Such check should show, of course, that the target's azimuth sent from the B-station to the target computer is the same as the B-station received back from that instrument. 90

As the BZM clutch turns the shaft 443, the latter turns a worm 459, slidably and drivably mounted thereon, a worm wheel 460 meshed with this worm being turned and with it a shaft 461 that carries it. The shaft 461 turns gears 462, thereby turning one side 281''' and the center 281'' of the differential 281, the shaft 282 being consequently turned, and the cam of the BZ2C controller being actuated. As the target's azimuth, or bearing, as observed from the B-station is shown in Fig. 1 to be increasing, the contact finger 283 will be engaged with the contact 284. In the present instance, with the conditions as shown in Fig. 1, the contact finger 283 will be swung against the contact 284 by the action of both the AZ2C and the BZ2C controllers, since both are responding to increasing target's azimuth that is being simultaneously sent from the A and the B observing stations. 105

So, current flows through the circuit previously described, from the positive line conductor 126 by conductor 286 to the contact finger 283 and the contact 284, thence by the conductor 288 into Fig. 23, to contact 291 and through the master control switch and back into Fig. 24 through the conductor 293, passing through contacts 294, and going by conductors 295 and 296 to the coil 297 of the PZM clutch, and by the conductor 298 to 115 the PZM brake coil, returning by the conductors 299 and 300 to the negative line conductor 134. 120

As previously set forth during the consideration of the receipt of the target's azimuth 130

from the A-station, the PZM clutch drives the shaft 302, though at this time it is while receipt of the target's azimuth from the B-station is being considered. Passing through Fig. 4, the shaft 302, after entering Fig. 3, drives through the aX differential to turn the shaft 307, so turning the miter gears 308 and the spur pinion 309. The latter turns the reference point azimuth gear 93 so that its arm 259 swings. As the shaft 307 also turns the gears 321 and drives through the side 251, the center 251' and the other side 251'' of the PRX differential, thereby turning the shafts 253 and 255, the gear 256 turns the range gear 94 an amount proportional to the turning of the azimuth gear 93, so that when the latter is turned the range gear turns with it, and there is no turning of the reference point range screw 258. Consequently, the compound nut 260—260' is moved only in accordance with the target's change in azimuth. As shown, this azimuth change, in the present instance is an increasing change in the azimuth PZ of the target's bearing from the reference point P, (see Fig. 1) and is in response to data received by the target computer from both the A and B stations. The compound nut 260—260', when moved as just set forth, slides the range screw 482 longitudinally, whereby the contact finger 464 of the AR2C controller engages the contact 465.

Referring to Fig. 24, it is apparent that current will now flow from the positive line conductor 126 shown in Fig. 24, by the conductor 126, by the conductor 232 to the contact finger 464 of the AR2C controller, to the contact 465 and by a conductor 466, which enters Fig. 23, and goes to a fixed contact 467 in the A_b row of the master control switch 173, whence the current continues through the brush 468 and a conductor 469, which enters Fig. 24, to a pair of now closed contacts 470 of the target computer's A-station range relay. From here the current flows by conductors 471 and 472 to and through the coil 473 of the ARM clutch, continuing by a conductor 474, a clutch brake coil, and conductors 475 and 180 to the negative line conductor 134.

As a result, the ARM clutch is energized to drive a shaft 476, shown in Fig. 3, slidably mounted on which to be driven thereby is a worm 477 that is meshed with a worm wheel 478 to drive a shaft 479, which through gears 480 drives one side 317'', the center 317'' and the other side 317' of the differential 317, thereby turning gears 318, the shaft 319 and the gear 320 to actuate the range gear 92. This gear turns the gear 481, so turning the range screw 482. Whenever the B-station stops transmitting azimuth, the compound nut 260—260', which is positioned in the slot of the arm 259, is held against movement longitudinally on the range screw 482. The latter, therefore, moves

longitudinally screwing itself through the nut and separating the contact 464 of the AR2C controller from the contact 465. This deenergizes the coil 473 of the ARM clutch, and stops the drive to the range screw 482. Accordingly, the range screw will have been moved by an amount representative of the change in range from the A-station to the target consequent upon the degree of change in azimuth of the target from the reference point P.

While the PZM clutch was driving the azimuth gear 93, shown in Fig. 3, as described, it was also driving through gears 310, (see Fig. 5), and the differential bX to turn the gears 312, the shaft 313, the miter gears 314 and the spur pinion 315, to thereby turn the reference point azimuth gear 93a simultaneously with and to the extent as the first mentioned reference point azimuth gear 93. The shaft 313 also turns gears 323 and drives through the PRX' differential and shafts 272 and 274 to cause the gear 275 to turn the range 94a in unison with the azimuth gear 93a, so preventing turning of the reference point range screw 258a. Consequently to the turning of azimuth gear arm 259a, the compound nut 260a—260'a' is swung, and slides the range screw 483, causing the contact finger 484 of the BR2C controller to engage the contact 485 thereof.

Thereupon current flows from the positive line conductor 126 shown in Fig. 24, by the conductor 286 to the contact finger 484 of the BR2C controller, which carries it to the contact 485, from which the current proceeds by a conductor 486, which enters Fig. 23, and leads to a fixed contact 487 in the A_b row of contacts in the master control switch. A brush 488 is now bearing on the contact 487 and a conductor 489 carries the current therefrom to a pair of now closed contacts 490 in the target computer's B-station range relay. From the contacts 490 the current proceeds by conductors 491 and 492 to a coil 493 of a clutch BRM, passing from this coil by a conductor 494 and through a clutch brake coil 495, from which the current returns by conductors 496 and 300 to the negative line conductor 134.

As now energized, the clutch BRM drives a shaft 497, (see Fig. 5) and a worm 498 that turns a worm wheel 499 fixed on a shaft 500, which through gears 501, drives through one side 327', the gears of the center 327'' and the other side 327''' of a differential 327, thus driving the gears 328 to turn the shaft 329 and gear 330. The gear 330 turns target computer's B-station range gear 96, which turns a gear 502 mounted on the range screw 483 in the target computer that is related to the B-station. The screw 483 screws itself through the compound nut 260a—260'a', causing the contact finger 484 to move out of engagement with the contact 485, thereby opening the cir-

cuit through the BRM clutch, and thus terminating the desired drive of the range gear 96 after it has turned to an extent representative of the change in range from the B-station consequent to the change in the target's azimuth as considered from the reference point P.

Such changes in the ranges observed from the A and B stations are introduced into 10 counters which show the ranges from those stations. Thus, when the ARM clutch drives the shaft 476, (see Fig. 3), this shaft turns gears 503, a shaft 504, other gears 505, another shaft 506 and sets of gears 507 and 508, 15 which drive counters 509 and 510. The counters 509 and 510 show, respectively, the longer and shorter observed ranges from the A-station.

Similarly, when the BRM clutch drives 20 the shaft 497, shown in Fig. 5, the latter turns the gears 511, a shaft 512, other gears 513, a shaft 514 and sets of gears 515 and 516, which actuate counters 517 and 518 that show, respectively, the longer and shorter observed 25 ranges from the B-station.

When the shaft 506, (see Fig. 3), is actuated, it turns gears 519, a shaft 520 and other gears 521, thereby operating the transmitter 13a, which communicates through the cable 30 14a with the receiver motor 15a at the A-station, which operates the adjacent range counter 16a. So, though no range is being transmitted from the A-station to the target computer, the latter instrument sends information to the A-station as to the current A-station range it has computed and is using, whereby the operators at the A-station may check it up with the target's range as given by the A-station range finders.

40 Reference to Fig. 5 shows that, in a similar way, the actuation of the shaft 514, which drives the B-station observed range counters 517 and 518, also turns gears 522, a shaft 523 and other gears 524, thereby operating 45 the transmitter 13b, which through the cable 14b communicates with the B-station, actuating the receiver motor 15b there, which causes the B-station range indicator to show the B-station range as computed and in use 50 in the target computer. As in the case of the A-station, already described, comparison may be had with the B-station range finders.

It has been shown that when the target computer is receiving the target's azimuth 55 from either the A-observing station, or the B-observing station, or from both, the shaft 302 is operated by the PZM clutch, as previously explained. As shown in Fig. 4, when the shaft 302 is actuated, it turns gears 525 60 and a shaft 526 that, through gears 527, turns another shaft 528, which, through gears 529 turns a further shaft 530 and a worm 531 carried thereby. The worm 531 drives a worm wheel 532, which turns a dial 533, this 65 dial having azimuth graduations that read

against an index pointer 534 to show the coarse computed target's azimuth from the reference point P.

For a finer reading, gears 535 are driven by the shaft 526 and, in turn, drive a shaft 536 that has affixed to it a worm 537 that turns a worm wheel 538, which turns a minor computed reference point azimuth dial 539 that reads against an index pointer 540.

The ratio of the reading of the major computed azimuth dial 533 to the minor dial 539 is 360:1, so that, while one revolution of the major dial 533 represents 360°, one revolution of the minor dial 539 represents 1°.

As shown in Fig. 4, the combined reading 80 of the dials 533 and 539 is about 75.25°, or 75°-15', which corresponds to the target's reference point azimuth PZ, as shown in Fig. 1.

The reference point azimuth is also plotted, 85 an azimuth pencil and protractor carriage 541 shown in Fig. 6, being actuated in a manner corresponding to that in which the range pencil and protractor carriage 376 is operated.

While the shaft 302 is being driven by the PZM clutch, it also turns gears 542 (Fig. 5) that turn a shaft 543, the latter, through gears 544, turning one side 545' and the center 545" of a differential 545, thereby turning the 95 shaft 546 to which the center of the differential is secured. This results in the actuation of the QZC' controller, causing the contact finger 547 thereof to engage the contact 548.

Reference to Fig. 25 shows that current 100 will consequently flow from the positive line conductor 126, by the conductors 352 and 549 to the brush 151, flowing from there by a conductor 550 to a post 551, to the contact finger 547, to the post 548, then going by a conductor 552 to a post 553, and by a conductor 554 to a post 555, through now closed contacts 556, proceeding by a conductor 557 to a post 558 and by a conductor 559 to a coil 560 of a clutch QZM. Continuing through a conductor 561 and a brake coil 562 of this clutch, the current returns by the conductor 366 to the negative line conductor 134.

The clutch QZM is, therefore, energized in 115 accordance with the target's increasing azimuth of the reference point range, which is in harmony with the conditions of the problem shown in Fig. 1. The clutch QZM, as seen in Fig. 5, then drives a shaft 563, which through gears 564 turns another shaft 565, 120 which extends into Fig. 6, where, through gears 566, it turns an azimuth feed screw 567 to drive the azimuth pencil and protractor carriage 541 toward the right for increasing azimuth of the reference point range.

Simultaneously, the shaft 565, through gears 568, drives another shaft 569, which, through other gears 570 turns a shaft 571. The latter, through gears 572, drives the side 125 545" of the differential 545, and, as the 130

side 545' is being driven from the PZM clutch, the center 545" of the differential tends to remain stationary and to keep the contact finger 547 associated with the contact 548, while the reference point azimuth PZ continues to increase.

The azimuth pencil and protractor carriage 541 is provided with a pointer 573, (see Fig. 6), that reads against the azimuth scale 100, better shown in Figs. 15 and 16. The carriage 541 carries an insulating block 574, (see Fig. 25), adapted to engage and close a pair of contacts 575, when the azimuth pencil and protractor frame 541 reaches the 15 end of its travel toward the right.

Current then flows from the positive line conductor 126, by conductors 381, 576 and 577 to and through the winding of a magnet 578, proceeding therefrom by conductors 579, 580 20 and 581 to and through the now closed contacts 575, the current continuing by conductors 582 and 583 to the decreasing azimuth coil 584 of the QZM clutch. The energization of the magnet 578 effects the opening of the 25 contacts 556, rendering the increasing azimuth coil 560 of the QZM clutch dead, and closes another pair of contacts 585. In consequence of the latter occurrence, the magnet 578 is kept energized, the current flowing 30 through it, now continuing from it by conductor 579, closed contacts 585, conductors 586 and 587 to and through the closed contacts 588, thence continuing by conductors 589 and 583 through the decreasing azimuth coil 35 584, and by the conductor 561, the QZM clutch brake coil 562 and the conductor 366 to the negative line conductor 134.

As a result, the azimuth pencil and protractor carriage 541, will move toward the 40 left for a distance indicative of a 10° retraction, and then resumes its travel in response to increasing azimuth. This it does in the same way and for the same reasons that were 45 set forth in the explanation of the corresponding action of the range pencil and protractor carriage 376, and there is no need for repeating them.

It may, however, be added that when the 50 azimuth carriage 541 is driven toward the left in response to decreasing target's azimuth, the current flows from the positive line conductor 126 by conductors 352 and 549, the brush 151, the conductor 550, to the contact finger 547, which, for decreasing azimuth, 55 carries the current to the contact 590 of the QZC' controller, whence it flows by conductors 591, 592 and 587 to and through the contacts 588, continuing by conductors 589 and 583 to and through the decreasing azimuth 60 coil 584 of the QZM clutch, thereafter proceeding by the conductor 561, the clutch brake coil 562 and the conductor 366 to the negative line conductor 134.

When the azimuth pencil and protractor 65 carriage 541 reaches the limit of its left hand

travel, its insulating block 593 will close a pair of contacts 594. Then, current will flow from the positive line conductor 126, by conductors 381, 576 and 577 to and through the winding of the electro-magnet 595, whence the current continues to flow by conductors 596, 597 and 598 to and through the now closed contacts 594, then going by the conductors 599 and 559 to the increasing azimuth coil 560 of the QZM clutch, the current continuing by the conductor 561, the clutch brake coil 562 and the conductor 366 to the negative line conductor 134.

The energization of the magnet 595 effects the closing of a pair of contacts 600 and the 70 opening of the contacts 588. The opening of the latter de-energizes the decreasing coil 584 of the QZM clutch, which then drives the azimuth pencil and protractor carriage 541 toward the right for a 10° retraction, when in the manner similar to that previously explained, it will resume its travel toward the left for decreasing azimuth of the target's 75 reference point range. The closure of the contacts 600 returns the current from the 80 magnet 595 to the negative side of the line by a new path after the contacts 594 are allowed to open by the withdrawal therefrom of the carriage 541, whereby the latter may 85 complete its full 10° retraction. Thus, after 90 the contacts 594 open, the current will flow continuously from the magnet 595 by the conductor 596, passing through the now closed contacts 600, and proceeding by the 95 conductors 601 and 554, the closed contacts 556, and by conductors 557 and 559 to and 100 through the increasing azimuth coil 560, continuing through the conductor 561, the clutch 105 brake coil 562 and the conductor 366 to the negative line conductor. As stated, this drive is for a 10° retraction, after which the carriage 541 resumes its travel towards the left.

A comparison will now be made of certain 110 of the mechanism of the target computer, shown in Figs. 3 to 5, with the triangulation shown in Fig. 1, whereby the treatment of the latter by the target computer will be more readily understood.

Fig. 1 represents a geographical triangulation, which is mechanically reproduced in the target computer, with certain necessary adaptations to the mechanical structure of the instrument. For example, there is a single reference point P, in the problem of 115 Fig. 1, which is doubly reproduced in the target computer. Thus, in Fig. 3, the common center of the azimuth gear 93 and the range gear 94 represents the reference point P, of Fig. 1. In Fig. 5, the common center 120 of the azimuth and range gears 93a and 94a, respectively represents exactly the same reference point P. It is because the target computer is divided into an A-station section and a B-station section, that this dou- 125 130

ble representation of the single reference point P of Figs. 1 and 43 is necessary.

The base line PA of Fig. 1 is shifted in the target computer, as previously explained and 5 in accordance with the shifted triangles that are shown in dotted lines in Fig. 43. In Fig. 3, the distance from the common center of the gears 93 and 94 to the common center of the gears 91 and 92, represents the base line 10 PA of Fig. 43, which in turn represents the PA base line of Fig. 1, except that it has been shifted to the zero line MN.

The base line PB of Fig. 1, after being shifted as shown in Fig. 43, will be found in 15 the mechanism of Fig. 5 to extend from the common center of the gears 93a and 94a to the common center of the gears 95 and 96.

In Fig. 1, the target's bearing, or observed range, from the A-station is shown by the 20 line AR, while, in Fig. 3, this observed range is represented by the distance from the common center of the gears 91 and 92 to the center of the compound nut 260—260'.

The reference point range is shown in Fig. 25 1 by the line PR, but in adapting the problem to the target computer, this line is split, so to speak, and is doubly represented as shown in Fig. 43. In the target computer itself, the point P is divided on account of the 30 distribution of the mechanism as previously explained. That is, the common center of the gears 93 and 94, in Fig. 3, represents the actual single reference point P, and just as truly as does the common center of the gears 93a and 35 94a, in Fig. 5. Accordingly, the reference point range PR of Fig. 1, is represented in Fig. 3 by the distance from the common center of the gears 93 and 94 to the center of the compound nut 260—260', and, in Fig. 5, 40 this same reference point range PR is again represented by the distance from the common center of the gears 93a and 94a to the center of the compound nut 260a—260a'.

The target's bearing, or observed range, 45 from the B-station is shown in Fig. 1 by the line BR, while in the target computer it is represented by the distance from the common center of the gears 95 and 96 to the center of the compound nut 260a—260a'.

50 Again examining Fig. 1, it will be appreciated that, as the target R moves, the ranges AR and BR, as well as the reference point range PR will lengthen or shorten, according to the direction of the target's movement, and 55 the azimuth of each of these ranges will change, unless the target be travelling directly along the line of one of the ranges, the azimuth of that range then not changing.

Therefore, when the gear 320, in Fig. 3, 60 turns the range gear 92 in response to increasing or decreasing range, this gear turns the gear 481 and the range screw 482, thereby lengthening or shortening the distance from the common center of the gears 91 and 92 to 65 the compound nut 260—260', thus preserving

the representation of the A-station range AR that this distance is intended to denote. If the lengthening or shortening of the range AR is accompanied by a change in its azimuth, the gear 91 will be operated to swing 70 the arm 262 and the range screw 482 mounted therein an amount representative of such azimuth change.

Obviously, if the target R moves so as to change either the A-station range AR, or 75 its azimuth, or both, the reference point range PR and the B-station range BR, since they also converge on the target, will change, and the azimuth of each with it. So, if the compound nut 260—260' be moved by the 80 range screw 482, as above set forth, it will push against or pull the reference point range screw 258, thus swinging the arm 259 carrying it, and turning the reference point azimuth gear 93 an amount proportional to the 85 change in the azimuth PZ of the reference point range PR, due to the change of the A-station range AR consequent upon the change in the target's position.

It has been previously made clear that the 90 corresponding reference point gears of the same kind shown in Figs. 3 and 5 operate simultaneously, since they relate to a single quantity. Therefore, the reference point gear 93a in Fig. 5 will move exactly to the same extent and to denote the same azimuth change as the gear 93, in Fig. 3. Also, the compound nut 260a—260a' will be just the same distance from the common center of the gears 93a and 94a, as the nut 260—260' is from the 95 common center of the gears 93 and 94, since it represents the same terminal of the same range measure, and the range BR from the B-station will have changed to extend to the same point R, (Fig. 1), that the AR range from the A-station terminates at, this being the target R, which is doubly represented in the target computer by the compound nuts 100 260—260' and 260a—260a'.

105 The method, under the Ab control, of operating the various range and azimuth gears above referred to has already been set forth, and reference to it has been avoided in the foregoing analogy of the mechanical and geographical range and azimuth conditions to 110 make the comparison more direct and clear. It has also been shown that, consequent to above outlined actions of the various range and azimuth gears and the range screws just referred to, dials, pointers, counters and scales, etc., are actuated to furnish a visual translation of these actions, in the form of direct readings of the ranges and azimuths thereof from the A and B-stations, and the reference point P, and the lengths of the base lines, etc.

115 Referring to Fig. 6, the range carriage 376 is seen to be provided with a pencil 602, and the azimuth carriage 541 carries a pencil 603, these pencils being adapted to mark on a record sheet 604, which, as shown in Fig. 8, is 120 125 130

mounted in the instrument in a roll on a spool 605, being drawn therefrom by a paper-feeding drive. This drive originates with the power motor 181, the armature shaft 182 of which, through gears 183 turns the power shaft 184. The latter, through gears 185 operates clock mechanism 186 and controls the electric circuit of the power motor 181, so that the latter is synchronized with time, as, consequently, will be the power shaft 184.

The power shaft 184, through gears 187, turns another power shaft 188, that extends through Fig. 4 and enters Fig. 5. Here, the shaft 188, through gears 244, turns a further power shaft 245, which enters Fig. 6, and, through gears 606, turns a power feed roll 607, shown in both Figs. 6 and 8. The latter figure shows that the record sheet 604 is drawn from its roll on the spool 605, over idler rollers 608 and 609, and so as to pass over a drafting board or plate 610. Thereafter, the record sheet 604 passes over the power roll 607, and between it and a pressure roll 611, which is eccentrically mounted. The pressure roll may accordingly be turned to either press the paper sheet 604 against the power roll 607 to feed the paper sheet, or to sufficiently release the paper so that the power roll 607 will revolve freely without moving the paper sheet 604, an operating handle 612 being provided to actuate the pressure roll 611.

Since the shaft 245, (see Fig. 6), is synchronized with time, the paper sheet 604 will be advanced over the drafting board 610 and toward the rear of the instrument in synchronism with time. To record subdivisions of time on the record sheet 604, time pencils 613 and 614 are provided, and they are held by holders 615 and 616, which are connected together by and rigidly to a follower rod 617 that is spring-pressed against and actuated by a cam 618. This cam makes one revolution per minute, and once in that period pushes the follower rod 617 to laterally displace the pencil holders 615 and 616, and the pencils 613 and 614.

Thus, due to the continuous feeding of the record paper 604 in synchronism with time, the pencils 613 and 614 draw straight time lines 619 and 620 having indications of minute steps 621 and 622 set off thereon because of the cam actuation just explained. To set the cam 618 so that it will act coincidently with a standard chronometer, and thereby also conform the time interval step indications 621 and 622 therewith, a knob 623 is operated until a pointer 624 is brought against the same indication of the fraction of a minute on the dial 625 that is shown by the second hand of the chronometer used for making the setting. This will correspondingly set the cam 618 to cause the time pencils to be actuated coincidently with the chronometer also. Such arbitrary change is possible

irrespective of the power drive from the time-controlled power shaft 245, which drive extends therefrom by gears 626, a shaft 627, other gears 628, a shaft 629, gears 630, a shaft 631, gears 632, a shaft 633, a pinion 634, a gear 635 meshed therewith, a friction clutch 636, a shaft 637 and gears 638 drivingly connecting the shaft 637 with the shaft 639 that carries the knob 623 and the pointer 624. The friction clutch comprises the hub 640 of the gear 635 which is slidably mounted on a sleeve 641 secured to the shaft 637, and a bent washer 642 pressed against the gear hub 640 by an adjustably fixed collar 643.

Also drawn on the record sheet 604 is a range line 644, which is made by the range pencil 602, and an azimuth line 645, is drawn by the azimuth pencil 603. In Fig. 6, the portion 644' of the range line 644 denotes a 5000 yard retraction, while the portion 645' of the azimuth line 645 signifies a 10° retraction.

Since the range line 644 is produced by the range pencil 602 moving with the carriage 376 in response to increasing or decreasing reference point range, and is plotted against time it will ordinarily be curved to some degree, except under certain conditions, as when there is no change in the range, and, hence, no alteration in the rate of change of range. Under the latter conditions, the carriage 376 remains stationary, as does the range pencil 602, the paper sheet 604 continuing to advance so that the pencil draws a straight range line.

When, however, the range pencil 602 moves, the range line 644 acquires an inclination or slope, which in Fig. 6 indicates increasing range, an opposite inclination denoting decreasing range. If the rate of change of range is uniform, the range line 644 will be straight and give a measure of such rate. When the rate of change of range is not uniform, the range line 644 will be curved and the inclination or slope of the tangent to the curved range line 644 with the center of the pencil 602 as the point of tangency, which is representative of the present instant, gives a measure of the rate of change of range.

The azimuth pencil 603 and the carriage 541 are movable in accordance with increasing or decreasing azimuth of the reference point range, i. e., the target's bearing from the reference point P, and is also plotted against time. If the rate of change of azimuth is uniform, the slope of the azimuth line 645 will give a measure of the rate of change of azimuth. Usually, however, the rate of change of azimuth is not uniform and the azimuth line 645 will be curved. When it is curved, the slope of the tangent to the azimuth line 645 with the center of the pencil 603 as the point of tangency, which is representative of the present instant, gives a measure of the rate of change of azimuth.

Not only does the target computer compute

the values previously referred to in the manner disclosed, but it also generates the target's reference point range and the azimuth thereof, and checks the computed and generated values against each other.

Furthermore, the generating mechanism of the target computer determines the target's course and speed, and resolves the resultant of these into the rate of change of range and 10 the rate of change of azimuth.

The generating mechanism of the target computer is driven from the power motor, through power shafts, so that in response to the turning of the power shaft 245, (see Fig. 15 6), the gears 626 turn the shaft 627, which turn the gears 628, and, hence, the shaft 629, the gears 630, the shaft 631, the gears 632, the shaft 633, gears 646, a shaft 647, other 20 gears 648, and a disk 649 of a variable speed drive device, or integrator JR, associated with the range values. The disk 649 drives a pair of balls 650 which drive a roller 651, that, through gears 652, a shaft 653 and gears 25 654 turn the shaft 149 and the gears 146 and 145 mounted thereon.

With the target computer set for short ranges, as shown in Fig. 21, the gear 145 will be in mesh with the gear 139, whereby the shaft 141, (see Fig. 6), will turn at the speed 30 for short ranges. The shaft 141 has secured to it a gear 655 that normally meshes with and drives a crown gear 656, which turns a shaft 657. The shaft 657 extends into Fig. 4 and is longitudinally slidably through and 25 turns a worm 658, which drives a worm wheel 659 fixed to a shaft 660.

At its opposite end, the shaft 660 drives through gears 661 to turn a shaft 662, which 40 through other gears 663 turns a shaft 664. This shaft through spur gears 665 drives the counter 666 that shows the generated reference point range for short ranges, which should equal the computed reference point 45 range shown by the counter 340. Another set of spur gears 667 drive the counter 668 for the generated reference point range for long ranges.

The shaft 660 also turns gears 669 that turn a shaft 670 and gears 671, the latter turning 50 one side 672' of a differential 672. As the PRM clutch, (see Fig. 5), drives the shaft 247, which extends into Fig. 4, and, as in that figure, the shaft 247 drives the gears 331 and the shaft 332, the latter, through gears 673 55 turns the other side 672'' of the differential 672 in accordance with computed reference point range. When, therefore, the computed and generated ranges correspond the equal speed of the opposite sides of the differential 672 maintains the center 672" of this differential stationary, so that its shaft 674 will 60 remain stationary, as will the gears 675, the shaft 676, the gears 677 and the comparison dial 678. If, after the computed and generated 65 counters have been synchronized, they

run at the same rate, the PR-JR mark 679 on the dial 678 will remain directly opposed to, or matched with a fixed index, 680. Any lack of synchronism will cause the dial 678 to turn and make the mark 679 swing to one side or the other of the fixed index 680, according to whether the computed or generated range drive is preponderant in speed. The JRL handle may then be pushed in and operated to turn the shafts 657, 660 and 670 70 to actuate the side 672' and the center 672" of the differential 672, thereby turning the shafts 674 and 676 to again align the dial mark 679 and the fixed pointer 680. At the same time, the turning of the shaft 660 will 80 result in the turning of the shafts 662 and 664, whereby the generated range counters 666 and 668 will be caused to again match the computed range counters 340 and 338. This same procedure is had in initially setting 85 up these counters preparatory to the solution of a problem like that shown in Fig. 1. Whenever the JRL handle is thus actuated, the shaft 657 is moved longitudinally of itself to disengage the crown gear 656, (see 90 Fig. 6), from the gear 655.

As the generated reference point counter 666 is actuated, the shaft 660, forming part of the drive thereto, also turns gears 681 and a shaft 682, which, through gears 683 operates the generated reference point range transmitter 20 that communicates by the cable 21 with the battery computer, where it 95 is utilized as hereinafter set forth.

Attention is again directed to Fig. 6, where 100 it may be seen that, as the shaft 627 turns when the previously referred to power motor is being operated, it also, through gears 684, turns the disk 685 of another variable speed drive device, or integrator, JZ which is associated with the azimuth of the reference point range. This variable speed device comprises the disk 685, a pair of balls 686 and a roller 687. The latter, through gears 688 105 turns a shaft 689 and gears 690, thereby turning the shaft 150 and the gears 147 and 148 affixed thereto. With the target computer set for short ranges, as shown in Fig. 21, the gear 147 is in mesh with the gear 142 slidably mounted on the shaft 144 to drive it.

Reverting to Fig. 6, the shaft 144, through gears 691 drives a shaft 692 that extends into Fig. 4 and, through gears 693, turns another shaft 694 that carries a gear 695, 120 which is normally in mesh with a crown gear 696 that is secured to a shaft 697. As the latter turns, it imparts rotary movement to gears 698, a shaft 699, other gears 700 and another shaft 701. Fixed to the shaft 701 is a worm 702 that meshes with a worm wheel 703 that turns with the outer ring dial 704. This ring dial reads against the fixed index 534 to give a measure of the generated azimuth of the reference point 130

range, or line of target's bearing from the reference point P.

Surrounding the dial 533, the outer ring dial 704 bears azimuth graduations corresponding to those of the dial 533, which it circumscribes, and therefore, the computed azimuth of the reference point range is readily comparable with the generated azimuth thereof. At its zero graduations, each of the dials 533 and 704 is provided with an arrow, pointing toward the arrow of the other dial, so that there is a follow-the-pointer method of comparing the dials, which discloses more quickly and easily whether the computed and generated azimuths of the reference point range are synchronized.

The dial 704 gives a coarse azimuth reading, but this is supplemented with a finer reading. To this end, the shaft 697 also turns gears 705 that turn a shaft 706 that carries a worm 707, which drives a worm wheel 708 that turns with an outer ring dial 709. This dial represents the fractional division of 1° of generated azimuth of the reference point range, and bears graduations like those of the inner dial 539, which also reads against the pointer 540. The dials 539 and 709 are provided at their zero graduations with co-acting follow-the-pointer arrows, which function like those of the major dials 533 and 704. As shown in Fig. 4, the combined reading of both dials 704 and 709 reveals the generated azimuth of the reference point range to be substantially 75.25° , $75^\circ-15'$. This is the same reading as is given by the dials 533 and 539 for the computed reference point range, and it also corresponds to the azimuth PZ of the reference point range PR, shown in Fig. 1.

To initially set the generated azimuth dials 704 and 709, or to synchronize them with the computed azimuth dials 533 and 539, the handle JZL may be pushed in and operated, thereby disengaging the crown gear 696 from the gear 695 and turning the shaft 697. This turns the shafts 699 and 706 and also effects the turning of the generated azimuth ring dials 704 and 709 through the actuation of the previously described drives. Also, when the shaft 697 turns, it causes rotary movement of miter gears 710 and 711, thereby turning a shaft 712, other gears 713 and a shaft 714, which, through gears 715, operates the reference point azimuth transmitter 17 that communicates through the cable 18 with the battery computer, the result of which will be more advantageously explained later on.

Again referring to Fig. 6, it will be clear that the slope of the reference point range line 644 and the slope of the azimuth line 645 will develop as the record sheet 604 moves under the pencils 602 and 603 while these pencils move laterally of the record sheet in response to the target's movements. The

slope of the line 644 will, accordingly, represent the rate of change of range, while the slope of the line 645 will denote the rate of change of azimuth. By pushing in and turning a knob dRL, a shaft 716 is turned and with it a worm 717, this imparting rotary movement to a gear sector 718 and swinging the transparent protractor arm 719, until an engraved median line thereon is substantially co-incident with the slope of the range line 644 if it is straight in consequence of a uniformly increasing or decreasing range rate. Then the turning of the knob dRL is stopped. With the more likely occurrence of a curved range line, the median line on the protractor arm 719 is placed tangent to such curved range line 644, the point of tangency obviously being at the center of the range pencil 602, which is indicative of the present instant to the operator.

At the same time, however, the protractor-setting shaft 716 turns gears 720 and another shaft 721, which drives gears 722 so as to turn a combined gear sector and bell-crank lever 723. The slotted short arm 723 of this bell-crank lever receives a pin that extends from a bar 724, the latter being combined with a ball-carrier 725 that holds the balls 650. Consequently, the balls 650 are positioned radially of the integrator disk 649 in accordance with the setting of the range protractor arm 719.

The disk 649 is uniformly driven, as already shown, by the time-controlling power drive, and the radial disposition of the balls 650 governs the rate of rotational speed of the roller 651. Since the slope of the median line of the protractor arm 719 represents the rate of change of range, i. e.,

$$\frac{dR}{dt}$$

105

and the disk 649 is driven in synchronism with standard time and drives the radially positioned balls 650, there is effected a multiplication of the range rate by time, which equals the generated range, and this quantity is mechanically expressed by the rotational displacement of the roller 651. Through the drives already traced, the turning of the roller 651 operates the generated range counters 666 and 668 shown in Fig. 4, as well as the transmitter 20 that communicates with the battery computer, as previously shown. Also, it operates the dial 678 to match the generated reference point range with the computed reference point range.

In the same way, a knob dZL is pushed in and turned to rotate a shaft 726, (see Fig. 6), which carries and drives a worm 727 that meshes with and turns a gear sector 728, which swings a transparent azimuth protractor arm 729, until an engraved median line thereon is brought substantially co-incident with the slope of the azimuth line 645 drawn

115

120

125

130

on the record sheet 604 by the azimuth pencil 603, if it is straight in consequence of a uniformly increasing or decreasing azimuth rate. Should the azimuth line be curved, as 5 it is more likely to be, the median line on the protractor arm 729 is placed tangent to such curved azimuth line 645, the point of tangency being at the center of the azimuth pencil 603 which is representative of the present 10 moment to the person adjusting the protractor arm.

The shaft 726, at the same time, turns gears 730, a shaft 731 and other gears 732, which 15 turn a combined gear sector and bell-crank 733. The latter has a short arm slotted to receive a pin projecting from a bar 734 that is combined with a ball carrier 735 that retains the balls 686, whereby when the azimuth 20 protractor arm is swung into a rate of change of azimuth indicating relationship to the azimuth line 645, the balls 686 are positioned radially of the disk 685 to represent the rate of change of azimuth, i. e.,

$$25 \quad \frac{dZ}{dt}$$

and the rotation of the disk 685 in accordance with time effects a multiplication which equals the generated azimuth. This is mechanically expressed by the rotational displacement of the azimuth integrator roller 30 687. The roller 687 in turn controls the already described drives to the generated azimuth dials 704 and 709, and to the generated 35 reference point azimuth transmitter 17 that communicates with the battery computer.

The target's course and speed is obtainable by turning the knobs dRL and dZL to set the 40 protractor arms 719 and 729 into relationship, respectively, with the range line 644 and the azimuth line 645, drawn on the record sheet 604, as shown in Fig. 6.

It has been shown that, when the range 45 protractor 719 is adjusted to the line 644, there is a resultant turning of the combined gear sector and bell-crank lever 723. This 50 swings the long arm 723" of the bell-crank lever 723, which is slotted and receives a pin that projects from an L-shaped slide 736, which slide is set by the bell-crank lever 723 in accordance with the range component of a vector which represents the target's course and speed.

In a similar manner, when the azimuth protractor 729 is set to the azimuth line 645, the 55 shaft 726 turns the gears 730, the shaft 731 and the gears 732 to turn the bell-crank lever 733. The long slotted arm 733" of the bell-crank lever thus swings and displaces a pin 60 737 that extends from a traveling nut 738, that is adapted to be moved along a screw 739 that is mounted in a frame 740 carried by one arm of another L-shaped slide 741. This 65 slide is, therefore, set by the bell-crank lever 733 in accordance with the deflection compo-

nent of the vector that represents the target's course and speed.

Both the range and deflection L-shaped slides have slotted arms, and these cross, and through the interstice thus formed projects 70 a pin which extends from a traveling nut 742. This nut is movable along a target's speed and course screw 743 that is mounted in a slotted arm 744 that projects from an azimuth, or target's course, gear 745, which gear is axially coincident with a target's speed gear 746.

Consequently, when the range and azimuth 75 protractors 719 and 729 are adjusted to the range and azimuth graph lines 644, and 645, respectively, the pin that projects from the nut 742 will be positioned by the combined resulting movements of the slides 736 and 741. This will occasion the turning of the slotted arm 744 of the target's course gear 745 and 80 the target's speed screw 743 carried thereby to a position which will denote the target's course. The distance from the common center of the gears 745 and 746 to the center of 85 the pin that extends from the traveling nut 742 is representative of the target's speed. Therefore, this distance represents a vector 90 of the target's course and speed, in mechanical form, and the distance r , in the direction in which the slide 736 moves, to the center of the slotted arm of this slide from the common center of the gears 745 and 746 is the range rate component of this vector. The distance q that the center of the slotted arm 95 of the slide 741 is from the common center of the gears 745 and 746 is the target's deflection component of the vector.

Hence, in Fig. 1, the line R—D corresponds to the distance from the common center of the gears 745 and 746 to the center 100 of the pin of the nut 742, and is the vector that represents the target's course and speed. In Fig. 1, the length of the line R—Ra corresponds to the distance r , in Fig. 6, of the 105 center of the slotted arm of the slide 736 from the common center of the gears 745 and 746, and this is the rate of change of range component of the vector R—D, of Fig. 1. Similarly, the line R—D', in Fig. 1, (which has the same magnitude as the line Ra—D), 110 corresponds to the distance q , in Fig. 6, of the center of the slotted arm of the slide 741 from the center of the gears 745 and 746, 115 which is indicative of the target's deflection component of the vector R—D, of Fig. 1.

To have a course the target must move, and in moving it has speed of some degree. Accordingly, the knob dZL , shown in Fig. 6, is pushed in, closing a pair of electrical contacts 747, the function of which will be explained later. The turning of the knob dZL , after it has been pushed in, to set the azimuth protractor 729 to the graph 645, causes the arm 733" of the bell-crank lever 733 to bear against the pin 737 of the nut 738, and 120 125 130

this acts through the slide 741 to cause the slotted arm of this slide to exert pressure against the pin of the nut 742. The target's course and speed screw 743 is slid longitudinally in consequence of this pressure sufficiently to move an electrical contact 748, which it carries, into engagement with either the contact 749 or the contact 750 of a controller TSC. If the speed of the target is increasing, 10 the contact 748 will be engaged with the contact 749.

Thereupon, current will flow from the positive line conductor 126, shown in Fig. 25, by the conductor 381 and other conductors 751 and 752 to the contact 748 of the TSC controller passing to the contact 749, then proceeding by a conductor 753 to the increasing coil 754 of the TSM clutch, from which the current flows by a conductor 755, the brake 20 coil 756 of the clutch, and by conductors 757 and 758 to and through the now closed contacts 747, returning by conductors 759, 760, and 366 to the negative line conductor 134.

As a result, the power shaft 245, shown in Fig. 5, transmits power through gears 761, a shaft 762, gears 763 and the clutch TSM, which now drives a shaft 764, which extends into Fig. 6 and through gears 765 turns a shaft 766. This shaft turns gears 767 and 30 768, and consequently one side 769' and the center 769" of a differential 769, thereby turning a shaft 770, gears 771, a shaft 772, gears 773, another shaft 774, gears 775, a shaft 776, gears 777 and a shaft 778, thereby 35 turning a gear 779 which turns the target's speed gear 746, which as shown in Fig. 11, is a double crown gear. The upper part of the double crown gear 746 turns a gear 780, (see Fig. 6), and thus the target's speed 40 screw 743, thereby shifting the nut 742 in accordance with the target's increasing speed.

As the nut 742 moves outwardly, lengthening its radius from the common center of the gears 745 and 746, the slide 741 is moved so 45 that the deflection component of the target's course and speed vector increases in value, this obviously being what actually occurs when the target increases its speed. This movement of the slide 741 moves the pin 737 50 of the nut 738, thereby swinging the arm 733" of the bell-crank lever 733, thus causing its short arm 733' to displace the pin that projects into it from the bar 734. The ball carriage 735 is accordingly shifted to position 55 the balls 686 at a correspondingly greater radius from the center of the disk 685 of the JZ integrator. The greater angular velocity of the annular path of the disk 685 which now engages the balls 686 drives the 60 latter at a proportionately greater speed, so that the integrator roller 687 is properly speeded up, as is the drive therefrom to the major and minor generated azimuth ring dials 704 and 709, shown in Fig. 4, and the 65 transmitter 17, which sends measures of the

azimuth of the reference point range (or, line of sight) to the battery computer.

If only the handle *dZL* is operated, the slotted arm of the slide 736 will remain stationary, and the slotted arm of the other slide 741 moves the pin of the nut 742 laterally of the imaginary center line of the target speed screw 743 as it is positioned before the nut is displaced. Actually, then, the target's speed screw 743 and the arm 744, which supports it, will be angularly displaced, thereby turning the target's course gear 745. From this it will be understood that the target computer in generating the graph 645 recorded an azimuth change that was consequently upon an altered value of the deflection component only of the target's course and speed vector. So, as the target's course gear thus turns, it also turns a pinion 781, (see Fig. 6), miter gears 782, a shaft 783, gears 784, 785 and 786 and a shaft 787, which extends into Fig. 4 and carries a worm 788, which meshes with a worm wheel 789.

As shown in Fig. 12, the worm wheel 789 is mounted on a shaft 790, that extends through a tubular shaft and at its upper end carries a target's course pointer 791, that, as seen in Fig. 4, reads against the computed and generated reference point azimuth dials 533 and 704, and from zero graduation thereof. The target's course pointer 791, in Fig. 4, shows the target's course to have an azimuth reading of 140°, which corresponds to the azimuth *H* of the target's course *R*—*D*, as shown in Fig. 1.

Attention is called to the fact that as the target moves along its course, its azimuth rate of change from the line of sight from the reference point varies inversely as the range. That is to say, at a certain range the target will at a given instant have a certain rate of change of azimuth from the line of sight. If, at that same instant the range were twice as great the rate of change of azimuth would only be half as much as at the first mentioned range, inasmuch as the target, steaming at a given rate, would travel the same linear distance at either range.

The already described action, resulting from setting the azimuth protractor 729 to the azimuth graph 645 by manipulating the knob *dZL*, must accordingly be modified. To this end, the shaft 657, which is driven from the JR integrator in response to generated range, turns a worm 792 that drives a worm wheel 793 to turn a shaft 794, which, through gears 795, turns another shaft 796 that, through gears 797, turns the generated range screw 739. This shifts the nut 738 and its pin 737 so that the previously described movement of this pin is modified, and with it the bell-crank lever arm 733", and so the balls 686 of the JZ integrator and its roller 687. The drive from the roller includes the modification so introduced, and so, of course,

will the generated azimuth dials 704 and 709, and the azimuth transmitter 17, shown in Fig. 4.

The modification thus accomplished amounts to dividing the target's deflection i. e., the azimuth component of the target's course and speed vector, by the generated range, and obtaining as the result the azimuth rate of change in degrees. To make this clear, let it be seen in Fig. 6, that a right triangle exists, one side of which is from the center of the bell-crank lever 733 to the center of the pin 737 of the travelling nut 738 on the generated range screw 739. Another side PR represents the reference point range, in yards, and the third side q represents the azimuth component, in yards, of the target's course and speed vector, i. e., the target's deflection. Therefore,

$\frac{q}{PR}$ = tangent of the angle at o ,

thus giving the angle in degrees between the side PR and the side $o-737$.

25 Were the range PR doubled, the target's deflection q would remain the same, since the target would travel the same distance at either range, as already explained. But, the angle in degrees between the lines PR and 30 o-737 would be only about half as much at the doubled range. To introduce the effect of this azimuth alteration into the target computer, the nut 738 is moved by the previously traced generated range drive to the 35 range screw 739 to change the length of the side PR of the triangle. The triangle side o-737 is then the effective length of the arm 733' of the bell-crank lever 733, and, under the conditions recited, this effective length 40 will be twice as long as the effective length of the short arm 733', which will thus move the bar 734 and the ball-carrier 735 to half the radial distance from the center of the disk 685 it was positioned at before the range 45 was doubled. Accordingly, the balls 686 will be positioned radially of the disk 685 to travel only half as fast at the doubled range, as will the integrator roller 687. Therefore, the 50 generated azimuth dials 704 and 709 will move only half the angular rate at the double range, which conforms to the literal conditions, and the azimuth of the reference point range sent to the battery computer 17 will 55 be correspondingly halved in speed.

55 As the shaft 766 turns, the gear 767 mounted thereon drives another gear 798 and gears 799 to turn a target's speed dial 800, which reads against a fixed index to show the target's speed in hundreds of yards per minute. 60 The shaft 766 also, through gears 801, turns a shaft 802, which extends into Fig. 5 and drives the target's speed transmitter 24, which communicates with the battery computer 65 through the cable 26.

Whe the handle dRL is pushed in and operated to set the range protractor 719 to the range graph 644, it closes electrical contacts 803, for a purpose explained later. As the knob dZL is turned to set azimuth protractor in accordance with the rate of change of the azimuth component (deflection) of the target's course and speed vector, the knob dRL is turned to set the range protractor in accordance with the rate of change of range component of the same vector.

The dRL knob being actuated, the shaft 716 rotates the gears 720, the shaft 721 and the gears 722, thereby causing the bell-crank lever 723 to press its slotted arm 723'' against the pin that projects into it from the range rate slide 736. The slotted arm of this slide presses against the pin that extends into it from the nut 742, thereby sufficiently turning the arm 744 and the target's course gear 745 to effect a transference of pressure through the pinion 781, the miter gears 782, the shaft 783, gears 784 and 785, a shaft 804, the center 805'' and one side 805' of a differential 805, the gears 806 and the worm gear 807. The worm gear 807 meshes with a worm 808, and, as the worm wheel cannot turn the worm, it shifts the shaft 809, which carries an electrical contact 810, to engage the latter with either a contact 811 or 812 of a controller THC, accordingly as to whether the range protractor 719 is to put pressure on the arm 744 to turn it to the right or left.

Should the shaft-carried contact 810 be engaged with the contact 811, current will flow from the positive line conductor 126, shown in Fig. 25, by the conductors 381, 751 and 813 to the contact 810, then passing to the contact 811 and going by a conductor 814 to and through the increasing rate coil 815 of a clutch THM, proceeding by a conductor 816 and a brake coil of the clutch and other conductors 817 and 818 to the now closed contacts 803. From here the current continues by conductors 819, 760 and 366 to the negative line conductor 134.

Consequently, the THM clutch is driven from the power shaft 192, shown in Fig. 3, through gears 820, a shaft 821 and other gears 822, and in turn drives a shaft 823 which extends into Fig. 6. Here, the shaft 823, through gears 824 turns the shaft 809 and the worm 808, thereby driving the worm wheel 807, the gears 806, the side 805' and the center 805'' of the differential 805. The differential center 805'' turns the shaft 804, which, through gears 785 and 784 turn another shaft 783, which, through the miter gears 782 turns the pinion 781, and, hence, the target course gear 745. This swings the arm 744 and the screw 743 to a position indicative of the target's course. 115 120 125

The shaft 804 also turns gears 825, which turn one side 769" and the center 769" of the differential 769, which turns the shaft 770,

the gears 771, the shaft 772, the gears 773, the shaft 774, the gears 775, the shaft 776, the gears 777, the shaft 778 and the gear 779 which turns the target's speed gear 746 in unison with the target's course gear 745. This prevents an actuation of the speed screw 743 in consequence of a course setting.

The electrical contacts 803 that are engaged when the *dRL* knob is pushed in, and 10 the similar contacts 747 that are closed when the *dZL* knob is pushed in, normally preserve the circuits that include the clutches THM and TSM open, as shown in Fig. 25. Any accidental circuit closure at either the THC or 15 TSC controllers will, therefore, fail to actuate either the THM or TSM clutches, but any deliberate operation of either of the *dRL* and *dZL* knobs completely closes the circuit and results in the intended actuation of the 20 clutches.

As the shaft 809 is turned, it turns a pair of gears 826, shown in Fig. 6, and, therefore, a shaft 827, which enters Fig. 3, and operates the target's course transmitter 23, which 25 communicates with the battery computer through the cable 25.

To keep certain parts of the target computer from over-running their proper extent of travel, safety limit-stops are employed, two types having been employed. 30 The limit stops of one type are shown at AR' in Fig. 3, PR' in Fig. 4, and BR' in Fig. 5. The description of one will suffice for the others.

35 In Fig. 4, as the shaft 332 rotates in response to a mechanical drive from the PRM clutch through the shaft 247, a pair of gears 828 turns a screw-threaded shaft 829, causing a consequent travel of a displaceable nut 830. This nut carries an electrical contact 831 which ultimately engages one or the other of the contacts 832 or 833, if the drive continues too long in one direction.

Say, therefore, the nut-carried contact 831 45 engages the fixed contact 833, having been traveling in response to increasing range. As shown in Fig. 24, current will then flow from the positive line conductor 126 by a conductor 834 to the contact 831, passing to the contact 833 and going by conductors 835 and 836 to and through the coil of an electromagnet 837 of a reference point range relay, from which coil the current returns by conductors 838, 839 and 180 to the negative line conductor 134. The magnet 837 attracts its armature and swings the insulated arm 840 secured to it, thereby opening the contacts 238 and closing contacts 841. The opening of the contacts 238 opens the circuit which 55 includes the AZ2C controller, which was previously described as closed to energize the coil 241 of the PRM clutch. The PRM clutch is accordingly rendered ineffective and it will no longer drive the shaft 247, shown in Fig. 63, or its ramifications.

The closure of the contacts 841 cause current to flow from the positive line conductor 126 by the conductor 842, (see Fig. 24), through signal lamps 843, and by conductors 844, 845, 846, 847, and 848 to and through the now closed contacts 841, and by conductors 849, 838, 839 and 180 to the negative line conductor. The signal lamps 843, therefore, light and call the operator's attention to the fact that one of the safety limit devices has acted.

At the same time, current will flow from the positive line conductor 126 by the conductor 842 to four coils 850, each of which is in a separate magnetic lock K, there being 80 four such locks. After passing through the four coils 850, the current returns by conductors 851, 845, 846, 847 and 848, the now closed contacts 841, and the conductors 849, 838, 839 and 180 to the negative line conductor 85 134. Simultaneously, the current flows from the positive line conductor 126 by conductors 852 and 853 to and through four other coils 854 each of which is in one of the magnetic locks K and opposes one of the first mentioned coils 850 in the direction of the flow of current, the current passing from each of the coils 854 by a conductor 855 to the negative line conductor 134.

90 From Fig. 24 it is clear that the coils 854 are permanently in circuit across the line conductors 126 and 134, but the coils 850 are dead until there is a circuit closure, as at the contacts 841, whereupon current flows from the positive line conductor 126 through 95 the previously traced circuit including the contacts 841, and the coils 850 also become energized concurrently with the coils 854.

95 Referring now to Fig. 37, which diagrammatically shows one of the locks K, it will be seen that, when only the coil 850 is energized, a core 855', about which both coils 850 and 854 are wound, becomes magnetized, attracting an armature 856, which is pivoted at 857 and has a locking projection 858 that is adapted to enter a notch in a disk 859 that is mounted on a shaft, which may be any one of the shafts 39, 51, 71 or 81 (Figs. 3 and 5). Therefore, shaft 39, or any of those mentioned 100 may be turned. But, when the other coil 854 becomes energized as well, due to the circuit closure and establishment already described, the current will flow reversely in one of these coils to the direction of its flow through the other coil, each coil neutralizing the magnetic influence of the other coil on the core 855. The core 855 will, therefore, not be magnetized, and a spring 860, will pull the armature 856 to cause it to thrust its locking projection 858 into the notch of disk 859 carried on the shaft, say 39.

105 In this way, the shafts 39, 51, 71 and 81 are locked, when a safety limit stop acts, and cannot be turned until the target computer 110 has been readjusted for a proper resumption 115 120 125 130 of its functioning. Thus, the mechanism for setting the length and azimuth of the base lines PA and PB is protected against inadvertent injury.

- 5 Other safety limit stops are present in the AR2C controller in Fig. 3 and the BR2C controller in Fig. 5, the contact 464 carried by the screw 482 co-acting with the contacts of the first, while the contact 484 co-acts with 10 the contacts of the BR2C safety limit stop. These limit stops act like the others, and the description now given of one will make clear the action of any of them.

From the foregoing, the operation of the 15 target computer under the Ab control will be understood. Its operation under the Ba control is substantially the same, except that it is reversed. That is, the angle PRB is the greater angle instead of the angle ARP, and 20 with this in mind the preceding description is adequate for the comprehension of the operation of the target computer under the Ba control. As previously noted, the use of the Ab or Ba controls meet the requirements of 25 the hereinbefore defined Case I.

One of the conditions covered by Case II, which deals with the receipt of range and azimuth from a single fixed observing station, requires the operation of the target computer under the A control. A problem falling within the category is illustrated in the diagram shown in Fig. 38, wherein the A-station alone is active. Inasmuch as the PA and PB base lines are surveyed quantities 30 that may ordinarily be regarded as constant, these base lines remain the same both as to length and azimuth as they are shown in Fig. 1. It should be understood, however, that other end stations than the illustrated one at 35 40 A and B may exist and be used at will as the A and B-stations, and, as they will have been previously surveyed, the information for setting up alternative or substitute base lines will be available.

45 Under the A control, the A-station observes the range of the target, and an operator sets up the observed range AR, as received from available sources, such as range finders, on a range indicator 9a, shown in Fig. 2, the 50 transmitter 10a operating simultaneously therewith. The transmitter 10a sends the measure of the observed range AR by the cable 11a to the receiver motor 12a in the target computer, shown in Fig. 3.

55 The armature of the receiver motor 12a turns miter gears 861, a shaft 862, other miter gears 863 and another shaft 864, which, through gears 865, turns one side 866' and the center 866" of a differential 866, the differential center 866" turning a shaft 867. This operates the AR1C controller, so that 60 its contact finger 868 engages a contact 869 for increasing observed range AR, or a contact 870 for decreasing range.

65 Assuming that the range is increasing, and

examining Fig. 24, it will be seen that current will flow from the positive line conductor 126 by a conductor 871 to the contact finger 868 and thereby to the contact 869 of the AR1C controller. From here the current flows by 70 a conductor 872, which extends into Fig. 23 and leads to a fixed contact 873 of the master control switch 173, which contact 873 is in the A row of fixed contacts.

Since, by manipulation of the knob 35, the 75 gearing 37 will have been operated to bring the line A on the dial 38 into register with the fixed index, and the rack 155 will have been simultaneously moved to carry the insulation bar 156 into position to cause the 80 brushes carried by it to come into contact with the A row of fixed contacts of the master control switch 173, the current will pass from the previously mentioned contact 873 to the brush 468. It will flow from here through the conductor 469, which extends into Fig. 24, and go to the closed contacts 470, thence going by conductors 471 and 472 to and through coil 473 of the ARM clutch, returning 85 through the conductor 474, the brake coil of 90 the clutch, and conductors 475 and 180 to the negative line conductor 184.

The ARM clutch will then be energized to 95 drive the shaft 476 in a direction corresponding to increasing reference point range. With the shaft 476 turns the worm 477, which drives the worm wheel 478, thereby turning the shaft 479, the gears 480, one side 317", the gears of the center 317" and the other side 317' of a differential 317. The 100 side 317' of this differential turns the gears 318, the shaft 319 and the gear 320, thereby turning the A-station range gear 92 of the target computer. The range gear 92 then turns the gear 481, and thus the A-station 105 range screw 482 of the target computer.

One effect of this is to move the range 110 screw 482 longitudinally, causing the contact 464 to engage one of the contacts of the AR2C controller, say, the contact 887'. Another result of the turning of the range screw 482 is to feed the compound nut 260-260' along this screw, and since it was assumed that the A-station range AR was increasing, this nut will relatively move outwardly 115 to increase the distance from the common center of the gears 91 and 92 to the center of the nut 260-260', so that it will represent the increased AR range.

Obviously, the movement of the nut 260- 120 260' along the A-station range screw should be accompanied by a swinging of the arm 259 of the reference point azimuth gear 93. To cause this, the contact 464 of the AR2C controller engages the contact 887' thereof as mentioned. A consequent flow of current flows from the positive line conductor 126, shown in Fig. 24, by the conductor 232 to the contact 464, to the contact 887', the 125 circuit continuing through the conductor 130

888, which enters Fig. 23, and goes to a fixed contact 874 of the A row in the master control switch 173, proceeding therefrom by the brush 292, which now bears on the contact 874, and a conductor 293, which enters Fig. 24. The circuit continues by the conductor 293 to and through the closed contacts 294, thence going by the conductors 295 and 296 to the coil 297 of the PZM clutch, 5 passing therefrom by the conductor 298 the clutch brake coil and the conductors 299 and 300 to the negative line conductor 134.

The PZM clutch, shown in Fig. 5, now drives the shaft 302, which extends through Fig. 4 and into Fig. 3, where, through the gears 304, it turns one side 97, the gears of the center 97' and the other side 97" of the differential αX , which, through the sleeve 305 and the gears 306, turns another shaft 20 307. This shaft turns the miter gears 308 and the pinion 309, thereby turning the reference point azimuth gear 93 in the direction to conform to the movement of the compound 260—260'.

Now, as the ARM clutch, shown in Fig. 3, turns the shaft 476, the gears 503 rotate the shaft 504, and this operates the safety limit stop AR', which need not be described as it acts like the PR' safety limit stop already 30 discussed. The shaft 504 also acts through the gears 505 to turn the shaft 506, and the gears 507 and 508, thereby operating the observed A-station range counters 509 and 510 of the target computer, which show the AR 35 range from the A station to the target.

The shaft 506, also acts through the gears 519 to turn the shaft 520, so operating the transmitter 13a, which transmits back to the A-station the A-station range AR set up and 40 used in the target computer.

As the shaft 307, shown in Fig. 3, is turned in response to the previously described drive from the PZM clutch, it turns the gears 321, the shaft 322, the center 251' and the side 45 251" of the PRX differential, which, through gears 252, turns the shaft 253, the gears 254 and the shaft 255, which carries the gear 256 that drives the reference point range gear 94 so that it turns in unison with the reference point azimuth gear 93, that 50 there will be no unwarranted change in the measure of reference point range by a drive that is intended to introduce only an azimuth 55 value.

It was shown that the shaft 307 turned because of the drive of the shaft 302 by the PZM clutch, and reference to Fig. 5 will reveal that the shaft 302 at the same time drives 60 through the gears 310, the side 311, the gears of the center 311' and the other side 311" of the δX differential, thereby turning the gears 312, the shaft 313, the gears 314 and the pinion 315 to turn the second reference point azimuth 65 gear 93a simultaneously with the first men-

tioned reference point azimuth gear 93, and to the same amount.

Let it also be noted that the shaft 247 in turning effects a simultaneous and equal drive of the reference point range gears 94, 70 in Fig. 3, and 94a, in Fig. 5, so that the nut 260—260' is exactly the same distance from the common center of the gears 93 and 94 that the nut 260a—260a' is from the common center of the gears 93a and 94a. 75

This parallelism in the turning of the gears and range screws is because the reference point range and azimuth gears and reference point range screws in Figs. 3 and 5 doubly represent exactly the same quantity, as hereinbefore explained. 80

Referring to Fig. 4, it is apparent that the shaft 302 also drives through the gears 525, the shaft 526, the gears 527, the shaft 528, the gears 529, the shaft 530, the worm 531 and the worm wheel 532 to turn the major computed azimuth dial 533. As the shaft 526 turns, it drives, through gears 535, the shaft 536, the worm 537 and the worm wheel 538 to turn the minor computed azimuth dial 539. 90 Thus, the computed azimuth of the reference point range PR is visually disclosed by the reading given by the dials 533 and 539.

As the observed range AR is being sent from the A-station by the transmitter 10a to 95 the target computer, the movement of the target is followed from the A-station by the telescope 1a, there being a simultaneous operation of the azimuth transmitter 2a. The observed azimuth of the AR range is thus 100 sent by the cable 3a to the azimuth receiver motor 4a in the target computer, shown in Fig. 3. The receiver motor 4a turns gears 159, the shaft 160, gears 161, one side 162' and the center of the differential 162, thereby 105 turning the shaft 163, bevel gears and the cam 165 to operate the AZ1C controller.

If the azimuth of the observed range AR be increasing, the contact 167 will engage the contact 168. Thereupon current will flow 110 from the line conductor 126, shown in Fig. 24, by the conductor 170 to contacts 167 and 168, and by the conductor 171, which enters Fig. 23 to a contact 171a in the A row of fixed contacts. The brush 174 bears on contact 171a, under the A control, and the current proceeds from brush 174 by conductor 175, which enters Fig. 24 and goes to the increasing coil 176 of the AZM clutch, continuing by conductor 177, the clutch brake coil 178 and conductors 179 and 180 to the other line conductor 184. 115

The AZM clutch now turns the shaft 209, gears 210, shaft 211, gears 212, shaft 213, gears 214, shaft 215, worm 216, worm wheel 217, shaft 218 and gears 219 to actuate the pointer 220. At the same time shaft 213 also turns gears 222 and the pointer 221. As previously shown, the pointers 220 and 221 co-operate with the dials 63 and 64 to give the 120 125

reading of the azimuth AZ of the observed range AR. In addition, the AZM clutch, through shaft 209, turns worm 223, worm wheel 224, shaft 225, gears 226, one side 227' and the center 227" of the differential 227. The differential center 227" turns the shaft 228, thereby operating the AZ2C controller so that its contact finger 229 engages the contact 230.

10 Reference to Fig. 24 shows that current will then flow from the line conductor 126 by conductors 232 and 233 to contact finger 229 and contact 230; then going by a conductor 919, which enters Fig. 23, to a contact 920' in the 15 A row of contacts in the master control switch 173. As the brush 921' now bears on contact 920', the current will proceed by it and conductor 922', which enters Fig. 24, to closed contacts 923', going from there by conductors 20 924' and 925' to the decreasing range coil 926' of the PRM clutch, and by conductor 242, the brake coil of the clutch and conductor 300 to the other line conductor 134.

As a result, the PRM clutch turns the shaft 25 for decreasing range, the shaft 247 extending through Fig. 4 and into Fig. 3, where it turns gears 248, shaft 249, gears 250, one side 251, the gears of the center 251' and the other side 251" of the differential 30 PRX. The differential side 251" drives gears 252, thus turning shaft 253, gears 254, shaft 255 and the gear 256, which turns the reference point range gear 94, which consequently turns the gear 257 and the reference point range screw 258. The latter moves the compound nut 260-260' longitudinally for decreasing reference point range, and the nut swings the arm 262 of the azimuth gear 91 for increasing azimuth of the AR 35 range, which is what should happen, it having been assumed that the azimuth AZ of the AR range from the A-station was increasing.

With the AZM clutch operating, the shaft 211 also operates the target computer transmitter 5a, (see Fig. 3), which through the cable 6a actuates the receiver 7a at the A-station to show the AZ azimuth set-up in the target computer.

50 At the time when the reference point range gear 94a is actuated to turn the gear 257a and the reference point range screw 258a, the nut 260a-260'a effects a longitudinal sliding movement of the B-station range screw 483 of the target computer. Should the BR range from the B-station, shown in Fig. 38, diminish, the sliding of the range screw 483 will engage the contact 484 carried by it with the contact 875 of BR2C controller.

55 Reference to Fig. 24 shows that there will be a resultant flow of current from the positive line conductor 126 by the conductor 286 to the movable contact 484 of the BR2C controller, the current passing to the contact 875 and flowing through the conductor 876,

which enters Fig. 23, to a fixed contact 877 of the master control switch 173, in the A row of fixed contacts. The brush 878 bears on the contact 877 under the A control, and leads the current to a conductor 879, which 70 enters Fig. 24, and goes to a now closed pair of contacts 880, the current then continuing by conductors 881 and 882 to the coil 883 of the BRM clutch. Passing through the coil 883 the current goes by the conductor 494, 75 the brake coil 495 of the clutch and the conductor 496 and 300 to the negative line conductor 134.

Reverting to Fig. 5, the BRM clutch now 80 drives the shaft 497 in a direction for decreasing B-station range, although the B-station is not transmitting the data, the A-station alone being active. In turning, the shaft 497 drives through the worm 498, the worm wheel 499, the shaft 500, the gears 501, the side 327', the gears of the center 327" and the other side 327"" of the differential 327, the differential side 327" driving through the gears 328, the shaft 329 and the gear 330 to turn the B-station range 90 gear 96 of the target computer. The gear 96 turns the gear 502 and the B-station range screw 483 of the target computer, shifting the compound nut 260a-260'a toward the 95 common center of the gears 95 and 96, this shortening of the distance therebetween being in accordance with the decreasing range BR in the problem of Fig. 38.

While the BR range is decreasing, the 100 azimuth of this range is increasing, since the AR range was said to be increasing, and the combined actions of the reference point range screw 258a and the B-station range screw 483 impart such motion to the nut 260a-260'a that the arm 276 of the B-station azimuth gear 95 of the target computer is turned and the gear 95 with it. This gear turns the pinion 277 and the miter gears 278, thereby driving the shaft 279, the gears 280 and the side 281' and the center 281" of the differential 281. The differential center turns the shaft 282 to operate the BZ2C controller, so that the contact finger 283 thereof is caused to move in a direction away from the contact 284. In so moving, the contact finger 283 comes into its neutral position, due to the position of the cam of the BZ2C controller, the continued turning of this cam causing the roller of the bell-crank lever 115 to be in engagement with the dwell of lesser radius of the cam, whereby the contact finger becomes engaged with the contact 285 of the BZ2C controller.

As a result, current will flow from the positive line conductor 126, shown in Fig. 24, by 120 the conductors 286 and 287 to the contact finger 283, passing thereby to the contact 285, from which the current flows by a conductor 884, which extends into Fig. 23, to a fixed contact 885, in the A row of con- 125

- tacts of the master control switch 173. The brush 437 bears on the contact 885, under the A control, and conveys the current to the conductor 438, which enters Fig. 24, and 5 leads to the coil 439 of the BZM clutch, whence the current flows through the conductor 440, the clutch brake coil 441, and returns through the conductors 442 and 300 to the negative line conductor 134.
- 10 It has been previously shown that the coil 439, when electrified, energizes the BZM clutch to drive the shaft 443 in a direction corresponding to increasing azimuth of the B-station range BR, which is the direction in 15 which the B-station azimuth gear 95 of the target computer was said to be turning. At the same time, the shaft 443 turns the gears 444 and the shaft 445, driving through other gears 446, the shaft 447, the gears 448, the 20 shaft 449, the worm 450, the worm wheel 451, the shaft 452 and the miter gears 453, to cause the pointer 454 to show against the graduations of the dial 67 the major measure of the increased azimuth BZ of the BR range 25 from the B-station to the target. The shaft 447 also actuates the miter gears 455 to turn the pointer 456 to show the minor measure of the increased azimuth BZ. Additionally, the shaft 445 turns the gears 458 to operate 30 the transmitter 5b, which sends the azimuth BZ of the BR range to the B-station, by the cable 6b, which goes to the receiver motor 7b at that station, the receiver motor operating the azimuth indicator 8b.
- 35 In other respects the target computer acts as it does under the already described Ab control. When operating under the B control, the operation of the target computer is similar to its now described action under the 40 A control, except that the B-station is active, and the A-station, and the angle BRP, in the problem, is greater than 45°.
- Another control which is used under Case II is the α control. This is employed when 45 the target computer is receiving the target's range AR and its azimuth from the A-station alone, and the angle ARP is less than 45°. A problem conforming to these conditions is shown in Fig. 39. As in the other problems, the base lines PA and PB, in the diagram of Fig. 39, may remain unchanged, but the position of the target at R will re-proportion the triangulation.
- 50 Under the α control, the A-station will transmit the target's observed range AR to the target computer where its reception operates the receiver motor 12a, which is shown in Fig. 3. Through the gears 861 this receiver motor drives the shaft 862, the gears 863, the shaft 864, the gears 865, and the side 866' and the center 866'' of the differential 866, thereby turning the shaft 867. The turning of the shaft 867 operates the AR1C controller, causing the contact finger 868 to 55 engage the contact 869 for an increasing AR

range, and 878 for a decrease in this range.

Assuming that the A-station observed range AR is increasing, the contact finger 868 of the AR1C controller will engage the contact 869. Thereupon, as shown in Fig. 24, current will flow from the positive line conductor 126 by the conductor 871 to the contact finger 868 of the AR1C controller, passing therefrom to the contact 869, and continuing by the conductor 872, which enters Fig. 23, to the fixed contact 866 in the a row of contacts in the master control switch. Repositioning of the master control switch brushes to the α control position will have placed the brush 468 on the contact 866, so that the current will pass through the brush 468 to the conductor 469, which enters Fig. 24. The conductor 469 leads to the now closed contacts 470, the current flowing therefrom by conductors 471 and 472 to the coil 473 of the ARM clutch, then passing by a conductor 474, and the clutch brake coil to a conductor 475, which joins a conductor 180 that conveys the current to the negative line conductor 134.

90 The ARM clutch consequently turns the shaft 476 in a direction for increasing range, and this shaft drives through the worm 477, the worm wheel 478, the shaft 479, the gears 480, the side 317'', the gears of the center 317' and the other side 317' of the differential 317 to turn the gears 318, the shaft 319 and the gear 320. The gear 320 turns the A-station range gear 92 of the target computer, which accordingly turns the gear 481 and the A-station range screw 482, thereby screwing the latter through the nut 260—260' to move longitudinally of itself, so as to carry the contact 464 against the contact 887.

100 When this engagement is made, the current will flow from the positive line conductor 126, shown in Fig. 24, by the conductor 232 to the contact 464 of the AR2C controller, from which the current passes to the contact 887 and continues by the conductor 888, which enters Fig. 23, and goes to a fixed contact 889 in the α row of contacts of the master control switch 173. From the fixed contact 889, the current flows through the brush 236 then to the conductor 237, which enters Fig. 24, proceeding thereby to the closed pair of contacts 238, from which the current flows by conductors 239 and 240 to the coil 241 of the PRM clutch, then passing through the conductor 242, the brake coil of the clutch and the conductors 243 and 300 to the negative line conductor 134.

110 Hence, the PRM clutch is energized to turn the shaft 247, shown in Fig. 5, in a direction for increasing reference point range. 115 Following the shaft 247 through Fig. 4 and into Fig. 3, it is seen to drive through gears 248, the shaft 249, the gears 250, one side 251, the gears of the center 251' and the other side 251'' of the differential PRX. The 120 125 130

drive continues through the gears 252, the shaft 253, the gears 254, the shaft 255, and the gear 256, which turns the reference point range gear 94. The latter turns the gear 257, thereby turning the reference point range screw 258.

It is thus seen that both the A-station range screw 482 and the reference point range screw 258 are simultaneously turning to advance 10 the compound nut 260—260', whereby the increased observed range AR and the increased reference point range are mechanically set off on their respective range screws 482 and 258, in the already described manner. Reference 15 to Fig. 39 shows that this is in accordance with the problem there shown, and which is treated under the α control, for, if the observed range AR increases, so must the reference point range PR.

20 It is evident that, with the change of the lengths of the AR and PR ranges, the vertex of the ARP angle being on the target, there will be changes in the azimuth of these ranges. Under the α control, the A-station 25 will transmit the azimuth of the observed range AR to the target computer, thereby operating the AR azimuth receiver motor 4a, shown in Fig. 3. This motor drives through the gears 157, the shaft 158, the gears 159, the 30 shaft 160, the gears 161, the side 162' and the center 162" of the differential 162, to turn the shaft 163, thereby operating the AZ1C controller.

The observed range AR from the A-sta- 35 tion, in the problem of Fig. 39, was assumed to be increasing, and the change of azimuth of this range will depend on the target's course. For convenience, this azimuth may be assumed to be increasing. Consequently, 40 the contact finger 167 of the AZ1C controller will be moved to engage the contact 168.

A resulting circuit is established from the positive line conductor 126 through conductor 170, shown in Fig. 24, to the contact finger 167 which extends the circuit to the contact 168, from which it goes by the conductor 171 into Fig. 23 and to a fixed contact 890 in the α row of fixed contacts in the master control switch 173. The brush 174 now bears 50 on the contact 890 extending the circuit by the conductor 175 into Fig. 24, where the conductor 175 leads to the coil 176 of the AZM clutch, the circuit continuing by the conductor 177, the clutch brake coil 178, and the conductors 179 and 180 to the negative line conductor 134.

The AZM clutch now turns the shaft 209, shown in Fig. 3, which then drives through the worm 223, the worm wheel 224, the shaft 60 225, the gears 226, one side 227' and the center 227" of the differential 227, thereby turning the shaft 228 and operating the AZ2C controller to throw the contact finger 229 to engage the contact 231.

65 Current will accordingly flow from the

positive line conductor 126 by the conductors 232 and 233 to the contact finger 229 of the AZ2C controller, passing therefrom to the contact 231, and proceeding by the conductor 234, which enters Fig. 23 and goes to a 70 fixed contact 891 from which the current is conveyed by a conductor 892 to another contact 893 in the α row of fixed contacts of the master control switch. Under the α control, the brush 292 carries the current from the contact 893 to the conductor 293, which enters Fig. 24 and leads to the now closed contacts 294, from which the current proceeds by the conductors 295 and 296 to the coil 297 of the PZM clutch, passing therefrom by the conductor 298, the clutch brake coil and the conductors 299 and 300 to the negative line conductor.

Referring to Fig. 5, the PZM clutch now 85 responsively drives the shaft 302, which extends through Fig. 4 and enters Fig. 3. Here, the shaft 302 drives through the gears 304, the side 97, the gears of the center 97' and the other side 97" of the α X differential, the 90 sleeve extension 305 of the differential side 97" turning and driving through the gears 306, the shaft 307, the miter gears 308 and the pinion 309, to turn the reference point azimuth gear 93. The reference point azimuth gear arm 259 is thus swung, as well 95 as the reference point range screw 258 mounted therein. Accordingly, there is an angular displacement of the compound nut 260—260', which results in swinging the arm 262 of the 100 A-station azimuth gear 91, whereby the latter turns. Thus, the increased azimuth of the increased A-station observed range AR and of the increased reference point range PR is 105 mechanically reproduced in the target computer.

As the AZM clutch turns the shaft 209 in contributing to this accomplishment, the gears 210 act to turn the shaft 211. Other gears 212 drive the shaft 213, gears 214, the shaft 215, the worm 216, the worm gear 217, the shaft 218 and the miter gears 219 to position the pointer 220 to read against the graduations of the PA base line dial to give a major reading of the increased azimuth 110 of the A-station observed range AR. The shaft 213 concurrently turns the miter gears 222 to position the pointer 221, thereby supplementing the just referred to major reading of the increased azimuth of the AR range by a micrometric addition thereto.

In Fig. 5, there are the other reference point azimuth and range gears 93a and 94a, hitherto explained as duplicating the corresponding set in Fig. 3. Manifestly, when the azimuth gear 93, in Fig. 3, is being turned, the shaft 302, Fig. 5, as it is being driven by the PZM clutch, turns the gear 310, and thus drives through one side 311, the gears of the center 311' and the other side 311" of the b X differential, to turn the gears 312, 115 120 125 130

the shaft 313, the miter gears 314, and the pinion 315 to turn the azimuth gear 93a. At the same time, the shaft 313 turns the gears 323 to drive through the shaft 324, the center 270' and the side 270" of the PRX' differential, so turning the gears 271, the shaft 272, the gears 273, the shaft 274 and the gear 275, thereby turning the range gear 94a in unison with the azimuth gear 93a. As previously explained, this prevents a turning of the range screw 258a in response to an azimuth-measuring movement.

The turning of the azimuth gear 93a swings its arm 259a, angularly displacing the compound nut 260a—260a' an amount proportional to the measure of azimuth made by the turning of the reference point azimuth gear 93a.

During the previously described drive 20 from the PRM clutch, which was shown to result in shifting the nut 260—260' along the range screw 258, shown in Fig. 3, the shaft 247 also drives the gears 267, shown in Fig. 5. The gears 267 drive the shaft 268, the gears 269, the side 270, the gears of the center 270' and the opposite side 270" of the PRX' differential, thereby driving through the gears 271, the shaft 272, the gears 273, the shaft 274 and the gears 275, to turn the range gear 94a. This gear then turns the gear 257a and the reference point range screw 258a, thus moving the compound nut 260a—260a' outwardly in accordance with increased reference point range. The nut 260a—260a' has now been shown to have been moved in response to changes in both the reference point range and its azimuth.

When the nut 260a—260a' is so moved, it is 40 apparent that it will also effect a change in the B-station observed range BR and its azimuth, which is a duplication of what actually happens in the field of action. Illustrative of how it happens in the target computer, it is obvious that, in such a problem as is shown in Fig. 39, solved under the α control, when the nut 260a—260a', shown in Fig. 5, is moved outwardly, it slides the B-station range screw 483 longitudinally to cause 50 it to carry the contact 484 of the BR2C controller into engagement with the contact 485.

Thereupon, current will flow from the positive line conductor 126, shown in Fig. 24, by the conductor 286 to the contact 484, passing 55 to the contact 485, and proceeding by the conductor 486, which enters Fig. 23, to the fixed contact 894. Under the α control the brush 488 bears on the contact 894 and carries the current to the conductor 489, which 60 enters Fig. 24 and leads to the now closed contacts 490. After passing therethrough the current flows by conductors 491 and 492 to and through the coil 493 of the BRM clutch, continuing from here by the conductor 494 65 through the clutch brake coil 495, and re-

turning by the conductors 496 and 300 to the negative line conductor 134.

The clutch BRM consequently turns shaft 497, shown in Fig. 5, and the worm 498, thereby driving through the worm wheel 499, the 70 shaft 500, the gears 501, the side 327' the gears of the center 327" and the other side 327''' of the differential 327 to turn the gears 328, the shaft 329 and the gear 330 to thereby turn the B-station range gear 96. The latter turns the gear 502 and the B-station range screw 483. Hence, this range screw and the reference point range screw 258a co-operate to shift the nut 260a—260a', the full 80 positioning of this nut including the already described resultant displacement due to azimuth movement of the reference point azimuth gear 93a. This latter movement also swings the arm 276 of the B-station azimuth gear 95, turning the latter gear. The B-station azimuth gear 95 then turns the pinion 277, which thus drives through the miter gears 278, the shaft 279, the gears 280, the side 281' and the center 281" of the differential 281, so 85 turning the shaft 282 and operating the BZ2C 90 controller. The shaft 279 also drives the gears 325, the shaft 326, the center 327" and the side 327''' of the differential 327, thereby turning the gears 328, the shaft 329 and the gear 330, which turns the B-station range 95 gear 96 in unison with the B-station azimuth gear 95, whereby there is an elimination of movement of the B-station range screw 483 in response to an azimuth actuation.

The above referred to operation of the 100 BZ2C controller results in the contact finger 283 thereof engaging the contact 285. Thereupon, the current will flow from the positive line conductor 126, shown in Fig. 24, by the conductors 286 and 287 to the contact 105 finger 283 of the BZ2C controller, passing to the contact 285, and proceeding by the conductor 884, which enters Fig. 23, to the fixed contact 895 in a row of fixed contacts of the master control switch 173. The brush 437 now bears on the contact 895 and carries the current to the conductor 438, which enters Fig. 24 and leads to the coil 439 in the BZM clutch, the current flowing therefrom by the conductor 440, the brake coil 441 of the 115 clutch, and the conductors 442 and 300 to the negative line conductor 134.

The BZM clutch accordingly drives the shaft 443 in a direction for increasing B-station azimuth. The shaft 443 drives through the worm 459, the worm wheel 460, the shaft 461, the gears 462, the side 281'', the center 281''' and the shaft 282 which operates the BZ2C controller to separate the contact arm 283 from the contact 285.

When the BZM clutch is operating as described, it also turns the gears 444, thereby driving through the shafts 445, 447, 449 and 452 and their associated gearing to set the pointer 454 against the graduations on the 130

main PB base line dial 67 to give a major reading of the azimuth of the B-station range BR. The shaft 447 also turns the miter gears 455 to set the pointer 456 against the dial 68 to provide a finer azimuth reading of the BR range. This range is set on the counters 517 and 518, shown in Fig. 5.

Through previously traced drives, the A-station observed range AR is set upon the 10 counters 509 and 510 shown in Fig. 3, the computed reference point range PR being set up on the counters 338 and 340, Fig. 4, and the generated reference point range showing on the counters 666 and 668. The azimuth 15 of the reference point range PR is shown by the setting of the computed and generated reference point azimuth dials 533 and 704. In other ways, the target computer acts under the *a* control in the same way as under the 20 previously described controls.

Under the *b* control the target computer acts as it does under the *a* control, except that the B-observing station is active, while the A-station is idle, and the angle BRP, in the 25 problem of Fig. 39, is less than 45°. The *b* control may, therefore, be understood from what has been said of the *a* control, it being remembered that under the *b* control there are reversed conditions, the B-station instead of the A-station, alone furnishing data to the target computer. In general, the action of the target computer embraced in Case II has been made plain.

In Case III, whether it be due to low visibility, a smoke screen, demolition, or any other cause both end observing stations A and B are inactive. The target computer is then operated under the P control, and receives data as to the target's course and speed only, 40 from airplane observations. The P control is also used for the initial setting of the target, and for restoring it to normal if it becomes stalled.

Under the P control, the target computer 45 is provided with data from the airplane observations that furnishes a basis for an estimate of the target's range and bearing from the reference point P. First using the estimated reference point range, the handle JRL, 50 shown in Fig. 4, is pushed in and turned. The inward thrust of the handle JRL, shown in Fig. 4, is of sufficient extent to move the shaft 657 longitudinally an amount that disengages the crown gear 656 mounted thereon, 55 and shown in Fig. 6, from the gear 655 thereby permitting the shaft 657 to be easily turned. As the shaft 657 turns, it drives through the worm 658, the worm wheel 659, the shaft 660, the gears 661, the shaft 662, the 60 gears 663, the shaft 664 and the gears 665 and 667 to set the estimated reference point range on the generated range counters 666 and 668. In turning the shaft 657 and the worm 658, the latter drives through the worm gear 659, the shaft 660, the gears 669, the shaft 670, the

gears 671, the side 672' and the center 672" of the differential 672, thereby turning the shaft 674. This shaft drives through the gears 675, the shaft 676, the gears 896, a shaft 897 and miter gears 898, thereby operating 70 the PRJC controller.

If the target's reference point range is increasing, for example, as in Fig. 1, the contact finger 899 will be swung to engage the contact 900. Current will then flow from the positive line conductor 126, shown in Fig. 24, by a conductor 901 to the contact finger 899 of the PRJC controller, passing therefrom to the contact 900, and proceeding by a conductor 902, which enters Fig. 23, to a fixed contact 903 in the P row of fixed contacts of the master control switch 173. Under the P control, the brush 236 bears on the contact 903 and conveys the current to the conductor 237, which enters Fig. 24 and leads to the now closed contacts 238, from which the current flows by the conductors 239 and 240 to the coil 241 of the PRM clutch, continuing therefrom by the conductors 242 and 300 to the negative line conductor 134.

The PRM clutch will accordingly be energized to turn the shaft 247 shown in Fig. 5 and extending into Fig. 4, in a direction for increasing reference point range P. In so turning, the shaft 247 turns the gears 331, so driving through the shaft 332, the gears 333, the shaft 334 and the gears 335 and 336 to operate the counters 338 and 340 to set up the estimated computed reference point range. As previously set forth, the counter exposed to show this range will depend on the range magnitude.

Meanwhile, the shaft 247 is also turning the gears 248, shown in Fig. 3, thereby driving through the shaft 249, the gears 250, the side 251, the gears of the center 251' and the other side 251" of the PRX differential, so turning the gears 252, the shaft 253, the gears 254, the shaft 255 and the gear 256 to turn reference point range gear 94. This range gear turns the gear 257 and the reference point range screw 258, moving the nut 260-260' outwardly to add in the increase in the reference point range.

Simultaneously, the shaft 247 turns the gears 267, shown in Fig. 5, and drives through the shaft 268, the gears 269, one side 270, the gears of the center 270' and the other side 270" of the PRX' differential, so turning the gears 271, the shaft 272, the gears 273, the shaft 274 and the gear 275. This turns the reference point range gear 94a, in the B-section of the target computer and hence, the reference point range screw 258a, thus shifting the nut 260a-2.0a' in accordance with the increase in reference point range.

Having set up the estimated reference point range, its estimated azimuth is introduced into the target computer. To accomplish this, the handle JZL, shown in Fig. 4, is

pushed in, the disengagement of the crown gear 696 from the gear 695 permitting the handle JZL to turn easily. This handle is then turned, actuating the shaft 697. This shaft, as shown in Fig. 4, drives through the gears 698, the shaft 699, the gears 700, the shaft 701 and the worm 702 to turn the worm wheel 703 and the generated reference point azimuth ring dial 704. The shaft 697, through the gears 705, turns the shaft 706 and the worm 707 to turn the worm wheel 708 and the supplementary fine-reading generated reference point azimuth ring dial 709. The shaft 697 also drives through the gears 710 and 904, a shaft 905, gears 906, one side 907' and the center 907" of a differential 907, thereby turning a shaft 908, which operates PZJC controller.

Should the azimuth of the reference point also be increasing, as in the problem of Fig. 1, a contact finger 909 of the PZJC controller will be swung to engage a contact 910. Thereupon, current will flow from the positive line conductor 126, shown in Fig. 24, by the conductors 901 and 911 to the contact finger 909 of the PZJC controller, passing therefrom to the contact 910, and proceeds by a conductor 912, which enters Fig. 23, to a fixed contact 913 in the P row of fixed contacts of the master control switch 173.

Under the P control, the brush 292 bears on the contact 913 and conveys the current to the conductor 293, which enters Fig. 24, and leads to the now closed contacts 294 from which the current continues to flow by the conductors 295 and 296 to and through the coil 297 of the PZM clutch, thereafter passing through the conductor 298, the clutch brake coil and the conductors 299 and 300 to the negative line conductor 134.

Because of this electrification of the PZM clutch, the latter turns the shaft 302, shown in Fig. 5, in a direction corresponding to the increasing azimuth of the reference point range. The shaft 302 extends through Fig. 4 and into Fig. 3, where it turns the gears 304 and thus drives through the side 97, the gears of the center 97' and the other side 97" of the aX differential, so turning the sleeve 305 and continuing the drive through the gears 306, the shaft 307, the miter gears 308 and the pinion 309, to turn the reference point azimuth gear 93 and its arm 259. This angularly displaces the nut 260—260' in accordance with the increase of azimuth of the reference point range, the manner of setting off the increase of this range on the reference point range screw 258, under the P control, having also been explained.

Now, because of the double mechanical reproduction in the target computer of the reference point range and azimuth, the shaft 302 will also turn the gears 310, shown in Fig. 5, thereby driving through the side 311, the gears of the center 311' and the other side

311" of the bX differential, so turning the gears 312 and continuing the drive through the shaft 313, the miter gears 314 and the pinion 315 to turn the other reference point azimuth gear 93a simultaneously with and to the same extent as the reference point azimuth gear 93. The nut 260a—260'a in Fig. 5, consequently has the same azimuth metering angular displacement as the nut 260—260', in Fig. 3.

Furthermore, as shown in Fig. 4, the shaft 302 turns the gears 525, thus driving through the shaft 526, the gears 527, the shaft 528, the gears 529, the shaft 530 and the worm 531 to turn the worm wheel 532, and, hence, the dial 533, which reads against the index 534 to show the major reading of the computed azimuth of the reference point range. The shaft 526 also drives through the gears 535, the shaft 536 and the worm 537 to turn the worm wheel 538, and so the dial 539, which gives a finer reference point azimuth sub-divisional reading that is supplementary to the major reading had from the dial 533.

From the immediately foregoing explanations and variously traced drives, it is clear that, by the proper turning of the JRL handle, the estimated reference point range is set up on both the computed and generated range counters 340 and 666, respectively. Both these counters should give the same reading, and with both sides of the differential 672 operating at the same speed, the center of this differential will hold the shaft 674 stationary, thereby also so maintaining the gears 675, the shaft 676, the gears 677 and the dial 678. The dial mark 679 will then remain stationary opposed to the index 680, showing that the computed and generated reference point counters are matched. It has also been made manifest that the estimated azimuth of the reference point range has been set up by the JZL handle on the computed and generated reference point azimuth dials 533 and 704, respectively. Moreover, the double sets of the reference point range and azimuth gears, and range screws, etc., in the target computer have also been set in accordance with the estimated reference point range and its azimuth, as hereinbefore set forth.

After this set-up, the target computer is operated by its power drive, in accordance with the generated reference point range and azimuth.

In Fig. 4, are shown the counters 666 and 668, one of which is exposed at a time in accordance with the condition of a short or a long range, and the exposed counter shows the short range. The counters are operated by a drive from the JR integrator, shown in Fig. 6. It has been shown that the time-controlled power shaft 245 acts through the gears 626, shown in Fig. 6, to turn the shaft 627, which drives through the gears 628, the shaft

629, the gears 630, the shaft 631, the gears 632, the shaft 633, the gears 646, the shaft 647 and the gears 648 to rotate the JR integrator disk 649.

5 In the previously described manner, the integrator disk 649 drives through the balls 650 to turn the roller 651 so that its movement corresponds to the generated reference point range. That is, the balls 650 are positioned 10 radially of the disk 649 in correspondence with the range rate, as previously explained, and the length of time that the balls are rotated at the angular velocity which their radial position permits the disk 649 to apply to 15 them, gives a resultant turning of the integrator roller 651 that is equivalent to the change in generated range. Hence, if dr = the range rate of the generated range, t = time, and JR = the change in generated 20 range, then $tdr = JR$. Since the roller 651 delivers the measure of the generated range, the gears 652 transmit it through the shaft 653, the gears 654, the shaft 149, and, for short ranges, the gears 145 and 139 to the shaft 141.

25 The shaft 141 turns the gear 655 which, through the crown gear 656 drives the shaft 657, which extends into Fig. 4. Here, the shaft 657 turns the worm 658 which turns the worm-wheel 659, thereby driving through the shaft 660, the gears 661 the shaft 662, the gears 663, the shaft 664 and the gears 665 and 30 667 to operate the generated range counters 666 and 668.

35 Although, after the initial manual setting, the handle JRL is disconnected from the shaft 657, the latter still turns since the JR integrator continues to drive it, as above outlined. Furthermore, the continued action of the shaft 657 maintains the drive through the 40 shafts 660, 670, and the intervening gears, to turn the side 672' and the center 672" of the differential 672, so driving through the shaft 674, the gears 675, the shaft 676, the gears 896, the shaft 897 and the gears 898 to operate 45 by power the PRJC controller, in the way that it was manually operated for the initial set up. The controller PRJC energizes the PRM clutch, as already described, and this drives the shaft 247, which drives the gears 50 331, shown in Fig. 4, and the shaft 332, which through the gears 333 turns the shaft 334 that, through the gears 336 and 339 operates the computed range counter 340. The shaft 332, through the gears 673, also turns the side 55 672''' of the differential 672, both sides of this differential now being turned, and both the computed and generated range counters 340 and 666 are operating simultaneously, while the dial 678 is stationary if these counters 60 are running in synchronism.

65 Similarly, after the JZL handle is disconnected from the shaft 697, that shaft becomes power-driven. In Fig. 6, the time-controlled power shaft 245 drives through the gears 626, the shaft 627 and the gears 684 to turn

the disk 685 of the JZ integrator. The position of the balls 686 radially of the integrator disk 685 is representative of the target's azimuth rate, which is multiplied by the rotational drive of the integrator disk, so that 70 the movement of the integrator roller 687 represents the change in generated azimuth of the target's reference point range. The roller 687 drives through the gears 688, the shaft 689, the gears 690, the shaft 150, the gears 147 and 142, the shaft 144 and the gears 691, to turn the shaft 692. This shaft extends into Fig. 4, where it drives through the gears 693, the shaft 694, the gear 695 and the crown gear 696 to turn the shaft 697. 80

The shaft 697 drives through the gears 710 and 907, the shaft 905 and the gears 906 to turn the side 907' and the center 907" of the differential 907, thereby turning the shaft 908, and operating the PZJC controller. As 85 before shown, this controller energizes the PZM clutch, causing it to turn the shaft 302, shown in Fig. 5. The shaft 302 turns the gears 542, which drive through the shaft 543, the gears 914, the shaft 915, which enters 90 Fig. 4, there turning the gears 916 to turn the side 907''' of the differential 907. Both sides of this differential, therefore, turn and the center 907" thereof tends to remain stationary. The shaft 697 through the gears 698 and 705, and the already described drives from each, actuate the generated azimuth dials 704 and 709 in accordance with any increase or decrease of the generated azimuth 95 of the reference point range. 100

It was assumed that the airplane discovered that the target's range and azimuth was increasing as related to the reference point P, and it was shown how the setting of the reference point range counters and azimuth 105 dials in accordance with the estimated reference point range and azimuth operates the reference point azimuth and range gears 93 and 94, shown in Fig. 3, as well as the duplicate azimuth range gears 93a and 94a, illustrated in Fig. 5.

Considering first the gears 93 and 94, in Fig. 3, if the target's reference point azimuth increases, the nut 260—260' moves the range screw 482 longitudinally to cause it to carry the contact 464 of the AR2C controller into engagement with the contact 465. Current then flows from the positive line conductor 126, shown in Fig. 24, by the conductor 232 to the contact 464, passing to the contact 465, and proceeding by the conductor 466, which enters Fig. 23, to the fixed contact 466', passing therefrom by a conductor another contact, another conductor, the fixed contact 467 and another conductor to a fixed contact 917 in the P row of fixed contacts of the master control switch 173. Under the P control, the brush 468 bears on the contact 917 and conveys the current to the conductor 469, which enters Fig. 24 and leads to the 115 120 125 130

now closed contacts 470, thence going by the conductors 471 and 472 to the coil 473 of the ARM clutch. From here the current flows through the conductor 474, the brake coil of the clutch, and returns by the conductors 475 and 180 to the negative line conductor 134.

The ARM clutch is thus energized to turn the shaft 476 in a direction corresponding to increasing A-station range. The shaft 476 drives through the worm 477, the worm wheel 478, the shaft 479, the gears 480, one side 317", the gears of the center 317", and the other side 317' of the differential 317, thereby turning the gears 318. This continues the drive through the shaft 319 and the gear 320 which turns the A-station range gear 92. This range gear turns the gear 481 and the A-station range screw 482 coincidently with the previously described turning of the reference point range screw 258. The compound nut 260—260', therefore, is advanced outwardly on both the reference point and the A-station range screws 258 and 482, respectively.

Obviously, this advance of the nut 260—260' is in accord with the already described turning effort of the reference point azimuth gear 93, and this results in a turning effort of the A-station azimuth gear 91. The latter, therefore, sufficiently turns the pinion 263, the miter gears 264, the shaft 265, the gears 266, one side 227" and the center 227" of the differential 227, and the shaft 228 to operate the AZ2C controller. For increasing A-station azimuth, the contact finger 229 is swung to engage the contact 230, after which current will flow from the positive line conductor 126, shown in Fig. 40, by conductors 232 and 233 to the contact 229, from which it flows to the contact 230. Thence, the current flows by a conductor 919, which enters Fig. 23, to a contact in the master control switch, proceeding by conductors 920 and 921, and intervening contacts to the fixed contact 922. Under the P control, the brush 174 rests in the contact 922 and then carries the current to the conductor 175, which enters Fig. 24 and leads to the coil 176 of the AZM clutch. Passing through this coil the current flows through the conductor 177, the clutch brake coil 178, and returns by the conductors 179 and 180 to the negative line conductor 134.

65 The AZM clutch is accordingly energized to turn the shaft 209, shown in Fig. 3, in a direction corresponding to increasing azimuth. It, therefore, drives through the worm 223, the worm wheel 224, the shaft 225, the gears 226, the side 227', the gears of the center 227" and the other side 227'" of the differential 227, to turn the gears 266, the shaft 265, the miter gears 264 and the pinion 263, thereby turning the A-station azimuth gear 91. Thus, both the A-station and reference

point azimuth gears 91 and 93, respectively, turn coincidently and at the same time the A-station and reference point range screws 482 and 258 are turning, whereby the resultant positioning of the nut 260—260' is representative of the target's position.

As the shaft 476 is turned it drives through the gears 503 and the shaft 504, and the rest of the previously described drive, to set up the A-station range on the counter 510. Also, the shaft 209 turns the gears 210 and shaft 211, and the balance of the already described drive, to position the pointers 220 and 221 to set up the azimuth AZ of the A-station range AR on the azimuth dials 63 and 64. Therefore, though the A-station is not in use, the information it would ordinarily transmit to the target computer is computed by that instrument from reference point conditions learned from airplane observations.

In a similar manner, the B-station relations to the target are ascertained. It was shown that the reference point range gear 94a, illustrated in Fig. 5, turns simultaneously with the reference point range gear 94, shown in Fig. 3. When the range gear 94a turns, it shifts B-station range screw 483, shown in Fig. 5, longitudinally, thus causing the contact 484 of the BR2C controller to engage the contact 485.

Thereupon, current will flow from the positive line conductor 126, shown in Fig. 24, by the conductor 286 to the contact 484 of the BR2C controller, from which the current passes to the contact 485, and proceeds by the conductor 486, which enters Fig. 23, to the contact 894, to another contact 487 and continues to the contact 923 in the P row of fixed contacts of the master control switch 173. At this time, the brush 488 bears on the contact 923 and carries the current to the conductor 489, which extends into Fig. 24 and leads to the now closed contacts 490. Thence, the current flows by the conductors 491 and 492 to the coil 493 of the BRM clutch, continuing by the conductor 494, the clutch brake coil 495 and the conductors 496 and 300 to the negative line conductor 134.

Referring to Fig. 5, the BRM clutch is thus energized to turn the shaft 497 in a direction corresponding to increasing B-station range BR. The shaft 497 drives through the worm 498, the worm wheel 499, the shaft 500, the gears 501, the side 327', the gears of the center 327" and the other side 327'" of the differential 327, to turn the gears 328. The latter turn the shaft 329 and the gear 330, thereby turning the range gear 96, and, consequently, the gear 502 and the B-station range screw 483.

Since the arm 259a, shown in Fig. 5, of the reference point azimuth gear 93a, turns in an increasing direction, the compound nut 260a—260'a' will bear against the arm 276 of the B-station azimuth gear 95, and actuate

this gear and the pinion 277 sufficiently to drive through the miter gears 278, the shaft 279, the gears 280, the side 281' and the center 281'' of the differential 281, thereby turning 5 the shaft 282. This operates the BZ2C controller, and since the direction of the azimuth of the BR range is increasing, the contact finger 283 will be swung to engage the contact 285.

10 Thereupon current will flow from the positive line conductor 126, shown in Fig. 24, by the conductors 286 and 287 to the contact finger 283, passing to the contact 285 and proceeding by the conductor 884, which extends 15 into Fig. 23 and leads to the contacts 885 and 895, and then to the contact 924, in the P row of fixed contacts of the master control switch 173. Under the P control, the brush 437 bears upon contact 924, and conveys the 20 current to the conductor 438, which extends into Fig. 24 and leads to the coil 439 of the BZM clutch, continuing by the conductor 440, the clutch brake coil 441, and the conductors 442 and 300 to the negative line conductor 134.

25 Consequently, the shaft 443, shown in Fig. 5, turns in a direction for increasing azimuth EZ of the B-station range BR. The shaft 443, so turning, drives through the worm 459, the worm wheel 460, the shaft 461, the gears 30 462, one side 281'', the center 281'' of the differential 281, thus turning the shaft 282 and the BZ2C controller to separate the contact arm 283 and the contact 285.

It is now manifest that both the reference 35 point range screw 258a and the B-station range screw 483 turn at the same time advancing the nut 260a—260a' and that the reference point and B-station azimuth gears likewise turn coincidently, contributing to 40 the action of the last mentioned range screws in positioning the compound nut 260a—260a' in a position indicative of that of the target.

When the shaft 497 turns it drives the gears 511 and shaft 512, and through the hereinbefore traced drive sets up the B-station range BR on the counter 518. Similarly, when the shaft 443 turns, it turns the gears 444 and the shaft 445 to operate the drive to the pointers 454 and 456, to set them 50 against the graduations of the dials 67 and 68, to show the azimuth BZ of the B-station range BR.

In other respects, the target computer, under the P control, acts as previously described, in connection with the other controls, plotting the reference point range and its azimuth and transmitting data to the battery computer, concerning the reference point range and the target's course and speed.

60 The various operations hereinbefore set forth involving the different actions and controls of the target computer, are illustrative of the great flexibility of this instrument, and its adaptability to following the target 65 wherever it may go. In the foregoing de-

scription of the target computer's actions, wherever the target's range and its azimuth was assumed to be increasing, it could have been regarded as decreasing just as well, and vice versa. The mechanism and circuits are present, so that, if desired, the action under the reversed conditions can be easily followed in the light of what has been described.

70 The artillery computer system, as thus far described has been shown to keep the reference point station informed as to the target's observed range and its azimuth as viewed from the A and B observing stations, and to compute and generate the target's range and azimuth from the reference point P, and also to compute the target's course and speed. It now becomes desirable to use the information furnished by the target computer for setting the guns, and these are quite apt to and probably would be a different location than the reference point station P, where the target computer may be positioned, though not necessarily so. When this is so, it is necessary, among other things, to relocate the range and to determine the azimuth of the relocated 80 range with precision, since this becomes the line of fire.

85 Accordingly, another instrument is included in the system and is descriptively designated as the battery computer. This instrument has its mechanical combination diagrammatically illustrated in Figs. 26 to 33 inclusive, these figures, when arranged as shown in Fig. 34, forming a single diagrammatic view.

90 Referring now to Fig. 1, the battery computer is located at, or is in communication with, the station G, which is also the position of the guns. Another triangle is accordingly present, formed by the base line P—G and the lines P—R and G—R, the line P—R representing, as before, the reference point range. The line G—R is indicative of the present range from the battery, and would be the line of fire, if the target were stationary. If, 100 however, the target moves, the distance R—R' will represent the extent of the target's travel in a given time, and the line G—R' will be indicative of the predicted or advance range, and will be the actual line of fire for a 105 moving target, whereby the projectile will be fired at the place in advance of the target, which will be reached by the target at the time the projectile arrives there.

110 In placing the battery computer in use, a number of initial settings are made. The base line P—G, shown in Fig. 1, is mechanically introduced into the battery computer, the handle PGL, shown in Fig. 29, being pushed in and turned to set off its length. The PGL handle turns the shaft 925, which passes from Fig. 29 into Fig. 31, there driving through gears 926, a shaft 927, a worm 928 mounted thereon, and a worm wheel 929 to turn the screw threaded shaft 930. This 115 120 125 130

shaft is threaded through an extension of a reference point slide 931, which acts as a travelling nut when the threaded shaft 930 is turned.

- 5 Thus, as the PGL handle is operated, the slide 931 is moved, its extension being formed into a pointer 932 that reads against a base line scale 933 to show the length of the base line P—G, of Fig. 1, in thousands of yards.
- 10 In Fig. 31, the shaft 925 also drives through miter gears 934 to turn a pointer 935, which reads against graduations on a supplemental dial 936 to show the hundreds of yards additional to the thousands of yards in the line
- 15 P—G, of Fig. 1, the dial 936 being subdivided to show as fine a variance as 10 yards, or finer if desired. The combined readings against the scale 933 and the dial 936 shows the length of the line P—G to be about 2750 yards,
- 20 which corresponds to the length of the line P—G in Fig. 1.

The operation of the PGL handle to effect this reading thus moves the slide 931, and, as the reference point azimuth gear 937 and 25 the reference point range gear 938 are carried by the slide 931, the common center of these gears is shifted to be a distance from the common center of gears 939 and 940 that is representative of the length of the base line P—G, 30 of Fig. 1. The gear 939 is designated the relocated azimuth gear, while the gear 940 is termed the relocated range gear, and their common center is indicative of the battery position G. A magnetic lock K, similar to 35 those used in the target computer, is shown in Fig. 29, and locks the shaft 925 against movement, except when the power is on in the battery computer and this instrument is in operating condition.

40 In considering the setting of the azimuth of the base line P—G, it will be assumed, for the sake of clearness, that the dials, etc., are in a zero position at the outset. Referring now to Fig. 40, the full line triangle PRG 45 corresponds to the same angle in Fig. 1, but is segregated from the rest of the problem in Fig. 40 to show with greater clarity its treatment by the battery computer. In its full line position in Fig. 40, the triangle PRG 50 represents the actual geographical triangulation, while the dotted triangle PR₁G₁ is indicative of a corresponding triangulation as set up by mechanical elements in the battery computer.

55 Now, with the base line P—G swung into the position it assumes in the instrument, it will be coincident with the zero line M—N, and will be represented by the length P—G. The reference point range will then be represented by the dotted line PR₁, and the 60 relocated range will be denoted by the dotted line G₁—R₁. The dotted triangle PR₁G₁ will then be equivalent to the full line triangle PRG, but will be in the assumed 65 position.

Having set off the length of the base line P—G, as above described, and wishing to set its azimuth in the battery computer, the crank handle $\alpha L'$, shown in Fig. 29, is pushed in and turned. Thereby, the shaft 941, which extends into Fig. 31, is turned and drives through the gears 942 to turn the shaft 943, which enters Fig. 28, and drives through gears 944, a shaft 945, other gears 946, a shaft 947 and a worm 948 mounted thereon to turn a worm wheel 949 and a dial 950.

The graduations on the dial 950 read against a fixed index 951 to show a coarse azimuth of the base line P—G from the zero line M—N, in Fig. 40. The shaft 947, shown in Fig. 28, also drives through spiral gears 952 to turn the dial 953, the graduations on which read against a fixed index 954 to show a supplementary and finer reading of the azimuth of the base line P—G.

To promote ready understanding of the relation of the full and dotted triangles of Fig. 40, reference is now made to Fig. 31, where the mechanical reproduction of the dotted triangle PR₁G₁, which is equivalent to the triangle PRG that represents the real conditions, exists. In Fig. 31, the common center of the gears 937 and 938 represents the reference point P, and the common center of the gears 939 and 940 indicates the position G of the battery, the imaginary line from the common center of the gears 937 and 938 to the common center of the gears 939 and 940 being representative of the base line P—G in its P—G₁ position. The distance from the common center of the gears 937 and 938 to the center of a compound nut 955 symbolizes the reference point range PR, which is shown by the line PR₁ in the dotted triangle of Fig. 40. In Fig. 31, the distance from the common center of the gears 939 and 940 to the center of the nut 955 indicates the relocated range GR shown in the dotted triangle as the line GR. The compound nut 955, is similar to the compound nuts 260—260' and 260a—260a' of the target computer, and, like each of these, represents the target R.

When the zero graduation of the major dial 950, shown in Fig. 28, is opposite the index 951, and the minor dial 953 has its zero graduation alined with the index 954, it is as though the base line P—G, shown in Fig. 40, occupied its position P—G₁, coincident with the zero line M—N. Therefore, when the P—G base line azimuth dials 950 and 953 are set, as before set forth, to show the azimuth MPG of the base line P—G, this base line P—G may be considered to have been moved through the reflex angle MPG to the full line position P—G, in Fig. 40. But, though the dials indicate this change, the imaginary line, in Fig. 31, between the common center of the reference point gears 937 and 938 and the common center of the battery position gears 939 and 940, which imaginary line represents

the base line $P-G_1$, has not changed its position. Hence, the reading of the dials 950 and 953 corresponds to the full line position $P-G$, shown in Fig. 40, and, to preserve the triangulation, the full line triangle PGR must be regarded as being swung about the reference point P through the angle MPG to the position it is shown to occupy in Fig. 40.

Whether the triangle PRG be in its dotted or full line position, the azimuth of its sides PR and GR is read from its base line $M-N$. Consequently, while the triangle PRG is in its dotted line position PR_1G_1 , its base line in its position $P-G_1$ is coincident with the zero line $M-N$, of Fig. 40, and the reference point range PR_1 has an azimuth equal to PZ_1 , and, when the triangle PRG is swung to its full line position, it has an azimuth $PZ=PZ_1\theta$.

20 The azimuth of the dotted position G_1-R_1 of the relocated range equals RZ_1 , while the azimuth of the full line position of the relocated range $G-R$ equals RZ , which is the azimuth of the relocated range RG from the zero line $M-N$.

It is apparent that though the $P-G$ base line azimuth dials 950 and 953 are turned from a zero position to give a reading of the $P-G$ base line azimuth MPG , there is no resultant movement of the reference point azimuth gear 937 and the relocated azimuth gear 939, shown in Fig. 31. Thus, there is no change in the position of the arm 956 of the reference point azimuth gear 937, nor of the arm 957 of the relocated azimuth gear 939, because while the dials 950 and 953 have, as stated, been moved to set up the reading of the azimuth MPG of the base line PG , the reference point azimuth pointers 988 and

40 989, which read, respectively, against the graduations of the dials 950 and 953, have been standing still. Now to set off the true azimuth of the reference point range PR from the instrument zero line, the pointer 988 (Fig. 28) must first be turned, through the angle θ to reach the zero graduation of the dial 950, after which the angular measurement of the azimuth PZ of the reference point range PR must be further set off on

50 the dial 950 by a continued turning of the pointer 988, the supplementary pointer 989 reading against the dial 953 to give the finer portion of the reading. Then the reference point azimuth pointers will show the true reference point azimuth PZ of the reference point range PR from the zero line $M-N$, as shown in Fig. 40, as well as in Fig. 1, while the arm 956 has moved through the angle θ plus PZ .

60 Before explaining the method of operating the reference point azimuth dials 950 and 953 above referred to reference will again be made to the operation of the handle aL' to show that the resultant turning of the shaft 941, turns the gears 958, shown in Fig.

31. The gears 958 drive through a shaft 959, the center 960" and one side 960' of a differential 960, the differential side 960' turning a pair of gears 961. One of these gears turns the side 962' and the center 962" 70 of a differential 962, so turning a shaft 963, which operates a controller RZC , swinging a contact finger 964 against a contact 965.

As a result current will flow from the positive line conductor 126, shown in Fig. 35, by conductors 966 and 967 to the contact finger 964, passing to the contact 965 and proceeding by a conductor 968 to and through a coil 969 of a clutch RZM , the current then going by a conductor 970 to the clutch brake coil 971, and returning by conductors 972 and 973 to the negative line conductor 134.

Such energization of the RZM clutch effects the turning of a shaft 974, shown in Fig. 29 and extending into Fig. 28, from which it enters Fig. 27 and drives through gears 975, a shaft 976, gears 977, another shaft 978, other gears 979, the latter turning a shaft 980 and a worm 981 carried thereby. The worm 981 turns a worm wheel 982, which turns with the dial 983, the latter having graduations thereon which read against a fixed index 984 to show the azimuth of the relocated range, but under the operation just described, the relocated azimuth dial 983 will also turn through an angle equal to the angle MPG , so that, in Fig. 40, the relocated range line G_1-R_1 may be regarded as having turned clockwise through an angle equal ⁹⁵ ¹⁰⁰ MPG until it has reached its full line position $G-R$, which has an azimuth from the base line $P-G$ equal to RZ .

As the shaft 974 turns, it also turns gears 985, shown in Fig. 28, thus turning a shaft 986, which enters Fig. 31 and through gears 987 turns a side 962" of the differential 962 in opposition of the opposite side 962' thereof, so that, when the turning of the handle aL' is stopped, the contact finger 964 is brought back to its neutral, or "off", position. Thus the RZM clutch becomes de-energized, and the shaft 974 ceases turning as, hence, does the drive that actuates the relocated azimuth dial 983, shown in Fig. 27.

It has now been shown that, when the aL' handle is operated to set the dials 950 and 953, shown in Fig. 28, to give the correct azimuth of the base line $P-G$, it also brings about an incorrect reading of the azimuth of the reference point range and the relocated range. When it was said that the reference point azimuth pointers 988 and 989 were reset to give the correct reference point azimuth from the zero graduations of the dials 950 and 953, it was not explained how this was done, but now will be.

The handle PZL , shown in Fig. 29, is pushed in and turned, thus turning a shaft 990, and driving through gears 991, one side 130

992' and the center 992" of a differential 992, to turn a shaft 993, thereby operating a controller PZ1C, so that a contact finger 994 will engage a contact 995.

5 Thereupon, current will flow from the positive line conductor 126, shown in Fig. 35, to the contact finger 994, which carries it to the contact 995, from which current flows by conductors 996 to 997 to the now closed contacts 10 998, whence the current continues by conductors 999 and 1000 to a coil 1001 in a clutch PZM'.

15 From here the current flows through a conductor 1002, a brake coil 1003 of the clutch and conductors 1004 and 973 to the negative line conductor 134.

20 As a result, the PZM' clutch now turns a shaft 1005, which is shown in Fig. 29 and extends into Fig. 31, where it turns a worm 20 1006, which drives through a shaft 1007, gears 1008, a shaft 1009, miter gears 1010 and a pinion 1011, thereby turning the reference point azimuth gear 937.

25 The shaft 1007 also drives through gears 1012, a shaft 1013, the center 1014" and a side 1014' of a differential 1014, gears 1015, a shaft 1016 and a pinion 1017, whereby the reference point range gear 938 is turned in unison with the reference point azimuth gear 30 937, thus avoiding an actuation of a reference point range screw 1018 in response to an azimuth measurement.

35 While the shaft 1005 is turning to effect the turning of the reference point azimuth gear, it also drives through gears 1019, shown in Fig. 29, this turning a shaft 1020, gears 1021 and a shaft 1022, which enters Fig. 28, there driving through gears 1023, a shaft 1024, a worm 1025, a worm wheel 1026, a shaft 40 1027 and miter gears 1028, which turn the major reference point azimuth pointer 988. The shaft 1022 also turns miter gears 1029, which turn the minor reference point azimuth 45 989. Thus, the pointers 988 and 989 are turned until they are set to indicate the reference point azimuth on the dials 950 and 953.

50 The shaft 1020, shown in Fig. 29, also turns gears 1030 and a side 992'" of the differential 992, which tends to swing the contact finger 994 of the PZ1C controller back to its neutral position.

55 The target computer was shown to have a transmitter 20, which was actuated to transmit the reference point range by the cable 21 to a reference point range receiver motor 22 in the battery computer, as will be readily understood from Fig. 2. The receiver motor 22 is also shown in Fig. 28, where, through a drive to be presently described, it operates the 60 reference point range counter 1062. As such operation begins, the counter 1062 will doubtless have a reading that related to a former operation of the battery computer, and does not correspond to the current reading of the 65 reference point range counters 340 and 666 of

the target computer, shown in Fig. 4. Therefore, the handle PRL, shown in Fig. 28, is pushed in and turned, thereby turning a shaft 1063, which drives through gears 1064, one side 1065' and the center 1065" of a differential 1065, thus actuating a shaft 1066, which operates a controller PR1C to swing a contact finger 1067 into engagement with a contact 1068 or 1069, say the contact 1068.

70 Thereupon, current will flow from the positive line conductor 126 to the contact finger 1067, passing to the contact 1068 and flowing through conductors 1070 and 1071 to and through the now closed contacts 1072, and continuing by conductors 1073 and 1074 to 75 a coil 1075 of the PRM' clutch, proceeding therefrom by a conductor 1076, the clutch brake coil 1077 and conductors 1078 and 973 to the negative line conductor 134.

80 With this energization, the clutch PRM' drives a shaft 1079, Fig. 29 which enters Fig. 31 and drives through gears 1080 and 1081, a shaft 1082, other gears 1083, turning a shaft 1084 that enters Fig. 28. In the latter Figure, the shaft 1084 turns gears 1085 and a shaft 1086, which operates the reference point range counter 1062, until it is synchronized with the similar counters 340 and 666 of the target computer, whereupon the handle PRL 90 is no longer turned. Thereafter, the receiver motor 22 drives through gears 1087, a shaft 1088 and other gears 1089 to turn the shaft 1063, thereby maintaining either a positive or a negative operation of the just described drive, as long as the movement of the target results in an increase or decrease in the reference point range. The shaft 1084 also turns gears 1084' and the side 1065'" of the differential 1065 to separate the contacts 1067 and 1068.

100 During the just described drive, the shaft 1079, shown in Fig. 31, drives through a worm 1090, a worm wheel 1091, a shaft 1092, gears 1093, one side 1014", the gears of the center 1014" and the other side 1014' of the differential 1014. The differential side 1014' turns the gears 1015, the shaft 1016 and the gear 1017, so turning the reference point range gear 938, which turns a gear 1094 and the reference point range screw 1018. Thus, the nut 955 is moved a distance from the common center of the gears 937 and 938 that corresponds to the reference point range set up on the counter 1062, in Fig. 28. The azimuth of the reference point range is also transmitted from the target computer to the battery computer, as will be more fully set forth hereinafter. The swinging of the arm 956 of the reference point azimuth gear 937, or the movement of the compound nut 955 by the range screw 1018, or both, results in the swinging of the arm 957 or a longitudinal sliding of the relocated range screw 1031, or both shown in Fig. 31. When there is a motion of the re-located range screw 1031 a contact 1032 car- 110 115 120 125 130

ried thereby will be brought into engagement with a contact 1033 or 1033' of a controller RRC. Assuming contact has been made with contact 1033, current will flow from the 5 positive line conductor 126, shown in Fig. 35, by the conductor 966 to the movable contact 1032 of the RRC controller, passing to the contact 1033 and continuing by conductors 1034 and 1035 to the now closed contacts 1036, 10 thence proceeding by conductors 1037 and 1038 to a coil 1039 of a clutch RRM, from which the current flows through a conductor 1040, the clutch brake coil 1041 and conductors 1042 and 973 to the negative line conductor 15 tor 134.

The RRM clutch then turns a shaft 1043, shown in Fig. 29 and which enters Fig. 28, where it turns gears 1044. These gears turn a shaft 1045, which enters Fig. 31, and there 20 drives through gears 1046, one side 1047', the gears of the center 1047'' and the opposite side 1047''' of a differential 1047, thus continuing to drive through gears 1048, a shaft 1049 and a pinion 1050, to turn the relocated 25 range gear 940. The gear 940 turns the gear 1051, which turns the relocated range screw 1031 to set off thereon a change in relocated range that is in a direction which corresponds to that in which the compound nut 955 is being 30 driven, as before described.

At the same time, the shaft 1043, which extends from Fig. 28 into Fig. 27 also turns gears 1052, shown in Fig. 27, and thus drives through a shaft 1053, other gears 1054 and a 35 coupled shaft 1055, to operate a counter 1056 to show the altered relocated range.

When there is a motion of the relocated azimuth arm 957 due to the movement of the compound nut 955 or the arm 956 the relocated azimuth gear 939 drives through a pinion 1057, a shaft 1058, gears 1059, another shaft 1060, gears 1061, one side 960'''', the gears of the center 960'' and the opposite side 960' of the differential 960. Thus, the drive 40 continues through the gears 961, one side 962' and the center 962'' of the differential 962, whereby the shaft 963 operates the controller RZC.

By reason of the establishment of an electrical circuit, as described, the clutch RZM operates the shaft 974, which resets the relocated azimuth dial 983, shown in Fig. 27, by an amount which will position the dial 983 to show the true azimuth of the relocated range 55 when read against the index 984.

Since, in the instrument, the P—G base line is not given any angular displacement, it remains coincident with the zero line M—N, of Fig. 40. As the reference point and relocated 60 azimuth gears 937 and 939, and the reference point and relocated range screws 1018 and 1031, and the nut 955 become adjusted, as described previously, the positions of these elements correspond to the dotted triangle 65 PR₁G₁, and the dials give readings which, as

shown, correspond to the full line triangle PRG, in Fig. 40, and the sides of this triangle read from the zero line M—N, which in the instrument corresponds to the indices of the dials, giving the true azimuth of the base line 70 P—G, the reference point range PR and the relocated range GR, as also shown in Fig. 1.

There are other initial settings made in the battery computer, for the initial velocity of the projectile at the muzzle of the gun, 75 for atmospheric conditions, for the height of the gun, for the velocity of the wind and the wind's direction, and also for the transmission interval, which is the time elapsed from the making of observations at the observing stations and extends through the period of sending instructions for the setting of the guns to the movement of firing the guns, at which latter time the time of flight of the projectile begins. These ballistic corrections are so interrelated that it will be advisable to unfold the explanations regarding them in the sequence in which they become effective. 80

In Fig. 1, the relocated range GR is shown 85 to be the present line of sight from the battery G to the target R, and it is prolonged beyond R in that figure to form one side of a vector diagram. The vector is RD and represents the target's course and speed, and in the battery computer this vector is mechanically reproduced in the form of a target's course and speed screw 1095, shown in Fig. 32. The common center of target's course gear 1096 and the target's speed gear 1097 is the zero end of the mechanical vector 90 RD, the magnitude of which is represented by the distance from the just mentioned zero common gear center to the center of a pin 95 projecting from a travelling nut 1098, which is slidable in a slot of an arm 1099 that extends from the target's course gear 1096. 100

The graphical vector RD, in Fig. 1, is resolved into two components, one being R—R^b along the line of sight G—R, and it represents the rate of change of relocated range. The other component as shown in Fig. 1 is an azimuth component R—D'' perpendicular to the line of sight and represents the target's deflection. These components are 105 mechanically expressed in the battery computer, the slide 1100, shown in Fig. 32, corresponding to the component R—R^b that represents the rate of change of relocated range, and another slide 1101, shown in Figs. 31 and 32, representing the component R—D'', which corresponds to the rate of movement of the target at right angles to the line of sight, or knots deflection. 110

The arm 1099 and pin 1098 are set to correspond to target course and speed as already determined by the target computer by handles TSL, shown in Fig. 28, and THL, shown in Fig. 27. When the handle TSL is turned 115 it drives through a shaft 1425, shown in Fig. 120 130

28, gears 1426, one side 1427' and the center 1427" of a differential 1427, so turning a shaft 1428 to operate a controller TSC, so that its contact finger 1429 swings into engagement with one of a pair of contacts, say 5 the contact 1430.

Reference to Fig. 35 shows that current will then flow from the positive line conductor 126 to the contact finger 1429, passing 10 to the contact 1430, and continuing by a conductor 1431 to the coil 1432 of a clutch TSM, proceeding by a conductor 1433, the clutch 75 brake coil 1434 and conductors 1435 and 973 to the negative line conductor 134.

Now receiving actuation from the shaft 15 1109, shown in Fig. 31, the TSM clutch turns a shaft 1436, which drives through gears 1437, a shaft 1438, gears 1439, a shaft 1440 and gears 1441 to turn a dial 1442, which reads 20 against a fixed index 1443, to show the target's speed. The shaft 1438 enters Fig. 32, where it drives through gears 1444, a shaft 1445, gears 1446, one side 1447' and the center 1447" of a differential 1447, so turning a 25 shaft 1448. This shaft drives through gears 1449, a shaft 1450 and a gear 1451, which turns the target's speed gear 1097, thus longitudinally displacing the travelling nut 1098 along the target's speed screw 1095. In 30 Fig. 28, the shaft 1436 also turns gears 1474, so turning the side 1427'" and the center 1427" of the differential 1427, thus returning the contact finger 1429 back to its neutral position, when the target's speed has been set 35 up.

The handle THL, shown in Fig. 27, is turned to set the target's course, and it turns a shaft 1452, which turns gears 1453, one side 1454' and the center 1454" of a differential 1454, thus turning a shaft 1455, which turns gears 1456, and a shaft 1457, thus operating a controller THC.

Accordingly, current will flow from the positive line conductor 126, shown in Fig. 35, 45 to a contact finger 1458 of the THC controller, passing to a contact 1459, thence flowing by a conductor 1460, a coil 1461 of a controller THM', a conductor 1462, the clutch 50 brake coil 1463, and conductors 1464 and 973 to the negative line conductor 134.

As a result, the clutch THM', driven from the shaft 1109, shown in Fig. 32, turns a shaft 1465, which drives through gears 1466, one side 1467' and the center 1467" of a differential 1467, thus turning a shaft 1468, which drives gears 1469 and 1470, another shaft 1471, miter gears 1472 and a pinion 1473. This pinion turns the target's course gear 1096, so swinging the slotted arm 1099 thereof 60 and displacing the nut 1098.

The slide 1100 is moved so that the distance of the median line of its slotted arm from the common center of the gears 1096 and 1097 represents the rate of change of relocated 65 range, while the distance of the median line

of the slotted arm of the slide 1101 indicates the rate at which the target is crossing the line of sight.

First considering the component that represents the rate of change of relocated range, 70 the slide 1100, corresponding to this component, positions a pair of balls 1102 radially of a disk 1103 of a generated relocated range integrator JR'. The disk 1103 is power-driven, a motor 1104, in Fig. 29 being time-controlled by clockwork 1105 to be synchronized with standard time, this motor driving through gears 1106, a shaft 1107 which extends into Fig. 30, gears 1108, a shaft 1109 which passes through Fig. 31 and enters Fig. 32, gears 1110, a shaft 1111, gears 1112 and a shaft 1113 with which turns the disk 1103. Since the position of the balls 1102 represents the rate of change of relocated range (dr') and the disk 1103 is uniformly rotated in accordance with time (t) there is a multiplication of the rate by time, the product being equivalent to the change in generated relocated range or tdr'. Accordingly, the roller 1114, shown in Fig. 32, turns 80 with a movement that is equivalent to the change in generated relocated range. The roller 1114 turns a shaft 1115, which drives through gears 1116, a shaft 1117, other gears 1118, a shaft 1119 gears 1120 and a shaft 1121, which enters Fig. 27 and turns gears 1122 and a shaft 1123, thereby operating a counter 1124 to show the generated relocated range. The computed relocated range and the generated relocated range should match, 85 and in Fig. 27 the counters 1056 and 1124 are shown to give the same reading. Means are provided to show quickly and without especial scrutiny, whether these ranges do 90 match. To this end, the shaft 1053 not only drives to operate the relocated range counter 1056, but it also turns gears 1125, and thus one side 1126' and the center 1126" of a differential 1126, which tends to turn a shaft 1127 95 in one direction. Now, the shaft 1123 turns gears 1128, a shaft 1129, gears 1130, and thus the side 1126'" of the differential 1126, so tending to turn the shaft 1127 in the opposite direction, whereby so long as the computed relocated range and the generated 100 relocated range remain equal, the shaft 1127 is simultaneously and equally urged for rotation in opposite directions and, therefore, remains stationary. Consequently, it does not turn miter gears 1131, nor the dial 1132. A line 1133 on the dial 1132 thus remains opposite a fixed index 1134, and the operator may tell at a mere glance that the computed 105 and generated relocated ranges are matched. Just as easily, he may detect when they are 110 not matched.

As the relocated range rate slide 1100 is moved to position the balls 1102 in accordance with the relocated range rate component of the target's course and speed vector, a rack 115

at its outer end turns a gear 1135, and miter gears 1136, which drive through a shaft 1137, other gears 1138, a shaft 1139, miter gears 1140 and a pinion 1141, to shift a rack 1142. The setting of this rack also gives a measure of the rate of change of relocated range. The rack 1142 carries a pin 1143, which extends into a slot in a pivoted arm 1144 of a multiplying device for range prediction. This range prediction device includes a slide 1145, which is provided with a slotted cross-bar 1146 in which is mounted a screw 1147 on which is mounted a travelling nut 1148, which has a pin that projects into the slot of the arm 1144. The screw 1147 has an unthreaded portion 1149 upon which is mounted a worm wheel 1150 that is adapted to be driven by a worm 1151. As will be explained later, the worm 1151 turns in response to the time of flight plus the transmission interval, and this sum is multiplied by the rate of change of relocated range, the product being the prediction in yards to be added to the present range to give the predicted, or advance range. To accomplish this, the pin of the travelling nut 1148 is moved longitudinally of the screw 1147, so that its pin acts against the walls of the slot in the arm 1144 and thus displaces the slide 1145, and, as already explained, the pin 1143, of the rate of change of relocated range slide 1142, also actuates the slotted arm 1144, the resultant movement of the slide 1145 being proportional to the number of yards algebraically added to the relocated range to give the advance range. In other words, the movement of the slide 1145 represents the range prediction in yards.

As it moves, the prediction slide 1145 turns a pinion 1152, and, thus, miter gears 1153, which drive through a shaft 1154, gears 1155, a shaft 1156, other gears 1157, one side 1158' and the center 1158" of a differential 1158, so tending to turn a shaft 1159. The shaft 1159 operates a controller CRC, and it is also subject to the effect of another drive from the shaft 1121, which represents the measure of the generated relocated range, as previously explained. The shaft 1121 drives through gears 1160, one side 1161' the gears of the center 1161" and the other side 1161'" of a differential 1161, spur gears 1162, bevel gears 1163, a shaft 1164 other gears 1165, a side 1158'" and the center 1158" of the differential 1158, thereby tending to turn the shaft 1159.

It is thus seen that the generated relocated range tends to cause the shaft 1159 to turn, and the shaft 1156 also tends to turn the shaft 1159; whereby the controller CRC is operable in response to the algebraic sum of the generated relocated range and the prediction increment, which sum amounts to the advance range, or $R + (t + t_i) dr$ where R = present range and dr = rate of change of range, t = time of flight and t_i = transmission interval.

Consequently, a contact finger 1166 of the CRC controller is responsively turned to engage one or the other of a pair of contacts, say the contact 1167. Current then flows from the positive line conductor 126, shown 70 in Fig. 35, by a conductor 1168 to the contact finger 1166 of the CRC controller, passing to the contact 1167, and continuing by a conductor 1169 to a coil 1170 of the CRM clutch, whence the current flows through a conductor 75 1171, the brake coil 1172 of the clutch, and conductors 1173 and 973 to the negative line conductor 134.

With the CRM clutch so energized, there is a power drive from the motor-driven power 80 shaft 1109 through gears 1174, shown in Fig. 33, a shaft 1175, which extends into Fig. 26, and continues the drive through gears 1176 and a shaft 1177 that enters Fig. 27. There the shaft 1177 drives through gears 1178 and 85 a shaft 1179, so that the CRM clutch drives through a shaft 1180, gears 1181, a shaft 1182, gears 1183, a shaft 1184, other gears 1185, another shaft 1186, gears 1187 and a shaft 1188, which enters Fig. 32. In this figure, the 90 drive continues through gears 1189, a shaft 1190 which enters Fig. 33, gears 1191, another shaft 1192, thereby turning miter gears 1193 and a pinion 1194. The latter turns a toothed disk 1195 of a time of flight mechanism, this 95 disk being provided with a series of spirally disposed holes 1196. A pinion 1197 has radially disposed pins 1198 projecting from its periphery to enter the disk holes 1196, whereby, as the disk 1195 is turned, the position of the pinion 1197 will shift radially thereof, so that a shaft 1199 on which the pinion 1197 is mounted, will turn in accordance with the measure of the time of flight of the projectile that is fired from the gun. 105

By way of explanation, it is pointed out that the time of flight increases more rapidly than the range, and the inner end of the spiral line of holes 1196 in the disk 1195 is the position the pinion 1197 will have for the 110 lowest range that can be considered, and, as the range increases, the pinion 1197 moves outwardly, the outer end of the spirally arranged line of holes represents the highest range that may be dealt with, and it is in 115 excess of any likely requirement, as is the low limit.

The spiral of holes 1196 is laid out in accordance with such a curve as is shown in the graph of Fig. 41, (Sheet 13) in which it may 120 be seen that the time of flight near the zero point changes slowly, as it would near the center of the disk 1195. As the range increases, it is apparent, in Fig. 41, that the time of flight increases more and more rapidly, as does the rotation of the pinion 1197 as it approaches the outer edge of the disk 1195. 125

The pinion 1197 turns the shaft 1199, which drives through gears 1200, a shaft 1201, gears 1202, one side 1203' and the center 1203" of a 130

differential 1203, so turning a shaft 1204, which operates a controller TFC to swing its contact finger 1205 into engagement with either of a pair of contacts, as, for example, 5 the contact 1206.

Then, current will flow from the positive line conductor 126, shown in Fig. 35, by a conductor 1207 to the contact finger 1205, passing to the contact 1206, and continuing 10 by a conductor 1208 to and through a coil 1209 of a clutch TFM. The current proceeds by a conductor 1210, the brake coil 1211 of the clutch, and the conductor 973 to the negative line conductor 184.

15 As the power shaft 1109 drives through the gears 1212, shown in Fig. 33, a shaft 1213 and the now energized clutch TFM, the latter drives through a shaft 1214, gears 1215 and a shaft 1216, which enters Fig. 32, 20 and drives through gears 1217, a shaft 1218 and gears 1219 to turn a shaft 1220, which turns with the center 1221" of a differential 1221, in accordance with the time of flight.

The transmission interval is now added to 25 the time of flight by operating a handle TIL, shown in Fig. 27. This handle turns a shaft 1222, which enters Fig. 32, and hence, a broad-faced gear 1223 carried thereby. When the TIL handle is pulled out, the gear 1223 is 30 moved into a dotted position 1223', so that it only turns a range gear 1224, which drives through other gears 1225, a shaft 1226, other gears 1227, a shaft 1228 and a pair of miter gears 1229 to turn a pointer 1230, which 35 shows by its movement the measure of the transmission interval as it is introduced.

The shaft 1226 carries the measure of the transmission interval to gears 1231, which drive through one side 1221', the gears of 40 the center 1221" and the other side 1221'" of the differential 1221. As the center 1221" of this differential was shown to deliver the measure of the time of flight, the side 1221'" of the differential turns in accordance with 45 the algebraic sum of the time of flight plus the transmission interval. This sum is carried along by gears 1232, a shaft 1233, gears 1234 and a shaft 1235 to the worm 1151, which it was previously stated was turned in accordance 50 with the sum of the measure of the time of flight plus the transmission interval, thus proving the correctness of and explaining the reason for that statement.

While the CRM clutch is effecting the 55 drive, as described, it turns the shaft 1188, which, in Fig. 32, drives through a pair of gears 1236, a shaft 1237, gears 1238, another shaft 1239, and gears 1240 to turn a shaft 1241. The shaft 1241 turns the center 1161" 60 and the side 1161'" of the differential 1161, and thereby drives through gears 1162, gears 1163, the shaft 1164, gears 1165, one side 1158" and the center 1158" of the differential 1158, so turning the shaft 1159 to operate 65 the contact finger 1166 of the CRC controller

to bring it to its neutral position, when the correct measure of advance range has been introduced, as above described.

It was shown that when the CRM clutch is driving as above set forth, the shaft 1190 is 70 turned, and, in Fig. 33, the shaft 1190 at such times turns a worm 1242, which then turns a worm wheel 1243 and a shaft 1244, which has a main threaded screw portion 1245 that is mounted in a slotted cross bar 1246 of an initial velocity slide 1247 of a multiplier. The turning of the screw 1245 shifts a travelling nut 1248 longitudinally of the screw, which has a pitch that varies in accordance with the variance of the function of the 80 quantity as represented by the movement of the screw. The nut as it is shifted carries a pin that projects into the slotted arm 1249, whereby the slide 1247 is shifted also. The initial velocity multiplier is also actuated by 85 the operator, who turns a handle vL, shown in Fig. 33. This turns a shaft 1250 and gears 1251, a shaft 1252 and gears 1253, thus turning a dial 1254 until the initial velocity of the gun is read against a fixed index 1255. 90 This action also turns a screw threaded portion 1256 of the shaft 1250, thus shifting a sleeve 1257 on the threaded portion. The sleeve 1257 is provided with a pin 1258 that enters and also shifts the slotted arm 1249, 95 the product of its movement and that of the travelling nut resulting in a movement of the initial velocity slide 1247. The slide 1247 has a rack that turns a pinion 1259 and miter gears 1260, so driving through a shaft 1261, 100 gears 1262, a shaft 1263, others gears 1264, one side 1265' and the center 1265" of a differential 1265, thus turning a shaft 1266.

Another correction is sent to the shaft 1266, for the hereinbefore described turning of the 105 shaft 1190 also effects the turning of another worm 1267, also shown in Fig. 33, which turns a worm wheel 1268, a shaft 1269 and on screw 1270, which has a variable thread in accordance with the variance of the function of the 110 involved quantity, and is operated thereby to shift a travelling nut 1271. The screw 1270 is mounted in a slotted cross bar 1272 of a slide 1273 of an atmosphere multiplier. The operator turns the handle AL, so turning a 115 shaft 1274, gears 1275, a shaft 1276 and gears 1277, thus turning a dial 1278 that reads against a fixed index 1279 to show the atmospheric conditions. As the shaft 1274 turns, its screw threaded portion 1280 shifts a sleeve 1281 threaded thereon, and which carries a pin 1282. This pin and a pin from the travelling nut 1271 extend into a slotted arm 1283 and their combined movements shift the atmosphere slide 1273, which has a rack that turns a pinion 1284 and miter gears 1285. These gears drive through a shaft 1286, gears 1287, a shaft 1288 and gears 1289, so turning 125 a side 1265'" and the center 1265" of the dif- 130

ferential 1265, to effect a turning of the shaft 1266.

Thus, the shaft 1266 turns in response to two corrections, due to the initial velocity at 5 the muzzle of the gun and to the atmosphere. The shaft 1266 extends into Fig. 26 where it drives through gears 1290, a shaft 1291, gears 1292, one side 1293', the gears of the center 1293" and the other side 1293''' of a 10 differential 1293.

Other corrections are here added through the differential 1293 as will now be explained. Having ascertained the velocity of the wind, the operator turns the handle WSL, shown 15 in Fig. 26, so turning a shaft 1294 and gears 1295, which turn a shaft 1296, gears 1297 and a wind velocity dial 1298, the latter reading against a fixed index 1299 to show the velocity of the wind in miles per hour. During 20 the making of this setting, the shaft 1294 also drives through gears 1300, a shaft 1301, gears 1302, one side 1303' and the center 1303" of a differential 1303, thus turning a shaft 1304. This shaft drives through gears 25 1305, a shaft 1306 and a gear 1307 to turn a wind speed gear 1308, which through another gear 1309 turns the wind speed screw 1310.

The wind direction is set up by the operator who turns the handle WZL, which turns 30 a shaft 1591, that drives through gears 1592, one side 1593', the gears of the center 1593", and the other side 1593''' of a differential 1593. The side 1593''' of the differential drives through gears 1594, a shaft 1595, gears 35 1596 and 1597, a shaft 1598, miter gears 1599 and a pinion 1600, to turn the wind direction gear 1311.

During this drive, the gear 1597 drives another gear 1601, a shaft 1602 and gears 40 1603, so turning the side 1303''' and the center 1303" of the differential 1303, whereby the shaft 1304 is turned. The shaft 1304 drives through gears 1305, the shaft 1306 and the gear 1307, thus turning the wind's 45 speed gear 1308 in unison with the wind's direction gear 1311, so that there shall be no actuation of the wind's speed screw in response to a wind direction setting. In turning, the shaft 1598 also drives through miter gears 1604, so turning the wind direction pointer 1605, which reads against a dial 1606 to show the direction of the wind.

When the wind's direction gear 1311 turns in accordance with the wind's direction the 55 travelling nut 1312, which is mounted in the slotted arm of the wind's direction gear 1311, is displaced.

The wind speed screw 1310 constitutes a mechanical wind vector, the distance there- 60 on from the common center of the wind speed and direction gears 1308 and 1311, respectively, to the center of the pin of a travel- 65 ling nut 1312 threaded on the screw 1310 representing the wind vector WV shown in Fig. 42.

The vector WV has a range component WS coincident with the direction of the advance range and a cross component WZ perpendicular to this range, and the setting of the travelling nut 1312 by the handles WSL and WZL, through the above described drives, results in the pin of the nut 1312 shifting the range component wind slide 1313 and the cross component slide 1590. The slide 1313 carries a pin 1314 that enters and actuates a pivoted and slotted arm 1315, which acts on a pin projecting from a travelling nut 1316. The nut 1316 is threaded onto a screw 1317 that has a thread of variable pitch 70 since the function of the quantity represented by its movement is variable. The screw 1317 is mounted in a slotted cross bar of a wind range component slide 1318, which is moved by movement of the pin of the travelling nut 1316. 75

The nut 1316 is also moved along the screw 1317, since shaft 1218, shown in Fig. 27, turns in response to the time of flight, and drives through gears 1319, a shaft 1320, gears 1321, another shaft 1322, other gears 1323, a shaft 1324, gears 1325, a shaft 1326, gears 1327, and a shaft 1328, which enters Fig. 26. In the latter figure, the shaft 1328 drives through gears 1329, a shaft 1330, a worm 1331, a worm wheel 1332 and an unthreaded portion 1333 of the screw 1317. This screw accordingly shifts the nut 1316, and the movement of the slide 1318 is due both to the actuation of the range component wind slide 1313 and the turning of the screw 1317, as just described, is equal to the range component of the wind multiplied by the time of flight. The slide 1318 has a rack that mechanically transmits the product 90 through a pinion 1334, miter gears 1335, a shaft 1336, gears 1337, one side 1338' and the center 1338" of a differential 1338, so turning 95 a shaft 1339. 100

A correction for the height of the battery is also introduced through the differential 1338. For this purpose, a handle h1, shown 110 in Fig. 26 is turned, thus turning a shaft 1340, which enters Fig. 27, there driving gears 1341, a shaft 1342, and other gears 1343, which turn with the battery height dial 1344, which reads 115 against a fixed index 1345. The shaft 1340 has a threaded portion 1346, which, in turning, shifts a travelling nut 1347, which has a pin that extends into and actuates a pivoted slotted arm 1348. The shaft 1188 which 120 was shown in turn in accordance with the predicted range drives through gears 1349, a shaft 1350, a worm 1351, a worm wheel 1352 and an unthreaded portion 1353 of a screw 1354. The turning of the latter shifts another travelling nut 1355, which has a pin 125 projecting into the slot of the pivoted arm 1348. The combined movements of the travelling nuts 1347 and 1355 shift the height slide 1356 an amount equivalent to a function of 130

the height of the battery multiplied by the predicted range.

Turned by a rack on the slide 1356 is a pinion 1357 and miter gears 1358, which turn a shaft 1359 that enters Fig. 26, and drives gears 1360, one side 1338" and the center 1338" of the differential 1338, to turn the shaft 1339.

The shaft 1339 is now shown to turn both 10 in response to multiplications involving the range component of the wind and the height of the battery. These combined values are transmitted from the shaft 1339, through gears 1361, a shaft 1362, gears 1363, and a 15 shaft 1364 to the center 1293" and the side 1293"" of the differential 1293. The side 1293"" was also shown to be turned in response to corrections for the atmosphere and the time interval. Consequently, the differential side 20 1293"" drives through gears 1365 to turn a shaft 1366 in accordance with corrections due to atmosphere, the time interval, the wind and the height of the battery.

The shaft 1366 enters Fig. 27, and there 25 drives through gears 1367, a shaft 1368, and other gears 1369, thus turning a shaft 1370 which turns the center 1371" and a side 1371' of a differential 1371. Since it was shown that the shaft 1188 drives in accordance with 30 the measure of the predicted range, it follows that the shaft 1186, shown in Fig. 27, transmits the predicted range through gears 1372 to the side 1371"" and the gears of the center 1371" to the side 1371' of the differential 1371. 35 Therefore, the side 1371' of the differential turns in accordance with the predicted range, plus corrections for the atmosphere, the initial velocity, the range component of the wind and the height of the battery.

40 Trial shots at the target may either overshoot or fall short of their objective, and any such inaccuracy may be offset by an arbitrary range correction in the setting of the guns. The arbitrary range correction is introduced 45 by turning the handle RCL, shown in Fig. 27. This action turns a shaft 1373, gears 1374, a shaft 1375, gears 1376, another shaft 1377 and gears 1378, which turn with a dial 1379. This dial shows the number of yards in either 50 direction necessary to correct the relocated advance range, and it reads against a fixed index 1380. As this is done, the shaft 1375 also turns gears 1381, one side 1382' and the center 1382" of a differential 1382, so turning a shaft 1383.

Now, as the side 1371' turns in response to the predicted range plus corrections for atmosphere, the initial velocity, the range component of the wind and the height of 60 the battery, these combined values are transmitted through the gears 1384 and the side 1382"" of the differential 1382 to the center 1382" thereof. Thus, the differential center 1382" turns the shaft 1383 in accordance with 65 the predicted range plus corrections for at-

mosphere, the initial velocity, the range component of the wind and the height of the battery, plus the arbitrary range correction, the ultimate algebraic sum thereof resulting in the final corrected range. The shaft 1383 70 operates a counter 1385 to show this range, and also drives through gears 1386, a shaft 1387, other gears 1388, a shaft 1389 and gears 1390 to operate the transmitters 29, shown in Fig. 27. The transmitter 29 communicates by 75 the cable 30 to the battery, as indicated in Fig. 2, showing the gun range by an instrument 31, and, if desired, the reading may be minutes of arc of gun elevation.

Referring again to Fig. 27, the shaft 1387 80 also drives through gears 1391, a shaft 1392 which enters Fig. 26, gears 1393 and a shaft 1394, which enters Fig. 33, and there drives through gears 1395, one side 1396' and the center 1396" of a differential 1396, thereby 85 turning a shaft 1397 to operate a controller RQC. A contact finger 1398 of this controller is thus swung to one of a pair of contacts, say a contact 1399.

Thereupon current will flow from the positive line conductor 126, shown in Fig. 36, by conductors 1400, 1401 and 1402 to the contact finger 1398, passing to the contact 1399, and continuing by a conductor 1403 to a post 1404, thence flowing by a conductor 1405, a post 1406, a conductor 1407, a now closed pair of contacts 1408, a conductor 1409, a post 1410, conductors 1411 and 1412 to a coil 1413 of a clutch RQM. The current continues to flow by a conductor 1414, the clutch 1415 and a conductor 1416 to the negative line conductor 134.

A drive is thus established from the power shaft 1175, shown in Fig. 33, through the RQM clutch, whereby this clutch drives 90 through gears 1417, a shaft 1418, gears 1419, and a shaft having a screw 1420. The drive feeds a carriage 1421 which carries a range pencil 1422. At the same time, the shaft 1418 turns gears 1423, one side 1396"" and the center 1396" of the differential 1396, thus 95 operating the shaft 1397 to return the contact finger 1398 to its neutral position as soon as the measure of the final corrected range is 100 set off.

The pencil 1422 is adapted to trace the final 105 corrected advance range, as it is relocated at the battery, on a record sheet 1424, which is like the record sheet 604 of the target computer, and need not be discussed at length.

Referring to Fig. 32, the pin 1098 positions the slotted arm of the slide 1101 in accordance with the component of target course and speed across the line of sight and, consequently, the slide 1101, as shown in Fig. 31, correspondingly displaces a pin which projects from a travelling nut 1475.

As was pointed out in connection with the target computer, while the target moves 110 along its course, the rate of change of azi-

muth varies inversely as the range, and this is just as true with regard to the battery computer. The explanation of the reason for this condition that was given in connection with the target computer is applicable to the analogous condition in the battery computer, it being remembered that instead of the azimuth being considered in connection with the reference point range PR, it is considered in connection with the relocated range GR.

To modify the operation of the mechanism of the battery computer in accordance with the inverse variance of the azimuth with respect to the relocated range, the shaft 1121, shown in Fig. 32, drives through a crown gear 1516 and a gear 1517 to turn a shaft 1518, which extends into Fig. 31. Here, the shaft 1518 drives through gears 1519, a shaft 1520, a worm 1521, a worm wheel 1522 and a shaft 1523 to turn the screw 1476. The traveling nut 1475 is consequently moved along the screw 1476, and, if, for example, the relocated range is increasing, the nut 1475 will travel to increase the distance between the center of its pin that slides in the slot of the arm 1478 and the center of the gear 1479. Thus, the angular displacement of the gear 1479 will be varied inversely as the relocated range. Obviously, the pinion 1480 and the gear 1481 will be turned correspondingly, so that the arm 1482 of the gear 1481 will shift the pin 1483, the arm 1484 and the ball-carrier 1485, so that the balls 1486 will be radially spaced from the center of the integrator disk 1487 inversely as the relocated range and directly as the component of target speed across the line of sight, the position of the balls representing the rate of change of azimuth of the relocated range.

The integrator disk 1487 is driven from the time-controlled power shaft 1107, shown in Fig. 30, through gears 1488, a shaft 1489, gears 1490, a shaft 1491, other gears 1492 and a shaft 1493, which extends into Fig. 31 and turns the disk 1487. Hence, the balls 1486 are set and driven in accordance with the rate of change of azimuth multiplied by time, which equals the change in azimuth of the relocated range, as is also the roller 1494 of the JZ' integrator. The roller 1494 drives through gears 1495, a shaft 1496, gears 1497 and a shaft 1498, which extends into Fig. 28, where it continues to drive through gears 1499, a shaft 1500, a gear 1501 and a crown gear 1502, so turning a shaft 1503, which enters Fig. 31. In the latter figure, the shaft 1503 drives through pairs of gears 1504 and 1505, which respectively turn shafts 1506 and 1507, both of which enter Fig. 27. In this figure, the shaft 1506 drives through gears 1508, which turn a shaft 1509 and a worm 1510 carried thereby. This worm turns a worm wheel 1511, which turns with a major ring dial 1512 that surrounds the computed azimuth dial 983, and which reads against the

fixed index 984 to show the coarse generated azimuth of the relocated range. The shaft 1507 turns a worm 1513, which turns a worm wheel 1514 and a minor ring dial 1515 to show a finer supplementary reading of the generated azimuth of the relocated range.

The ball carrier 1485 has a rate of change of azimuth slide 1524 rigidly combined with it, so that as the balls are set, a rack on the slide 1524 turns a pinion 1525, thus turning miter gears 1526, a shaft 1527, gears 1528, one side 1529' and the center 1529" of a differential 1529, so turning a shaft 1530 to operate a controller ZSC. A contact finger 1531 will be thrown to engage one of a pair of contacts, say the contact 1532.

Accordingly, current will flow from the positive line conductor 126, shown in Fig. 35, by a conductor 1533 to the contact finger 1531, passing to the contact 1532, there flowing by a conductor 1534 to a coil 1535 of a clutch ZSM, and proceeding by a conductor 1536, a brake coil 1537 of the clutch and conductors 1538 and 973 to the negative line conductor 134.

The now energized ZSM clutch Fig. 31, is driven from the power shaft 1109 and turns a shaft 1539, which drives through gears 1540, a shaft 1541 that enters Fig. 30, gears 1542 and a shaft 1543, which turns a screw 1544 in accordance with the rate of change of azimuth of the relocated range. The screw 1544 shifts a sleeve 1545, which is threaded onto it, this sleeve being provided with a pin 1546 that extends into a slotted arm 1547 of a multiplier.

Another factor is brought to this multiplier, as will now be explained. It has been shown that the clutch TFM, (see Fig. 33), drives through a shaft 1214, gears 1215 and a shaft 1216 that enters Fig. 32, in accordance with the time of flight. The shaft 1216 turns gears 1217 and a shaft 1218, the latter also driving through gears 1548 and a shaft 1549 to turn the center 1550" and a side 1550' to the measure of the time of flight.

The time interval handle TIL, shown in Fig. 27, is turned, thus turning the shaft 1222, which extends into Fig. 32, where the broad-face gear 1223, either as shown, or in its dotted position 1223", turns an azimuth gear 1551. This gear drives through a shaft 1552, gears 1553, gears 1554, a shaft 1555, other gears 1556, another shaft 1557, and miter gears 1558 to turn a pointer 1559, which shows by its movement the measure of the transmission interval, as it is being introduced into the battery computer. The side 1550" of the differential 1550 is operated simultaneously with the gears 1553, thus sending the measure of the transmission interval through the center 1550" and the side 1550' of the differential 1550.

The differential side 1550' has now been shown to be driven in accordance with the

time of flight plus the transmission interval, which sum carries through gears 1560, a shaft 1561, gears 1562, a shaft 1563, gears 1564, a shaft 1565, which passes through Fig. 31 and enters Fig. 30. There, the shaft 1565 drives through gears 1566, a shaft 1567, gears 1568, a shaft 1569, gears 1570 and a shaft 1571 that carries and turns a worm 1572. The worm 1572 turns a worm wheel 1573, thereby turning a shaft 1574 and a screw 1575. The latter is turned, as shown, in accordance with the time of flight plus the transmission interval, and shifts a traveling nut 1576 in accordance with this sum, the nut having a pin 1577 that enters the slot of the arm 1547. The angular displacement of the arm 1547 is equivalent to the rate of change of azimuth and this combined with the movement of the nut 1577 along screw 1575 in accordance with the sum of the time of flight and the transmission interval, is equal to azimuth prediction, and this is represented by the longitudinal displacement of a slide 1578.

Meshing with the slide 1578 is a pinion 1579 that is driven by a rack on the slide. Turning with the pinion 1579 are miter gears 1580, which drive a shaft 1581, gears 1582 and a shaft 1583 that enters Fig. 29. The shaft 1583, in this figure, drives through gears 1584, a shaft 1585, other gears 1586, another shaft 1587, gears 1588, one side 1589' and the center 1589" of a differential 1589, thus carrying the azimuth prediction to this point. The azimuth prediction added to the sum of the wind azimuth and the drift gives the target's deflection, and to show how this is obtained reference will now be had to Fig. 26, wherein a slide 1590 is actuated by the pin of the traveling nut 1512, which projects into the slotted arm of this slide, to set off the azimuth component of the wind. The slide 1590 carries a pin 1607 that enters a pivoted slotted arm 1608 of a multiplier, which further comprises a slide 1609 having a slotted cross bar 1610 provided with a slot 1611 in which is mounted a screw 1612, threaded upon which is a traveling nut 1613. This nut is provided with a pin 1614 that also enters the slot of the pivoted arm 1608, the nut being operable in accordance with the time of flight.

Thus, as has been previously shown, the time of flight clutch TFM, shown in Fig. 33, drives through a shaft 1214, gears 1215, a shaft 1216 that enters Fig. 32, gears 1217, a shaft 1218 that extends into Fig. 27, gears 1319, a shaft 1320, gears 1321, a shaft 1322, gears 1323, a shaft 1324, gears 1325 and a shaft 1326. The shaft 1326 turns gears 1615 and a shaft 1616 that enters Fig. 26 and turns a worm 1617 mounted thereon. The worm 1617 turns a worm wheel 1618, and a shaft 1619 to turn the screw 1611, thereby shifting the traveling nut 1613.

The pin 1607 thus acts on the slotted piv-

oted arm 1608 in accordance with the azimuth component of the wind, and the pin 1614 on the traveling nut 1613 also moves on the arm 1608 in response to the time of flight, thereby effecting a multiplication of these factors, the result being a movement of the slide 1609 which represents a correction due to the azimuth component of the wind, which is added to the set forward azimuth to give the predicted azimuth.

The slide 1609 is movable in response to the just described azimuth correction due to the azimuth component of the wind, and has a rack that turns a pinion 1620 and miter gears 1621. The gears 1621 drive through a shaft 1622, gears 1623 and a shaft 1624 that enters Fig. 27. In this figure, the shaft 1624 drives through gears 1625, one side 1626' and the center 1626" of a differential 1626, to turn a shaft 1627 in accordance with the azimuth correction due to the azimuth of the wind.

It has already been shown that the shaft 1322 turns in response to the time of flight, and this is proportional to the drift, so that the shaft 1322 may be regarded as driving through gears 1628, shown in Fig. 27, one side 1626'" and the center 1626"" of the differential 1626, to turn the shaft 1627 in response to the drift of the projectile. Hence the shaft 1627 is turned in response to the correction due to the azimuth component of the wind plus the drift.

This sum is carried through gears 1629 and a shaft 1630, which passes through Fig. 28 and into Fig. 29, where it drives through gears 1631, one side 1589'" and the center 1589"" of the differential 1589. Thus, the differential center 1589"" is turned in response to the wind azimuth correction plus the drift plus the predicted azimuth, that came through the differential side 1589', as before set forth, the sum equalling the target's deflection, a measure of which is given by a shaft 1632. This shaft drives through gears 1633 and 1634, and a shaft 1635, which enters Fig. 28, to operate an indicator 1636, which gives a reading of the target's deflection.

As shown in Fig. 29, the gear 1633 also turns another gear 1637, so turning one side 1638' and the center 1638" of a differential 1638, thereby turning a shaft 1639 in accordance with the target's deflection. This is added to the generated azimuth, as will now be explained.

The drive from the generated azimuth integrator JZ' to the generated azimuth dials 1512 and 1515, shown in Fig. 27, has already been described, and it includes a shaft 1503, shown in Fig. 28. To initially set up the target's azimuth on these generated azimuth dials, a handle GZL, shown in Fig. 28 is pushed in, disengaging the crown gear 1502 from the gear 1501, to effect the easy turning of the shaft while the generated azimuth dials are being turned to show the target's azi-

muth which is to be had from available information.

Thereafter, the shaft 1503 is power driven from the azimuth integrator JZ', and, as it turns, the shaft 1503 drives through gears 1640 shown in Fig. 28, thus turning a shaft 1641 which enters Fig. 29 and drives through sets of gears 1642 and 1643 so turning one side 1638''' and the center 1638'' of the differential 1638. This turns the shaft 1639 in response to the generated azimuth of the target; and this shaft was shown to be also turned in the measure of the target's deflection. Thus, the shaft 1639 turns in accordance with the sum of these values which is equal to the advance target's azimuth. In turning the shaft 1639 drives through gears 1644, one side 1645' and the center 1645'' of a differential 1645, so turning a shaft 1646 and thus operating a controller CZC to swing its contact finger 1647 into engagement with one of a pair of contacts, say the contact 1648.

There is then a responsive flow of current from the positive line conductor 126 (Fig. 35) by a conductor 1649 to the contact finger 1647, the current passing to the contact 1648 and going by a conductor 1650 to a coil 1651 of a clutch CZM, whence the current flows through a conductor 1652, the clutch brake coil 1653, and conductors 1654 and 973, to the negative line conductor 134.

Referring to Fig. 29, the now energized clutch CZM is driven from the power shaft 1107, through gears 1655 and a shaft 1656, the CZM clutch in turn driving through a shaft 1657, gears 1658, a shaft 1659, gears 1660, one side 1661' and the center 1661'' of a differential 1661, so turning a shaft 1662. The shaft 1662 drives through gears 1663, a shaft 1664, gears 1665 and 1666, a shaft 1667, gears 1668, another shaft 1669, other gears 1670, a shaft 1671, gears 1672, another shaft 1673, gears 1674 and a shaft 1675, which passes through Fig. 28 and enters Fig. 27. In the latter figure, the shaft 1675 drives through gears 1676, a shaft 1677, gears 1678, and a shaft 1679 which enters Fig. 26, where it drives through gears 1680, a shaft 1681, gears 1682, and a shaft 1683 to turn a worm 1684. This worm turns a worm wheel 1685 and a dial 1686, which reads against a fixed index 1687 to show a course reading of the corrected azimuth of the advance range from the battery G. The shaft 1681 also drives through spiral gears 1688 to turn a minor dial 1689 that gives a finer supplementary reading of the corrected azimuth of the advance range, when read against a fixed index 1690.

Simultaneously with the foregoing drive, the shaft 1659, shown in Fig. 29, also drives through gears 1691, one side 1645''' and the center 1645'' of the differential 1645, to cause the shaft 1646 to return the contact finger

1647 to its neutral position, when the corrected azimuth is shown by the dials 1686 and 1689.

During the above described drive, the shaft 1664, which extends from Fig. 29 into Fig. 30, turns the gears 1692, one side 1693' and the center 1693'' of a differential 1693, thus turning a shaft 1694 and operating a controller ZQC, to swing its contact finger 1695 into engagement with one of a pair of contacts, say the contact 1696.

Reference to Fig. 36 shows that current will then flow from the positive line conductor 126, by conductors 1400, 1697 and 1698, to the contact finger 1695, passing to the contact 1696, and proceeding by a conductor 1697, a post 1698, a conductor 1699, now closed contacts 1700, a conductor 1701, a post 1702, and a conductor 1703 to a coil 1704 of a clutch ZQM. From here the current continues by a conductor 1705, the brake coil 1706 of the clutch, and conductors 1707 and 1708 to the negative line conductor 134.

As will be understood from Fig. 30, the clutch ZQM will be driven from the power shaft 1107, through gears 1709 and a shaft 1710, this clutch in turn driving through a shaft 1711, gears 1712, another shaft 1713, gears 1714, a shaft 1715 and a screw 1716. Threaded onto the screw 1716 to travel longitudinally thereof is a carriage 1717, which is provided with a pencil or marker 1718, adapted to inscribe a graph of the corrected azimuth of the advance range on the record sheet 1424 of the battery computer. The power shaft 1107 drives through gears 1719 to turn a feed roller 1720. In general, the record sheet-feeding mechanism of the battery computer is similar to that of the target computer, and need not be further described, except to say that no protractors are used.

Attention is again directed to Fig. 29, where there is shown a handle ZCL, which is used to introduce an arbitrary correction in azimuth. This correction is determined by trial shots which, if they fall to the right or the left of the target, show the need of correction in the train of the gun. After the amount of this azimuth correction has been determined by trial, the ZCL handle is turned, so turning a shaft 1721. The shaft 1721 drives through gears 1722, a shaft 1723, gears 1724, another shaft 1725 and miter gears 1726, so turning an arbitrary azimuth correction dial 1727 to read against a fixed index 1728 to show when the proper amount of correction has been introduced into the instrument. At the same time, the shaft 1721 also turns the gears 1729, shown in Fig. 29, and one side 1661''' and the center 1661'' of the differential 1661, so turning the shaft 1662.

The arbitrary azimuth correction will, therefore, be transmitted through the gears 1663, the shaft 1664, gears 1665 and 1666, the

shaft 1667, gears 1668, the shaft 1669, the gears 1670, the shaft 1671, the gears 1672, the shaft 1673, gears 1674 and the shaft 1675 to the gears 1676, shown in Fig. 27. The 5 drive continues through the shaft 1677, gears 1678 and the shaft 1679 that turns the gears 1680, in Fig. 26. The gears 1680 turn the shaft 1681, causing the gears 1682, the shaft 1683, the worm 1684 and the worm wheel 1685 10 to reset the corrected azimuth dial 1606, by an amount equivalent to the arbitrary correction set by the handle ZCL. Meanwhile, the spiral gears 1688 correspondingly reset the minor corrected azimuth dial 1689, so that 15 both the dials 1606 and 1689 coact to give a reading of the final corrected azimuth, which is transmitted to the guns, which are trained in accordance therewith.

The shaft 1664, shown in Fig. 29, turns 20 with the measure of the final corrected azimuth, and, therefore, drives through the gears 1665 and 1730, a shaft 1731 and gears 1732, thus operating the transmitter 32. As shown in Fig. 2, the transmitter 32 communicates by the cable 33 with a gun train instrument 34, from the reading of which 25 the guns are trained.

It is also to be observed, that, in Fig. 29, the shaft 1664, now shown to include the 30 arbitrary azimuth correction as its measure of turning, extends into Fig. 30, there actuating the controller ZQC, so that it too will include the arbitrary azimuth correction. Since the clutch ZQM is operated under the 35 control of the ZQC controller, the shafts 1711, 1713 and 1715 will also include the arbitrary azimuth correction, and, hence, so will the movements of the screw 1716, the carriage 1717, and the azimuth pencil 1718.

40 The battery computer has now had its reference point range and the azimuth thereof synchronized with the same quantities as shown by the target computer. The battery computer has further had its base line P—G 45 properly set up in this instrument, in addition to which there have been initial settings in the battery computer for the initial velocity of the gun, the atmospheric conditions, the height of the gun, the velocity and 50 the direction of the wind, and the transmission interval.

The observing stations A and B, or substitutes therefor, continuously and automatically send data to the target computer and 55 the latter is adjusted to the magnitude of the problem, so as to deal with relatively high or low values, by the simple manipulation of the knob 103, shown in Fig. 21. This was hereinbefore demonstrated to suit the 60 target computer to the conditions of gunnery problems varying in magnitude, and it was shown that the transmitters 13a, 20 and 13b, related, respectively, to the A-station range AR, the reference point range PR and 65 the B-station range BR, are also adjusted to

low and high ranges. How these transmitters are suited to the different range conditions may be understood from Fig. 22, where-in one of the transmitters, as 20, for example, is diagrammatically shown.

A conductor 1733, shown in Fig. 22, from 70 a suitable source of electro-motive force is connected to a terminal lug 1734 of the transmitter, a conductor 1735 leading therefrom to a post 1736, or other suitable support that carries a brush 1737. The brush 1737 bears upon the periphery of a slip ring 1738, which is supported on, but insulated from, a shaft 1739. Conductors 1740 and 1741 electrically 75 connect the slip ring with quadrantal segments 1742 and 1743, respectively, which quadrantal segments variously engage brushes 1744, 1745 and 1746, which are mounted, respectively, on posts 1747, 1748 and 1749. Conductors 1750, 1751 and 1752 80 connect the posts 1747, 1748 and 1749 to terminal lugs 1753, 1754 and 1755, respectively. These associated elements constitute the long 85 range portion of the transmitter.

Also mounted on, but insulated from, the 90 shaft 1739 is a semi-circular segment 1756, which is electrically connected to the intermediate slip ring 1738 by a conductor 1757. Adapted to bear on the semi-circular segment 1756 in proper order are brushes 1758, 1759 and 1760, carried by posts 1761, 1762 and 1763, which are respectively connected by 95 conductors 1764, 1765 and 1766 to terminal lugs 1767, 1768 and 1769. The above elements which are associated with the semi-circular 100 segment 1756 form the short range portion of the transmitter.

Bearing on the terminal lugs 1769, 1767 and 105 1768 are the contact brushes 121', 122' and 123', as shown in Figs. 21 and 22. In the latter figure, the brushes 121', 122' and 123' are shown to have conductors 1770, 1771 and 1772 attached to them, and these conductors extend through the cable 21 to the receiver 110 motor 22 in the battery computer, as shown in Fig. 2, as well as in Figs. 4 and 28.

The shift mechanism, illustrated in Figs. 20 and 21, is shown to have been operated by the knob 103 to adjust the target computer to short ranges, and, therefore, each of the transmitters 13a, 20 and 13b will have its short range portion included in a circuit, that of the transmitter 20 extending to the battery computer, the circuit of the transmitter 13a going to the A station, and that of the transmitter 13b running to the B station.

The suiting of these transmitters to short 120 and long ranges will be readily understood from a comparison of the portions thereof that relate to the short and long range values. First considering the short range portions of one of the transmitters, as the transmitter 20, shown in Fig. 22, the semi-circular segment 1756 turns within and is borne upon at 125 suitable times by three equi-distant brushes 130

1758, 1759 and 1760, which may conveniently be spaced 120° apart, and the semi-circular segment 1756, in the illustrated embodiment of the invention, will be turned one complete 5 revolution to cause a given actuation of the receiver motor 22 in the battery computer.

In the long range portion of the same transmitter, there are two quadrantal segments 1742 and 1743, which, at proper times 10 are borne upon by three brushes 1744, 1745 and 1746, which are half the number of degrees apart that the short range brushes 1758, 1759 and 1760 are. That is, the short

15 range brushes are 120° apart, while the long range brushes are only 60° apart, and, therefore, during a single revolution of the shaft 1739, the long range transmitter portion, comprising the two quadrantal segments 1742 and 1743, and the three brushes 1744, 1745 and 1746, will make twice as many steps 20 as the low range portion, comprising the single semi-circular segment 1756 and the three brushes 1758, 1759 and 1760. Consequently, the receiver motor which is in circuit with the transmitter will drive twice as much for long ranges as for short ones. This is exactly the same ratio of change that 25 is obtained through the shifting mechanism shown in Figs. 20 and 21.

30 In the case of the transmitter 20, shown in Fig. 4, the cable 21 communicates with and actuates the receiver motor 22, shown in Fig. 28, which drives through gears 1087, a shaft 1088 and gears 1089, to drive the shaft 35 1063 which was initially actuated by the PRL handle, in accordance with the reference point range, as already described.

The reference point azimuth transmitter 17, shown in Fig. 4 is in electrical communication, through the cable 18, with the receiver motor 19, shown in Fig. 29, the motor 19 driving through gears 1773, a shaft 1774 and gears 1775 to turn the shaft 990. This shaft, as clearly set forth hereinbefore, 40 effects the operation of the PZ1C controller, and, hence, the PZM' clutch. This clutch acts to set the reference point azimuth pointers 988 and 989 (Fig. 28) to show the azimuth of the reference point range, on the 45 dials 950 and 953 of the battery computer. As already shown, the PZM' clutch also effects the reproduction of the azimuth of the relocated range in the mechanical simulation of the geographical triangle treated by 50 the battery computer.

The battery computer has also been shown to add in the previously enumerated ballistic corrections, and to furnish the final corrected range and the final corrected azimuth 55 hereof, for transmission to the battery for the direct setting of the guns, in accordance with the advance range. The target computer was also shown to transmit the target's course and speed to the battery computer, there setting the mechanical target's

course and speed vector, and mechanically resolving the components of this vector so that the rate of change of the relocated range is set up in the JR' integrator, the output of which represents generated relocated range, 70 and the rate of change of relocated azimuth is set up in the JZ' integrator, which gives the generated azimuth of the relocated range.

I claim:

1. In an artillery computing system, an instrument comprising a mechanical triangle having termini of a theoretical side thereof adjustable to be set and retained to the measure of a base line between a reference point and an observing station, and physically variable sides theoretically extending from the opposite termini of the base line respectively representing observing station and reference point ranges and converging at a point representative of a target. 75

2. In an artillery computing system, an instrument comprising a mechanical triangle having points spaced to represent the measure of a base line from a reference point to an observing station, mechanically variable sides representative respectively of observing station and reference point ranges, and a target-designating member adjustable along both of said variable triangle sides, 80 and means responsive to measures of a target's movements operable to shift said member in accordance with the observed and reference point ranges and the variable sides 85 in accordance with the azimuth thereof. 90

3. In an artillery computing system, an instrument comprising adjustable mechanical triangle-forming elements, a control switch adapted to be set in accordance with a geographical triangulation, receivers responsive to measures of a target's movements transmitted from a plurality of observing stations, electric circuits, operating means adapted to be energized and selectively included in circuit by said switch, and mechanism operable by the energized operating means to set the triangle-forming elements in accordance with observed and reference point ranges and the azimuth thereof. 100

4. In an artillery computing system, an instrument comprising adjustable mechanical triangle-forming elements, mechanism to maintain part of the resulting triangulation fixed in value, a control switch adapted to be selectively set in accordance with the range and azimuth of a target from one observing station or individually from a plurality of observing stations, and according to angles of a geographical triangulation, 105 receivers responsive to measures of a target's movements transmitted from the plurality of observing stations, electric circuits, operating means adapted to be energized and selectively included in circuit by said switch, 110 mechanism operable by the energized oper-

120

125

130

ating means to set the triangle-forming elements in accordance with observed and reference point ranges and the azimuth thereof, and means visualizing the values of said 5 ranges and their azimuth.

5. In an artillery computing system, an instrument comprising receivers responsive to measures of the range and azimuth of a target from different observing stations, 10 circuit-closers controlled by said receivers, a selective control switch having a plurality of circuit-establishing positions, operating devices adapted to be energized, electrical circuits some of which in one position of 15 said switch are closed by circuit-closers governed by measures of the target's azimuth which circuits energize different operating devices, and actuating means responsive to the energized operating devices to measure 20 the range and azimuth of the target from a reference point.

6. In an artillery computing system, an instrument comprising receivers responsive to measures of the range and azimuth of a target from different observing stations, 25 circuit-closers controlled by said receivers, a selective control switch having a plurality of circuit-establishing positions, electrical circuits some of which in one position of said 30 switch are closed by circuit-closers governed by measures of the target's range and azimuth from a single observing station which circuits energize different operating devices, and actuating means responsive to the energized operating devices to measure the range 35 and azimuth of the target from a reference point.

7. In an artillery computing system, observing station forming means and a reference point from which individual ranges are 40 adapted to extend to a target, an instrument related to the reference point and comprising a power supply, reference point range and azimuth determining elements operable 45 thereby including a reference point range evaluating member, means for determining observing station range and azimuth including an observing station range evaluating 50 member, and a target representing device operable by both of said members.

8. In an artillery computing system, an adjustable mechanical triangulation having elements operable according to a target's 55 range and azimuth, a mechanical vector representing the target's course and speed, setting means therefor, means for resolving said vector into the rate of change of range and into the deflection of the target, means to divide the deflection to secure the rate of 60 change of azimuth, and mechanism responsive to the determination of the rates of change of range and azimuth operable to generate the target's range and azimuth, and means responsive to said mechanism to operate said elements.

9. In an artillery computing system, means to generate a target's range and azimuth from a reference point, circuit-closers controlled by said means, a selective control switch having a plurality of circuit-establishing positions, electrical circuits some of which in one position of said switch are closed by said circuit-closers, operating devices in 70 circuit with said circuit-closers and adapted to be energized, and elements set by said operating devices to indicate the reference point range and azimuth of a target.

10. In an artillery computing system, means to generate a target's range and azimuth from a reference point, circuit-closers controlled by said means, a selective control switch having a plurality of circuit-establishing positions, electrical circuits some of which in one position of said switch are closed by said circuit-closers, operating devices in 75 circuit with said circuit-closers and adapted to be energized, elements set by said operating devices to indicate the reference point range and azimuth of a target, other circuit controllers adapted by the actuation of said 80 elements to close others of said circuits and actuating means responsive to the closure of the last named circuits to indicate the range and azimuth of the target from remote observing stations.

11. In an artillery computing system, means to generate a target's range and azimuth from a reference point, circuit-closers controlled by said means, a selective control switch having a plurality of circuit-establishing positions, electrical circuits some of which in one position of said switch are closed by said circuit-closers, operating devices in circuit with said 90 circuit-closers and adapted to be energized, elements set by said operating devices to indicate the reference point range and azimuth of a target, other circuit controllers adapted by the actuation of said 95 elements to close others of said circuits and actuating means responsive to the closure of the last named circuits to indicate the range and azimuth of the target from remote observing stations.

12. In an artillery computing system, means to generate the range and azimuth of a target and including variable speed mechanism, a plotting device operable to draw graphs of the range and azimuth and provided with members adapted to be positioned in conformity to the graphs, and means to adjust said variable speed mechanism in accordance with the positions of said members.

13. In an artillery computing system, an adjustable mechanical triangulation having elements operable according to a target's range and azimuth, a mechanical vector, means for setting said vector in accordance with the speed and course of the target, vector resolving means operable in proportion to the rate of change of range and the deflection components of the vector, means to secure 125

the rate of change of azimuth, variable speed mechanisms adjustable in accordance with the rates of change of range and azimuth and operating to generate the target's range and azimuth, and means responsive to said mechanisms to operate said elements.

14. In an artillery computing system, a mechanical vector comprising elements adapted to be set in accordance with the course and speed of a target, course and speed setting members, electric switches closed thereby during setting operations, circuit-closers, operating devices adapted to be energized, electrical circuits each including one of said switches, circuit-closers and operating devices, and actuating means responsive to said devices to operate said elements and set said mechanical vector.

15. In an artillery computing system, a mechanical vector comprising elements adapted to be set in accordance with the course and speed of a target, course and speed setting members, normally open electric switches adapted to be closed thereby upon actuation of said members, circuit-closers, operating devices adapted to be energized, electrical circuits which include said switches, circuit-closers and operating devices, and means responsive to said devices to operate said elements to set said mechanical vector and to visualize the target's course and speed.

16. An artillery computing system comprising computing mechanism operable in accordance with data received from a distant station to determine the range and azimuth of a target with respect to an arbitrary reference point that is distinguished from the location of artillery, and means responsive to said mechanism for relocating the range and azimuth of the target with respect to the location of the artillery.

17. An artillery computing system comprising computing mechanism operable in accordance with data received from a distant station to determine the range and azimuth of a target with respect to an arbitrary reference point that is distinguished from the location of artillery, means responsive to said mechanism for relocating the range and azimuth of the target with respect to the location of the artillery and means for correcting the relocated range and azimuth to give predicted range and azimuth.

18. An artillery computing system comprising a mechanical triangulation representative of a geographical triangulation between an arbitrary reference point that is distinguished from a gun position, observing stations and a movable target, said mechanical triangulation having parts positioned in accordance with base lines extending between the reference point and observing stations and elements settable according to reference point range, and means controlled in accordance with data of lines of sight from the observing stations to the target to operate said mechanical triangulation to set said elements to measure the range from the reference point to the target.

19. An artillery computing system comprising an adjustable mechanical triangulation representative of an alterable geographical triangulation formed by base lines extending between an arbitrary reference point that is distinguished from a battery station and observing stations and ranges extending therefrom to a movable target, means controllable from said observing stations to change the angularities of said mechanical triangulation in accordance with angular changes in the geographical triangulation, and mechanism related to a battery station and operative in response to changes in said mechanical triangulation to evaluate the range from a battery to the target.

20. An artillery computing system comprising adjustable triangle-forming computing mechanism related to an arbitrary reference point that is distinguished from a battery station, said computing mechanism being representative of a geographical triangle formed by a base line extending between the reference point and an observing station and by ranges from the point and station to a relatively movable target, means to primarily set said mechanism in accordance with such geographical triangle, operating means controlled in accordance with data received from the station adapted to operate the mechanism to measure reference point range, and other mechanism related to a battery station controlled by said computing mechanism to measure the range from a gun to the target.

21. An artillery computing system comprising computing mechanism related to a reference point in a geographical triangulation existing between the reference point, observing stations and a relatively movable target, said mechanism being operable in a selected manner, means operable in accordance with the target's movements as related to the observing stations to actuate said mechanism in accordance with the observed target's azimuth from different stations to indicate reference point range and the azimuth thereof.

22. An artillery computing system comprising computing mechanism related to a reference point in a geographical triangulation existing between the reference point, observing stations and a relatively movable target, said mechanism being operable in a selected manner, means operable in correspondence with the target's observed movement to actuate said mechanism in accordance with the target's range and the azimuth thereof from a single observing station to indicate the reference point range and the azimuth thereof.

23. An artillery computing system comprising computing mechanism related to a reference point in a geographical triangulation existing between the reference point, observing stations and a relatively movable target, said mechanism being operable in a selected manner and adapted to generate reference point range and its azimuth, means operable in accordance with the target's movements as related to the observing stations, selective means effecting the operation of said mechanism as related to one or more of the observing stations to compute reference point range and its azimuth, and means for substituting the generated reference point range and its azimuth for computed reference point range and the azimuth thereof.

24. An artillery computing system comprising computing mechanism related respectively to an arbitrary reference point that is distinguished from a battery station and to a battery station in a geographical triangulation formed by base lines extending between the reference point and the observing and battery stations and by ranges from the point and stations to a relatively movable target, the computing mechanism related to the point being responsive to observed movements of the target and having a reference point range-measuring element and the computing mechanism related to the battery station being actuated in accordance with the operation of said element and having an element to measure the range from a gun to the target.

25. In an artillery computing mechanism for use in connection with a geographical triangulation formed by base lines extending between an arbitrary reference point that is distinguished from a battery station and observing and battery stations and by ranges from the point and stations to a movable target, mechanism related to the reference point and operable in accordance with measures of a target's movements and adapted to compute reference point range, mechanism related to the battery station adapted to receive reference point range from the reference point computing mechanism and to compute range from a gun to the target, and having means to indicate a predicted range.

26. An artillery computing system for use in connection with a geographical triangulation existing between an arbitrary reference point that is distinguished from a battery station, observing stations, a battery station and a relatively movable target, computing mechanism related to the reference point and operable in accordance with measures of a target's movements and adapted to compute and generate reference point range, computing mechanism related to the battery station to which reference point range is transmitted from the reference point computing mecha-

nism and operable to compute and generate the range from a gun to the target.

27. An artillery computing system for use in connection with target-movement measurements at observing stations and comprising computing mechanism related to an arbitrary reference point that is distinguished from a gun position and removed from the observing stations, and means operable in accordance with the measured movements of the target controlling the operation of part of said computing mechanism to disclose the range and azimuth of a target from the observing stations, parts of said mechanism being operable to compute and generate the reference point range and its azimuth. 70 75 80

28. An artillery computing system for use in connection with target-movement measurements at observing stations and comprising a computing instrument related to an arbitrary reference point that is distinguished from a gun position, said instrument being operable under different controls, means operable according to the target-movement measurements for operating part of said computing mechanism in response to observed range of a target from one or more of the observing stations, parts of said mechanism being operable to compute and generate the reference point range and its azimuth and means to selectively operate said computing instrument. 85 90 95

29. In an artillery computing system, means at an arbitrary reference point that is distinguished from a battery station including elements for actuation in accordance with measures of a target's movements and operable to determine the reference point range to a target, and computing mechanism at a battery station receptive of measures of reference point range from the means at the reference point and having elements adjustable in accordance therewith to give relocated range from the battery station to the target. 100 105 110

30. In an artillery computing system, means related to an arbitrary reference point that is distinguished from a battery station and operable to determine the reference point range to a target and its azimuth, and computing mechanism related to a battery station responsive to reference point range and its azimuth transmitted from the reference point to determine the target's relocated range from the battery station and its azimuth. 115 120

31. In an artillery computing system, means related to an arbitrary reference point that is distinguished from a battery station and operable to determine the reference point range to a movable target and its azimuth, and computing mechanism related to a battery station responsive to reference point range and its azimuth transmitted from the means related to the refer- 125 130

ence point and operable to determine the target's relocated range from the battery station and its azimuth, said mechanism being operable to correct the relocated range for the 5 target's deflection.

32. In an artillery computing system, means related to an arbitrary reference point that is distinguished from a battery station to receive remotely observed target's range 10 and its azimuth, measure the target's course and speed and operable to determine a target's reference point range and its azimuth, and computing mechanism related to a battery station responsive to said means 15 proportionately to measures of reference point range and its azimuth and operable to determine relocated range from the battery station to the target and its azimuth.

33. In an artillery computing system, 20 mechanism related to a battery station including an adjustable mechanical triangle representative of a geographical triangle formed by a base line extending between an arbitrary reference point distinguished from 25 a battery station and the battery station and by ranges from the point and station to a relatively movable target, means to set one side of the mechanical triangle in accordance with the geographical base line, and means 30 related to the reference point to determine the target's reference point range and its azimuth, said mechanical triangle becoming set in accordance therewith and to indicate the target's range and azimuth as relocated 35 at the battery station.

34. In an artillery computing system, 40 mathematical mechanism related to a battery station having a portion adapted to be set in accordance with the length and azimuth of a base line extending between an arbitrary reference point that is distinguished from a battery station and the battery station, and means related to the reference point operable 45 to determine and transmit to said mathematical mechanism the target's range and azimuth from the reference point, said mathematical mechanism being operable to determine the target's range and azimuth as relocated at the battery station.

35. In an artillery computing system, 50 means related to an arbitrary reference point that is distinguished from a battery station, said means being operable to determine the target's range and azimuth from the reference point, and mathematical mechanism related to a battery station responsive to said means and operable to reproduce the target's 55 reference point range and its azimuth, said mechanism being actuated to establish the target's range and azimuth as relocated at the battery station and to correct the relocated range to give a predicted range and its azimuth.

36. In an artillery computing system, 60 means related to an arbitrary reference point

that is distinguished from a battery station, said means being operable to determine a movable target's range and azimuth from the reference point, and mathematical mechanism related to a battery station responsive to said means and operable to reproduce the target's reference point range and azimuth, 70 said mechanism being actuated to establish the target's range and azimuth as relocated at the battery station and to correct the relocated range to give a predicted range and its azimuth, there being means to indicate the target's deflection. 75

37. In an artillery computing system, 80 means related to an arbitrary reference point that is distinguished from a battery station, said means being operable to determine movable target's range and azimuth from the reference point, and mathematical mechanism related to a battery station responsive to said means and operable to reproduce the target's reference point range and azimuth, 85 said mechanism being actuated to establish the target's range and azimuth as relocated at the battery station and to correct the relocated range to give a predicted range and its azimuth, means to additionally correct the last named range and azimuth for other influences, there being means to indicate the angular measure of the correction. 90

38. In an artillery computing system, 95 means related to an arbitrary reference point that is distinguished from a battery station, said means being operable to determine the target's range and azimuth from the reference point, and mathematical mechanism related to a battery station responsive to said means and operable to reproduce the target's reference point range and azimuth, 100 said mechanism being actuated to compute and generate the target's range and azimuth as relocated at the battery station. 105

39. In an artillery computing system, 110 means related to an arbitrary reference point that is distinguished from a battery station, said means being operable to determine the target's range and azimuth from the reference point, and mathematical mechanism related to a battery station responsive to said means and operable to reproduce the target's reference point range and azimuth, 115 said mechanism being actuated to compute and generate the target's range and azimuth as relocated at the battery station and to correct the relocated range to give a predicted 120 range and its azimuth.

40. In an artillery computing system, 125 means related to an arbitrary reference point that is distinguished from a battery station, said means being operable to determine the target's range and azimuth from the reference point, and mathematical mechanism related to a battery station responsive to measures of reference point range and azimuth transmitted from said means and oper- 130

able to determine and record the target's range and azimuth as relocated at the battery station.

41. In an artillery computing system, a battery mathematical mechanism operable in response to transmissions of the range and azimuth of a target from a reference point to measure the target's range and azimuth as relocated at a battery station, and comprising predicting means operable to determine a movable target's corrected relocated range and azimuth from a gun in accordance with the algebraic sum of an interval of transmission of directive information to the gun and 15 the time of flight of a projectile from the gun to the target.

42. In an artillery computing system, a battery mathematical mechanism operable in response to transmissions of the range and azimuth of a movable target from a reference point to measure the target's range and azimuth as relocated at a battery station, said mechanism including means for correcting the relocated range to give a predicted range 25 and its azimuth and an arbitrary correction for the predicted range.

43. In an artillery computing system, a mathematical mechanism related to a battery station operable in response to transmissions of a movable target's reference point range and azimuth and comprising means to measure the target's range and azimuth as relocated at the battery station, correcting elements to establish the target's predicted 30 range and azimuth from its relocated range and azimuth, and arbitrary correcting means for the predicted range and azimuth.

44. In an artillery computing system, a mathematical mechanism related to a battery station operable in response to transmissions of a movable target's reference point range and azimuth and comprising means to measure the target's range and azimuth as relocated at the battery station, and means to 40 correct the target's relocated range and azimuth including a correction for the effect of the height of a gun.

45. In an artillery computing system, a mathematical mechanism related to a battery station operable in response to transmissions of a movable target's reference point and range and comprising means to measure the target's range and azimuth as relocated at the battery station, and means to correct the 50 target's relocated range and azimuth including a correction for the effect of the atmosphere on the projectile of a gun.

46. In an artillery computing system, a mathematical mechanism related to a battery station operable in response to transmissions of a movable target's reference point and range and comprising means to measure the target's range and azimuth as relocated at the battery station, and means to correct the target's relocated range including a correction 55

for the initial velocity of the projectile of a gun.

47. In an artillery computing system, a mathematical mechanism related to a battery station operable in response to transmissions of a movable target's reference point range and azimuth and comprising means to measure the target's range and azimuth as relocated at the battery stations, and means to correct the target's relocated range and azimuth including a correction for the effect of the wind on the projectile of a gun. 75

48. In an artillery computing system, a mathematical mechanism related to a battery station operable in response to transmissions of a movable target's reference point range and azimuth and comprising means to measure the target's range and azimuth as relocated at the battery station, and means to correct the target's relocated range and azimuth including corrections for the effect on the projectile of a gun of the height of the gun, the atmosphere, the initial velocity of the projectile and the wind. 80

49. In an artillery computing system, means associated with a reference point in a geographical triangulation existing between this point, observing stations and a target, said means being responsive to measures of observed range and its azimuth and including an adjustable physical triangulation movable in accordance with changes in the geographical triangulation and reference point range and its azimuth, means to evaluate the elements of the geographical triangulation, and shifting means to adjust the evaluating elements in accordance with the magnitude of the geographical triangulation. 90

50. In an artillery computing system, means associated with an arbitrary reference point that is distinguished from a battery station, said point being located in a geographical triangulation existing between this point, observing stations and a target, said means being responsive to measures of observed range and its azimuth and including an adjustable physical triangulation movable in accordance with changes in the geographical triangulation and reference point range and its azimuth, means to evaluate the elements of the geographical triangulation, and means related to a battery station responsive to the means associated with the reference point and operable to establish the range from a gun to the target and the azimuth of that range. 105

51. An artillery computing system comprising elements operable to reproduce the conditions of geographical triangulations which exist between an arbitrary reference point that is distinguished from a battery station, observing stations, a target and a battery station, said elements being arranged to relate the reproduced triangulations to a common base line, certain of said elements 115

being adjusted to determine the range and azimuth of the target with respect to the reference point, and means operating in accordance therewith adjusting others of said elements in accordance with the range and azimuth of the target as relocated with respect to artillery.

52. An artillery computing system comprising elements operable to reproduce the conditions of geographical triangulations existing between an arbitrary reference point that is distinguished from a battery station, observing stations, a target and a battery station, said elements being arranged to relate the reproduced triangulations to a common base line, certain of said elements being adjusted to determine the range and azimuth of the target with respect to the reference point, means operating in accordance therewith adjusting others of said elements in accordance with the range and azimuth of the target as relocated with respect to artillery, and modifying mechanism correcting the relocated range and azimuth to give a predicted range and its azimuth.

53. Artillery computing apparatus comprising a mechanical triangulation representative of a geographical triangulation and having operable linearly extending range-measuring elements pivoted about axes representative of observing stations and a reference point that is removed therefrom and distinguished from a gun position, target representing means pivotally connecting co-acting range-measuring elements, said co-acting elements having positive operating connections to said target representing means, and actuating means for the individual elements operable in accordance with changes in the geographical triangulation.

54. Artillery computing apparatus comprising a mechanical triangulation representative of a geographical triangulation and having crossing arms pivoted about axes representative of observing stations and a reference point that is removed therefrom and distinguished from a gun position, range screws mounted in the respective arms, target representing means pivotally combining co-acting range screws and provided with connected swivelling portions individually operable by the range screws of individual arms, and actuating means operable to position said arms according to the observed azimuths of a target from the represented observing stations and to operate said range screws according to evaluated ranges therefrom, whereby the target representing means are positioned in accordance with the position of the target.

55. An artillery computing system comprising a mechanical triangulation having adjustable converging elements pivoted about axes positioned to set off at a reduced scale the disposition and extent of base lines ex-

tending between observing stations and an arbitrary reference point, target representing means pivotally connecting the converging elements, actuating means operable to position the elements pivoted about the axes representative of the observing stations and the reference point respectively in accordance with the range and azimuth from the observing stations and the range and azimuth from the reference point that is distinguished from observing stations and a battery station, and a second mechanical triangulation controlled from the first triangulation in accordance with reference point range and its azimuth as established thereby and having an element consequently set in accordance with the range and its azimuth from a battery station.

56. Artillery computing apparatus comprising longitudinally extending converging elements each provided with means for measuring a different range, said elements being pivotally mounted about axes representative of an observing station and an arbitrary reference point that is distinguished from a gun position, adjusting means for relatively positioning the pivotal mountings of said elements to cause the axes thereof to set off a measure of a selected base line extending between the represented reference point and observing station, target representing means pivotally connecting said elements and mounted to slide longitudinally of both said elements, and actuating means operable to concomitantly operate said range-measuring means of said elements to displace said target representing means and to position one of said elements in accordance with the range and azimuth of a target from the reference point.

57. Artillery computing apparatus comprising a mechanical triangulation having longitudinally extending converging elements each provided with range-measuring means, said elements being pivotally mounted about axes located in correspondence to observing stations and an arbitrary reference point that is distinguished from a gun position, and to representingly define base lines extending between such stations and reference point, target representing means pivotally connecting the converging elements and controlled by said range-measuring means, actuating means for operating said range-measuring means and elements respectively in accordance with the range and its azimuth from the respective observing stations to a target and in accordance with a consequent range and its azimuth from the reference point to the target, and selective means operable to combine portions of said actuating means to control the mechanical triangulation according to changes in the range and azimuth as transpiring at either or both observing stations.

58. Artillery computing apparatus comprising an adjustable triangle-forming computing mechanism provided with angularly displaceable elements having normally fixed fulcrums at one end of each, said fulcrums being relatively adjustable in accordance with selectable base lines between observing stations and a point of reference, and target representing means pivotally connecting said elements beyond their fulcrums and being slideable along said elements, means to primarily set different elements of said mechanism in accordance with a geographical triangulation that includes the observing sta-

10 tions, point of reference and a movable target, and actuating means operable to alter said triangle-forming elements to correspond to changes in the geographical triangulation.

59. Artillery computing apparatus comprising an adjustable mechanical triangulation having a plurality of range-measuring elements settable in accordance with ranges to a movable target from a plurality of geographical locations, said elements being pivotally mounted about axes disposed to measure base lines between said locations, means indicative of a target under the joint control of the elements that are pivoted about certain of the axes that are at different locations pivotally connecting such elements, said target-indicating means being displaceable thereby, actuating means operable according to changes in the range from different geographical locations to the target and the azimuth of such ranges, said last named means actuating part of said range-measuring elements proportionately to such changes, and effecting a consequent axial and range-measuring operation of the remainder of said 40 elements proportionately to the range of the target from another of said geographical locations and the azimuth of the last named range.

60. Artillery computing apparatus comprising longitudinally extending converging elements pivoted about normally fixed axes and being mutually connected pivotally to be displaceable to vary their convergence and their lengths between said pivotal axes and their mutual pivotal connection, said elements, their pivotal axes and mutual connection being disposed to form sides, adjacent angles and a point representative of a geographical triangulation containing a target, observing stations and an arbitrary reference point that is distinguished from a gun position, selectively operable actuating means therefor, and a selective control for operating said actuating means in accordance with the relative values of adjacent geographical angles at the target.

61. Artillery computing apparatus comprising mechanically operated electric controllers operable in accordance with a target's movements as determined from observing sta-

tions, electrical operating devices governed by said controllers, other electric controllers actuated in response to said operating devices, an adjustable mechanical triangulation comprising elements adapted to be positioned in accordance with the sides and angles of a geographical triangulation containing observing stations, a target and a reference point that is distinguished from the observing stations and a gun position, and operating mechanism from the second named controllers to adjust said mechanical triangulation to correspond to the geographical triangulation.

62. Artillery computing apparatus comprising converging members provided with normally fixed pivotal axes and means for turning the same thereabout proportionately to measures of azimuth as related to separated points, range screws mounted on said members, means for concurrently revolving said range screws proportionately to distances from said points to a single movable object, separately formed travelling elements each displaceably mounted on a single one of said members to be displaceable longitudinally thereof and being pivotally united to pivotally connect said members, said elements having threaded connections to the range screws on the members with respect to which the respective elements are displaceable.

63. Artillery computing apparatus comprising data-introducing means for operation proportionately to a target's movements as related to a point remote from the apparatus, and computing mechanism partly operable in response to the operation of said data-introducing means to compute the range from a reference point to the target and the azimuth of that range, said mechanism including means to determine the target's course.

64. Artillery computing apparatus comprising data-introducing means for operation proportionately to a target's movements as determined at a point remote from the apparatus, and computing mechanism partly operable in response to the operation of said data-introducing means to compute the target's range from a reference point and the azimuth thereof, said mechanism including means to determine the target's course and speed.

65. Artillery computing apparatus comprising data-introducing means for operation proportionately to a target's movements as related to an observing station, and computing mechanism including a mechanical triangulation having sides adjustably pivoted at a target-representing vertex thereof, said sides being angularly displaceable about normally fixed individual pivoting means, and means to relatively set said individual pivoting means to define another

- side of said triangulation in representation of a base line extending between the observing station and a reference point, said mechanism being responsive to said data-introducing means to set the first named sides in accordance with ranges from the observing station and reference point to a relatively movable target. 66. An artillery computing system comprising data-introducing means for operation proportionately to a target's movements as related to different observing stations, and computing mechanism comprising a plurality of adjustable mechanical triangulations, means to set one side of each of said triangulations to the measure of a base line from an arbitrary reference point to one of the different observing stations, said mechanism being responsive to said data-introducing means to set another side of each triangulation to represent the range of a target from the different observing stations, and to set another side in each of said mechanical triangulations to the measure of the reference point to the target. 67. Artillery computing apparatus comprising linearly and angularly displaceable elements settable to the measure and azimuth of base lines which extend between an arbitrary reference point and different observing stations, data-introducing means for operation in accordance with a target's movements as related to the observing stations, mechanism responsive to said means to indicate the observed ranges of a target and the azimuth thereof, and means co-acting with said elements to compute a target's range and azimuth from the reference point. 68. Artillery computing apparatus comprising data-introducing means for operation proportionately to a target's movements as related to different observing stations, and computing mechanism provided with means adapted to be set to the measure and azimuth of base lines between a reference point and the observing stations, said mechanism being responsive to said data-introducing means and operable to compute and indicate the observed ranges of a target and the azimuth thereof, co-acting elements operable to determine the course and speed of the target, and means including variable speed mechanism actuated to generate the reference point range to the target and its azimuth. 69. Artillery computing apparatus comprising data-introducing means for operation proportionately to a target's movements as related to different observing stations, and computing mechanism comprising elements selectively operable in accordance with the angularities of a geographical triangulation formed by fixed base lines between an arbitrary reference point and the observing stations and by ranges from the point and stations to a movable target, controls for select- ing the co-operative relationship of said elements, said mechanism being operable to be set to the measure and azimuth of the base lines, and being responsive to said data-introducing means to indicate the observed ranges and the azimuth thereof and operable to determine the reference point range to the target and its azimuth. 70. Artillery computing apparatus comprising data-introducing means for operation proportionately to a target's movements as related to observing stations, and computing mechanism responsive to said data-introducing means and operable to measure the observed range from the stations to a movable target, said mechanism including means to compute and generate the range from a reference point to a target, and shifting mechanism to adjust said computing mechanism to higher and lower ranges. 71. Artillery computing apparatus comprising computing mechanism having parts for adjustment according to the ranges of a target from observing stations and a reference point and the azimuth of those ranges, actuating means therefor for operation proportionately to changes in the named ranges and the azimuth thereof, generating mechanism operable to generate the same ranges and the azimuth thereof, means controlled by said computing and generating mechanisms to indicate the relationship of the computed and generated ranges and the azimuth of each, said computing mechanism being initially settable to the observed and reference point ranges and the azimuth thereof. 72. In an artillery computing apparatus, computing mechanism operable in accordance with a target's observed position to determine its position from an arbitrary location removed from where the target is observed, co-acting elements for indicating the target's position as related to the arbitrary location, rate-multiplying target position generating mechanisms controlling said elements, and adjusting means for said generating mechanisms operable to set the same in accordance with rates of change of components of the target's travel. 73. In an artillery computing apparatus, computing mechanism operable in accordance with a target's observed position to determine its position from an arbitrary location removed from where the target is observed, co-acting elements for indicating the target's position as related to the arbitrary location, rate-multiplying target position generating mechanisms controlling said elements, adjusting means for said generating mechanisms operable to set the same in accordance with rates of change of components of the target's travel, and means to interrupt the control of said elements by said generating mechanism and to set said elements and mechanisms at will.

74. In an artillery computing apparatus, computing mechanism comprising means for operation in accordance with a target's observed position, angularly and linearly adjustable co-acting elements responsive thereto and in part adapted to be consequently positioned according to the relation of the target to an arbitrary location removed from where the target is observed, rate-multiplying target position generating mechanisms, operating means from said generating mechanisms to said part of the co-acting elements that relate the target and arbitrary location, and target position indicating means concomitantly actuated therewith.

75. In an artillery computing apparatus, mechanism including correlated elements adjustable in accordance with changes in the range of a target from a given location and the azimuth of that range, variably operable generating mechanisms operatively connected to said first named mechanism and respectively operable according to the range of the target from the mentioned location and the azimuth thereof, a mechanical target's course and speed vector, vector-resolving means having component-measuring elements displaceable according to the target's range and deflection, adjusting connections from said resolving means to said generating mechanisms to vary the operation thereof, and means responsive to the range generating mechanism co-acting with the element displaceable according to the target's deflection to actuate the adjusting connection to said azimuth generating mechanism according to the target's deflection divided by the generated range.

76. In an artillery computing apparatus, computing mechanism comprising elements adjustable in accordance with measures of a target's range and the azimuth thereof from a plurality of locations, a plurality of independently operable controlling means for the elements that measure the target's range and its azimuth with respect to different locations, including range and azimuth generating mechanisms governing certain of said elements that effect the measures with respect to one of the locations, a target's mechanical course and speed vector, vector-resolving means therefor controlling said generating mechanisms, and selecting means for variably relating said controlling means to selectively directly control certain of said elements and effect a consequent positioning of others thereof.

In testimony whereof I affix my signature.
HANNIBAL C. FORD.
